UNITED STATES PATENT OFFICE.

ALEXANDER E. KEITH, OF CHICAGO, ILLINOIS, ASSIGNOR, BY MESNE ASSIGNMENTS, TO AUTOMATIC ELECTRIC COMPANY, A CORPORATION OF ILLINOIS.

TELEPHONE SYSTEM AND APPARATUS.

1,307,977.

Specification of Letters Patent. Patented June 24, 1919.

Application filed April 12, 1906. Serial No. 311,327.

To all whom it may concern:

Be it known that I, ALEXANDER E. KEITH, a citizen of the United States of America, and resident of Chicago, Cook county, Illinois, have invented a certain new and useful Improvement in Telephone Systems and Apparatus, of which the following is a specification.

My invention relates to automatic or semi-automatic telephone systems in general. It relates more particularly to automatic or semi-automatic telephone systems in which either part or all of the exchange switching apparatus is controllable and operable by the subscribers through the medium of make-and-break or impulse-transmitting devices located at the subscribers' sub-stations. Telephone switching machinery for this purpose is ordinarily operated on the step-by-step principle. Consequently, the calling subscriber obtains the desired connection by simply transmitting electrical current impulses corresponding to the digits of the number of the called subscriber's sub-station, provided the exchange be of the full automatic type. If only semi-automatic in character only part of the general operation of connecting up the two subscribers' lines will be accomplished directly by the calling subscriber.

Generally stated, the object of my invention is the provision of an improved and highly efficient automatic or semi-automatic telephone exchange system.

Special objects of my invention are the provision of improved automatic switching machinery for the exchange or central station; the provision of improved individual switches for the subscribers' lines—that is to say, switches each of which is individual to a subscriber's telephone line and adapted to be employed by the subscriber for performing a trunking operation preliminary to the trunking operation or operations which correspond to the first digit of the called number; the provision of an improved construction and arrangement whereby an automatic telephone system may be divided into a main or central exchange, a plurality of auxiliary or sub-exchange stations connected by trunk-line cables with the main or central station, and a plurality of subscribers' sub-stations connected by individual telephone lines with the said auxiliary or sub-exchange stations; and the provision of certain details and features of

improvement tending to increase the general efficiency and serviceability of a telephone system of this particular character.

In certain respects it will be seen that my invention is in the nature of an improvement on the telephone system disclosed in my prior application, Serial No. 229,373, filed in the United States Patent Office October 21, 1904. Also, in certain respects it will be seen that my invention is in the nature of an improvement on the individual-switch and system set forth in my prior application, Serial No. 258,026, filed in the United States Patent Office April 29, 1905.

It will also be understood, of course, that it is an object of my invention, as will hereinafter more fully appear, to provide certain novel combinations and circuit arrangements tending to increase the efficiency of a telephone system.

To the foregoing and other useful ends my invention consists in matters hereinafter set forth and claimed.

In the accompanying drawings, Figure 1 is a top plan view of one of the individual-switches secured to an angle-iron perpendicularly disposed to form a switch-supporting rack-board or unit. In front of each switch there is provided a bank of trunk-line terminals, the structure of which is shown in cross-section in Figs. 2 and 3. Over said bank the said switch exercises control through the medium of a forwardly-extending arm which pivotally supports a circuit-closing plunger.

Fig. 4 is an enlarged view of the bank-engaging terminal of the plunger.

Figs. 5, 6, 7, 8 and 9 are details of the bank.

Fig. 2, as stated, is a section of bank and is taken on the line 2—2 of the bank shown in Fig. 1. The bank-springs are shown disengaged, and the plunger just at the point of entering into the bank, which plunger (in Fig. 3) is shown driven home, having thus seized a trunk-line.

Fig. 10 shows a top view of the master-switch or switch-operating machine secured to one of the angle-irons of the board structure, and discloses a step-by-step operative device comprising a pawl and ratchet wheel, together with a cam, wiper and bank of contacts.

Fig. 11 is a section on the line 11—11 of Fig. 10 showing the structure of the bank and wiper.

Fig. 12 shows the position of the interrupter-springs of the master-switch when the armature of the interrupter-magnet is attracted.

Fig. 13 gives an idea of the relative arrangement of the individual-switch and controlling master-switch mounted upon the structural angle-irons, and showing the common or plunger-shaft, at the upper end of which latter appear the bank-terminals which the master-switch-wiper engages.

Fig. 14 is a diagrammatic representation of the circuits of the master-switch and individual-switch shown in Fig. 13, together with a sufficient number of the most important mechanical details to make the diagram clear. In this figure only the first set of bank-springs are given, but it will be understood that nine other sets in addition combine to form one bank, and that corresponding common springs of corresponding positions of the same group of banks are connected in multiple, which springs will be designated hereinafter.

Fig. 15 is a simplified diagram of certain circuits common to the individual-switches and master-switch of the same group, which will be explained hereinafter.

Fig. 16 is a modification of the master-switch-bank and corresponding circuits.

Fig. 17 is a diagrammatic perspective representation of the central office automatic selector-switch known as the first-selector.

Fig. 18 is a similar view of a switch known as the second-selector.

Fig. 19 is a similar drawing of the connecting switch known as the connector.

Figs. 20, 21 and 22 represent diagrammatically a calling sub-station #1122 connected with a called substation #2211, through the medium of the individual switch A of the calling line (which, like all other switches, draws current from the central battery B), the repeater C, first-selector D, second-selector E, repeater C¹, connector F and individual-switch A¹ of the called line.

In Fig. 21 the central battery B is shown with its positive terminal preferably grounded at G, and in Fig. 20 the master-switch associated with the individual-switches of the group to which the individual-switch A belongs is shown at H.

Figs. 23, 24, 25, 26 and 27, like Figs. 20, 21 and 22, show the sub-station #1122 connected with the substation #2211, and represent diagrammatically the distribution of the switches and illustrate more minutely the trunking arrangement. For instance, Figs. 23 and 24 taken together represent individual and connector switches of the 1100-board to which the subscriber #1122 belongs, and among which are the individual-switches A and I, and show repeaters c¹ which, like the repeater C, are terminals of

the trunk-lines leading to the first-selectors. Fig. 25 represents first-selectors of the first hundred of the first thousand, among which are the first-selectors D and J, and the first-selectors of the first hundred of the second thousand, among which are the first-selectors K and L, and shows how the banks of all of the first hundred first-selectors of the different thousands are connected. Fig. 26 shows the second-selectors of the first hundred of the first and second thousands, among the latter of which are the second-selectors E and M, and among the former the second-selectors N and O; shows repeaters c² which, like the repeater C¹, are controlled by all the second-selectors of the second thousand when their wipers are raised to the second bank level, and which are terminals from which outgoing trunk-lines lead to the connectors of the twenty-second hundred group of subscribers; and shows the repeaters C² that are used by all the second-selectors of the first thousand when their wipers are raised to the second bank level, from which outgoing trunks lead to connectors of the twelfth hundred set of subscribers. Fig. 27 shows the connectors of the twenty-second hundred group of subscribers, among which are the connectors F and P, together with individual-switches of the same hundred, among which are the individual-switches A¹ and A², and also shows the subscribers' lines leading to subscribers of the said group, among which is the subscriber #2211.

Fig. 28 shows more generally the relative arrangement of the different units in the system and sub-stations and the trunking arrangement.

Fig. 29 shows diagrammatically two sub-stations connected through switches, all of which are located at the central station, the connection not including second-selectors nor repeaters but only an individual-switch, a connector and a second individual-switch.

Fig. 30 shows a trunking or auxiliary station located on a pole-top.

Fig. 31 shows a similar station in a man-hole.

Figs. 32 and 33 are plan and topographical views, respectively, of a section of a town or city illustrating a distribution of the sub-exchanges or trunking stations.

The individual-switch, as shown in Fig. 1, is built about a metallic base or frame 2 and comprises a plunger 3 and plunger-arm 4. It is also equipped with a bridge-cut-off-relay 5, a trip-magnet 6, and switch-release-magnet 7. A section of the metal from the central portion of the frame is removed to make the structure as light as possible, while another section of the same portion is turned up at right angles to the base of the frame to form a lug or flange 8 upon which the said switch-release-magnet is mounted. Said flange has stamped through it a cou-

ple of circular holes 9 (Fig. 13) through which the ends of the cores 10 are passed to maintain the coils of the said release-magnet parallel with the base of the frame. In this position they are retained by a locking U-shaped collar 11 between the faces of which the magnet supporting flange extends and which collar has four openings, two on each of the parallel faces, and arranged to form two tandem sets through which the cores of the switch-release-magnets also pass, as shown. After the magnets are inserted in position they are then tightened in place by a shearing action produced upon the said cores of the switch-releasing-magnets between the flange and the capping collar, by means of a screw 12 that passes through a threaded portion on the said collar, the end of which screw is forced onto the upper edge of the magnet supporting flange 8. The said switch-release-magnet is provided with an armature 13 that is pivoted on a pin 14 which rises from the base of the switch. This armature is held normally away from the pole-pieces by any suitable spring 15. The said armature carries pivotally secured on its end a second armature 16 that is controlled by the trip-magnet 6 and which is normally held away from the pole-pieces of said trip-magnet by any suitable spring 17. The pin 18 about which the armature 16 oscillates is carried on the end of the armature 13. The plunger 3 is pivotally secured by the pin 19 to the plunger-arm 4, which latter is in turn pivoted to a pin 20 that rises from the switch-frame 2. Upon the angle-irons 21 and 22 the switches are mounted, and the banks as well. For instance, the bank Q which the individual-switch A controls is mounted upon a base 23 and secured to the angle-irons 21 and 22 by screws 24 and sustained in a position midway between the two said supports 21 and 22. Normally, the plunger 3 is retained out of engagement with the bank Q, as shown in Fig. 2, and in engagement with the plunger controlling shaft 25 that is operated by the master-switch or switch-operating machine H of the group to which the individual-switch A belongs—and to which further reference will be made—by a suitably constructed catch-piece 26 permanently secured upon the end of the armature 16 that normally engages the rear end of the plunger-arm 4, as shown. The force that causes the plunger 3 to be thrust into the bank Q whenever the catch 26 is disengaged from the plunger-arm 4 is supplied by a spring 27 one end of which is secured to the base upon the flange 8, while the other end is latched in any suitable manner to the rear end of the plunger-arm 4. The individual-switch as a whole is suitably secured to the switch supporting member by the screws 28 and operates in general as follows: First the plun-

ger-releasing-magnet 6 is energized for a moment, as the subscriber's switch-hook rises, and the armature 16 attracted, in order that the catch 26 may be disengaged from the butt-end 29 of the plunger-arm 4; 70 then, the spring 27, by its spring tension, rotates the plunger arm 4 about the pivot 20 and thrusts the plunger 3 into the bank Q at a point determined by the position of the plunger shaft 25, which latter rotates about an axis at right angles to the individual-switch-frame 2. When the plunger enters the bank, the bank springs are not only brought into contact, but there is a rubbing or longitudinal action which keeps the contact points clean from dirt and dust. This is due to the fact that the ends of the movable contact springs of the bank Q are bent up slightly. When the movable springs are forced into contact with the stationary 80 springs by the plunger, the pressure on them tends to straighten them out. Since the rear end of the springs is stationary, this straightening action moves the upper end 85 of the spring outward, causing it to rub slightly upon the stationary spring. This will be clear by reference to Figs. 2 and 3 of the drawings. This is very advantageous, as it makes it possible to employ circuit-closing contacts which will operate satisfactorily without platinum points. The long shaft 25 (as shown in Fig. 1) is channeled longitudinally, the walls of which channel are approximately at right angles to each other. Within said channel the outer 90 or butt-ends of all idle plungers of the individual-switches located along its length normally rest. The said outer or butt sections of the plungers, of course, are properly shaped to snugly fit into the said channel, 95 and are of such length that when the plungers are in normal position they may be rotated about their pivots (similar to the pivot 19), for purposes hereinafter to be described. 100 In operating the individual switch the trip-magnet 6, as stated, is only energized momentarily, to operate the armature 16, and after the catch 26 disengages from the plunger-arm 4 the spring 17 upon the switch-release-armature 13 restores the trip-magnet-armature 16 to its normal position. The catch 26 then falls against the terminal 29 of the plunger arm 4 and out of locking engagement therewith. The plunger thus brought into use may be restored by a momentary energization of the switch-release-magnet 7, (when the subscriber restores his receiver) which latter attracts its armature 13, thus raising the armature 16, and causing the catch 26 to project beyond the raised position of the butt-end 29 of the plunger-arm 4, at which instant, of course, the end of the catch 26 slides over the said end of the plunger-arm 4. As soon as the switch-release-magnet becomes deenergized the re- 125 130

tracting spring 15 restores the switch-release armature 13 to its normal position, at which time, of course, the plunger is drawn into normal position and moved back into engagement with the plunger-shaft 25 against the tension of the plunger-arm retracting-spring 27. It will be understood that the rotary motion of the plunger-shaft is oscillatory, and that at no time does the longitudinal groove in said shaft pass to such a position that any plunger, after it has left the shaft, may not return to the said channel. For instance, if the plunger 3 leaves the shaft at the right-hand extreme position of the shaft indicated in Fig. 1, and the said shaft advances to its extreme position to the left, upon being released the said plunger will return to normal position, adjusting itself opposite the last bank position on the extreme left-hand ready for use. The bridge-cut-off relay 5 is attached to a frame 30 by means of a screw 31, which frame is secured to the base of the switch by other screws 32. The said relay, at the instant that the plunger enters the bank, as will be pointed out, becomes energized and attracts its armature 33. This armature is pivoted to the end of the relay-frame and vibrates about an axis that passes through the pivots 34 only one of which is shown. This armature is provided with an operating arm 35 the end of which is insulated. Said arm controls three contact-springs 36, 37 and 38 that are mounted upon the magnet-frame; said springs are held in place by a couple of screws 39 and are suitably insulated from each other. The bank Q is made of a multitude of parts. Referring to Figs. 1, 2, 3, 5, 6, 7, 8 and 9 particularly, it will be noticed that the said parts are clamped between metallic plates 40 and 41 to form a unit, the former of which plates is provided with flanges 42 for supporting the bank as a whole between the angle-irons 21 and 22. The two plates are held united by screws 43 that extend through the bank but from which all circuit establishing parts are insulated. Considering the details from right to left (Fig. 2) it will be seen that beneath the clamping-plate 41 there is a piece of insulation 44 that separates said plate from the rest of the structure, underneath which insulation there is in turn a common metallic piece *a* the inner rim of which is bent inwardly, as clearly shown in Fig. 5. Beneath this conductor there is another piece of insulation 45 under which is another common metallic piece *b* a part of which is shown in perspective in Fig. 6. Separating this last conductor *b* from a metallic brace 46 is another piece of insulation 47, and on the other side of said brace still another piece of insulation 48. Beneath the said last insulation there is a common comb-like metallic piece *c* (Fig. 6) the ends of the teeth of which are

bent toward the outer portion of the bank, and which teeth are each adapted to be thrust into engagement with the former described common piece *b*, there being ten teeth, one to each bank position. Beneath the said comb there is still another insulating piece 49 between which and an insulating or central member or comb 50 (shown in Fig. 9) there is a row of metallic springs *d*, of the type shown in Fig. 8, insulated from each other, and each adapted to be pressed into engagement with the previously described common member *a*. Said springs are individual to each position. The said comb 50 is provided with regularly distributed short stout radially-projecting teeth 51 between which guiding channels for the plunger tip are provided, and opposite each of said channels one set of bank springs is located and, therefore, of the springs *d* there is one allotted opposite each space or channel. Upon the other side of the central member there is another set of springs *e* like spring *d* shown in Figs. 5 and 8, but each arranged with its end bent in an opposite direction—a layer of insulation 52, then a set of springs *f* (shown in Fig. 7) similar to the springs shown in Fig. 8 but shorter. Beneath the said set of springs there is further insulation 53 and another brace 54, and then further insulation 55 and another common member *g*—similar to the member *b* shown in Fig. 6—with which the springs *f* are adapted to engage, and further insulation 56 and another common member *h* like the member *a* shown in Fig. 5 and in connection with which the springs *e* are also adapted to engage. Beneath this last member there is another layer of insulation 57, and then follows the outer clamping member 40. The end of the plunger 3 is drawn out into a finger 58 which is adapted to be thrust into any one of the spaces between the teeth 51 of the central member 50. Above said finger is an insulating piece 59 held at right angles to the plane of the plunger, and which, when the plunger-finger 58 enters any one of the spaces between the teeth of the central member 50, forces the springs *e* and *d* of the particular bank position thus occupied by the plunger, and on one side of the bank, in contact with the common members *b* and *a*, respectively; and on the other side the corresponding springs *f* and *e* are forced into contact with the common members *g* and *h*, respectively.

The master-switch *H*, as shown in Figs. 10 and 13, is built upon a frame 60 and provided with a motor-relay or magnet 61, an auxiliary-relay 62 and differential-relay 63, a cam-controlling ratchet-wheel 64, and a trunk-selecting wiper-arm 65 comprising a cam 66 and a wiper 67, which wiper-arm is rigidly secured to the plunger-shaft 25 and is common to all individual-switches of the same.

group. In addition the said master-switch is provided with an automatic circuit-interrupter which is controlled by the motor-magnet, as will be described. The switch-frame is rigidly attached to the angle-iron 21, while the bank R is supported between the said angle-iron and an adjacent angle-iron 22. Rising from the base of the switch-frame is a flange upon which is pivotally supported the ratchet-wheel 64 having four lugs 68, 69, 70 and 71. The said ratchet-wheel is provided with a hub 72 that keeps it away from the walls of the supporting flange 73 through which the pivoting screw 74 passes and which is locked upon the other side by the nut 75. On the lower side of said ratchet-wheel and secured by the bolt 76 to the same flange 73 is a pawl 77 which operates in connection with the ratchet-wheel, and which is kept in engagement with the teeth thereof by a retracting-spring 78. The object of this pawl is to retain the said ratchet-wheel always in its advanced position and prevent any backward rotation thereof. The power for rotating said ratchet-wheel is provided by the motor-magnet 61, which latter is secured to the magnet-frame 79, which frame is in turn attached to the base of the switch by the screw 80. The said motor-magnet comprises two coils and is provided with an armature 81 that is retained normally away from the pole-pieces by a retracting-spring 82, the tension of which is regulated by a thumb-screw 83. The retracting movement of the armature is limited by a portion 84 which is bent at right angles toward the frame of the switch and which, when the armature is in normal position, rests against the magnet-frame 79, as indicated. The said armature is also provided with two forwardly-extending arms or sections 85 and 86, the former of which carries a pawl 87 for operating the ratchet-wheel 64, and the latter a roller 88 on its bifurcated extremity for operating the automatic current interrupter connected with the motor-magnet. The pawl is pivotally secured upon the end of the arm 85 and is normally held in position by a suitable retracting-spring 89 one end of which is secured to the pawl supporting arm and the other to the rear end of the pawl itself. From the base of the switch-frame rises a pedestal 90 which projects in front of the armature-arm 86, the upper end of which pedestal is bent over the said arm 86 and supports a pair of springs 91 and 92 secured to the said pedestal by screws 93, said springs being insulated from each other. Upon a section 94 of the frame 60 that extends at right angles to the ratchet-wheel supporting flange 73 is riveted a spring 95 the end of which is U-shaped. The end of said spring above the U-shaped section normally rests against the roller 88 on the end of the armature-arm 86, and the spring 92 is of such length that its end rests normally upon the roller 88, and at the same time upon the extremity of the said perpendicular spring 95, in normal contact with the second circuit contact-spring 91. The energizing circuit of the motor-magnet comprises in series the said springs 91 and 92, and when energized the said magnet, of course, attracts its armature, at which time the roller 88 upon passing over the U-shaped section of the spring 95 forces the said spring from under the circuit spring 92, which latter then falls away from its mate spring 91, thereby destroying the continuity of the energizing circuit through the said propelling or motor-magnet. At once the armature 81 returns to its normal position and the roller 88 restores the circuit spring 92 into contact with its mate or coöperating spring 91, and thereby permits the perpendicular spring 95 to return to its normal position under the said spring 92. Again the circuit through the motor-magnet is established, and the same operation occurs again and again, as long as the battery that energizes the said motor-magnet is retained in series with the said magnet and the springs 91 and 92. The interrupter here shown is the same as that described in United States Letters Patent No. 841,004, granted January 8, 1907, to John Erickson for improvement in interrupters for electro-magnets. Of course it will be evident that each time the armature 81 is attached the pawl 87 drives the ratchet-wheel 64 around one step in the direction indicated by the arrow, in which position the said ratchet-wheel is caught by the auxiliary-pawl 77. The bank R of the master-switch is clamped between two plates 96 and 97, as shown in Fig. 11, one of which plates acts as a support for the said bank, between the supporting angle-irons 21 and 22, and which is secured to the said angle-irons by screws 98. Beneath the plate 96 is an insulation sheet 99 below which in turn are arranged a number of bank-contacts *i* insulated from each other and beneath which in turn is another sheet of insulation 100 that forms the central portion of the blank. On the other side of this insulation is a common metallic member *j* similar to the member *b* shown in Fig. 6, but which may be divided into sections, as shown in Fig. 14, for purposes hereinafter described, and which is provided with a suitable terminal to which suitable connections may be soldered. Beneath the said common plate and the second clamping plate 97 there is another sheet of insulation 101, all of which parts are held rigidly in position by screws 102 which pass through the upper clamping-plate 96 and which engage suitably threaded sections in the lower plate 97. Integral with the rear clamping-plate 97 is

an outwardly-projecting member or bearing 103 through which the plunger-shaft 25 passes. Upon said shaft and secured thereto by the screw 104 are the cam 66 and hub 105, located nearly opposite the ratchet-wheel 64. It is by means of the said cam that motion is imparted to the common plunger-shaft 25. Secured upon the said shaft there is also, as stated, the wiper-arm 65 held rigidly in position by the set-screw 106 in the hub 107. The said wiper-arm 65 carries on its end the wiper 67, the free end of which forms two flexible contacts riveted together at their inner ends and secured to said arm 65 by screws 108. The ends of said wiper are adapted to slide over the bank of contacts R. One engages one of the bank-contacts *i* at each step, and the other slides upon the lower common plate *j*, by which means the engaged contact *i* is always kept in electrical connection with the said common plate by the said wiper. The cam-arm and wiper-arm are so adjusted upon the plunger-shaft that when either one of the pins 68, 69, 70 or 71 engages the cam at a point marked by the line 109 the wiper 67 engages the first bank-contact 110, and so that when the said pin advances to a position marked by the second line 111 the second bank-contact 112 is engaged by the wiper 67, and for each consecutive position of the engaged pin the wiper engages one of the succeeding bank-contacts. The construction is such that after the engaging pin 68, for instance, has traveled to the end of the cam, then at the next step of the ratchet-wheel the said cam disengages from the said pin 68 and falls into engagement with the succeeding pin 71 at the point 109. The force for thus operating the cam from one pin to the other is provided by any suitable spring-power—in this case by a coil-spring contained within the cup 113—which latter is rigidly screwed to the shaft by the set-screw 114. The said spring has one end fastened to the outer covering of said cup and the other to the arm 115, which latter is retained in a permanent position by a suitable pin that projects from the bearing 103 and passes through an opening on the end of the arm 115. The action of the switch operating machine or master-switch is in general as follows: When a subscriber by means of his individual switch seizes upon the already selected idle trunk-line corresponding to the position in which the master-switch-wiper 67 is resting (Fig. 10), he causes a guarding potential to be established at the contact-point 110 at the instant that his plunger seizes the said trunk line. The differential-relay 63 then becomes energized and connects the motor-magnet 61 and interrupter-springs 91 and 92 in series with the operating battery B. The said motor-magnet then attracts its armature 81 and 65 thrusts the spring 95 out of engagement with the interrupter-spring 92, as described. At the same time the pawl 87 engages the ratchet-wheel 64, rotating the latter one step. If the master-switch-wiper is in the 70 position indicated in Fig. 10, the pin 68 will be found engaging the cam 66 at a point indicated by the line 109; then when the interrupter-armature is attracted, as stated, the pin 68 passes to a new position, marked 75 by the line 111, which position corresponds to the position of the wiper 67 while it is in engagement with the second bank-contact 112. It will be noticed that by the time that the armature 81 reaches the pole-pieces of 80 the attracting magnet the pawl 87 strikes with the rear surface of its forward end the stop or bumper piece 116, to insure a positive and limited action of the ratchet-wheel 64, and in order that the latter may not be 85 carried by momentum more than one step and thus cause the wiper 67 to pass over more than one contact at each step. However, as soon as the circuit is interrupted, and when the interrupter-springs 91 and 92 disengage, the retracting-spring 82 then restores the armature 81 to its normal position, and the interrupter-spring 92 into engagement with the spring 91, and to a position over the 90 latch or pilot-spring 95. In the meantime 95 the circuit through the differential-relay 63 is destroyed as soon as the wiper 67 leaves the contact-point 110, unless the next contact-point is provided with a guarding potential. In the latter case, of course, the 100 differential-relay 63 is retained energized, and when the interrupter-springs reengage the motor-magnet is energized again. As a result the ratchet-wheel is rotated another 105 step, and the pin 68 passes to a position in contact with the cam-arm 66 (marked by the line 117), causing the wiper 67 to pass to the third bank-contact 118. Unless the said contact 118 is busy and thereby protected by a guarding potential, the 110 energizing circuit through the differential-relay 63 is destroyed as soon as the wiper 67 leaves the bank-contact 110, at which time the operation of the switch comes to an end as soon as the motor-magnet 115 armature 81 regains its normal position. At the same time that the differential-relay 63 is energized, the auxiliary-relay 62 is energized also, and the circuit controlled by the latter will be fully described. It 120 will be seen that the office or duty of the master-switch is to at all times maintain the idle plungers which are under the control of the plunger-shaft in a position opposite an idle trunk-line, and to cause all 125 plungers that are released to instantly assume similar positions relative to their banks. Such trunk-line may be seized in

stantly by any one of the said idle plungers at which instant the plunger-shaft is automatically advanced by the motor-magnet to carry all remaining idle plungers before 5 the next idle trunk-line. The differential-relay 63, as shown in Figs. 14 and 15, is made up of four windings 119, 120, 121 and 122. These windings are so arranged that the windings 119 and 121 reinforce 10 each other, and so that the windings 120 and 122 reinforce each other; but the first set of windings are wound in opposition to the last set. The battery, furthermore, is permanently bridged between the first 15 set of windings and the second set of windings from points midway between the coils 119 and 121 and the coils 120 and 122. It will be noticed that a current is continually flowing from the non-grounded terminal of battery B through the windings 119 and 120 to the grounded terminal of the battery B, and also through the windings 121 and 122 to the grounded terminal of the said battery; but since the windings 20 119 and 120 oppose each other, and the windings 121 and 122 also oppose each other, the relay 63 is retained in an unmagnetized state. The auxiliary-relay is composed of two windings 123 and 124, but these windings 25 are not differentially arranged. If my individual-switch is used in connection with a purely automatic system each subscriber must be provided with an approved or suitable sub-station apparatus adapted 30 to be used in transmitting electric impulses over the calling subscriber's line to operate the automatic central switching apparatus which, in a ten thousand system, as stated, will require (besides the individual-switches) first-selectors, second-selectors and 35 connectors. Furthermore, between the individual-switches and the first-selectors there may be inserted repeaters. The sub-stations employed in each case are of a well-known type, such as the one shown in 40 Fig. 20 connected with the individual-switch A. The sub-station is at once recognized by the peculiar switch-hook 125 which is made with a number of cam-like 45 arms 126, 127, 128, 129 and 130. The primary circuit at said station is purely local and comprises in series a transmitter 131, a battery 132, the primary winding 133 of the induction-coil 134, and a couple 50 of springs 135 and 136 by means of which the said circuit is maintained closed or open by the cam-arm 129, depending upon whether the switch-hook is up or down. Said hook is held pivoted by one end to the 55 screw 137, and is forced to rise whenever the weight of the receiver 138 is removed from it, by a suitable switch-hook-spring not shown. The secondary circuit comprises the receiver 138 in series with the secondary winding 139 of the induction-coil 134, the 60 contact-point 140, the spring 141 of the signalling-device controlled by the signalling-button 142 (whereby the said spring 141 will be separated from the contact-point 140 and closed in connection with the 65 contact-point 143), and two other circuit-closing springs 144 and 145. This last circuit is, of course, connected in the main line circuit whenever the switch-hook is raised. The said sub-station is provided in 70 addition with a ringer 146 and a ringing circuit including the said ringer, spring 147 and cam-arm 130 in series; and while the switch-hook is down said ringer is bridged or closed across the main line when the cam-arm 130 engages with the spring 147. At 75 such a time the said cam-arm 130 (by means of spring 147) causes the springs 144 and 145 to be retained open. While the hook is up, however, the said bridge is open because the cam-arm 130 is withdrawn from the ringer circuit spring 147, and the springs 144 and 145 are restored in contact. The cam-arm 128 controls the continuity of 80 a ground circuit between the so-called ground-post 149 and the ground terminal G¹, by means of the springs 150 and 151 that are included in said circuit. The sub-station is provided in addition with a group of three springs 152, 153 and 154 85 which are known as the release-springs and by means of which the main line-conductors may be grounded simultaneously for the purpose of restoring the exchange apparatus in a manner that will be fully explained. When the hook is depressed the said release-springs are forced together by the cam-arm 127, which engages a laterally-projecting member 155 on the end of the spring 154. The engaging portion of the 90 cam-arm 127 and spring 154 is constructed with their surfaces at an angle to each other, so that as the hook goes down one surface of the projection 155 is engaged by the cam-arm, and when it rises the opposite surface 95 is met. In this way, when the switch-hook descends, the spring 154 is momentarily forced into electrical connection with the springs 153 and 152; but when the hook returns the said spring 154 is simply shoved 100 one side in the opposite direction. It will be seen that at the limit of each stroke of the hook the cam-arm 127 clears the spring 154. The office or duty of the cam 126 is to engage (as the switch-hook rises) 105 the spring 156 for a moment, which latter, after the ground circuit springs 150 and 151 come into contact, is connected to the ground terminal G¹. The said cam 126 is electrically connected with the so-called 110 rotary side of the subscriber's line. With this construction, therefore, when the subscriber removes his receiver from the switch-hook he momentarily connects the 115 said rotary side of the line with ground. 120

It will be understood, of course, that at the extreme position of the switch-hook the cam-arm 126 is out of engagement with the said spring 156. The electric impulse-transmitter or calling device employed by the subscriber may be of any suitable design. The simple type illustrated, however, comprises two push-buttons 157 and 158, two contact-points 159 and 160, two springs 161 and 162 and the ground-post 149. The spring 161 and contact 159 are normally retained together, as well as the spring 162 and contact 160; but when the button 157 is pressed the spring 161 is separated from the contact-point 159 and connected with the ground-post 149, and when the button 158 is pressed the second spring 162 is pressed onto the same ground-post after the said spring leaves the contact-point 160. It has been stated that the individual-switch may be located at any desired point. It may be in the main central office itself or at a distance from the central office. Where the subscriber is at a very great distance from the main central office, the latter form is the more desirable for economy, and in that case each trunk-line leading from the banks of the individual-switches is provided with a repeater—that is, an instrument which will receive all electric pulsations transmitted by the subscriber, and which will in turn repeat them to the trunk-line by which the subscriber may be connected to the main central office. Since the automatic system under consideration is a trunk-release system, three conductors are ordinarily allotted to each trunk-line between individual-switches and first-selectors. But it will be described how, with a repeater, it is possible to reduce the number of said conductors to two. The connection between the individual-switch A and the first-selector D through the repeater C is shown in Figs. 21 and 20. The said repeater comprises a couple of line-relays 163 and 164 one known as the vertical-line-relay and the other as the rotary-line-relay. Said relays have under their control a number of springs among which are the so-called trunk-release-springs 165 and 166 and the impulse-transmitting line-relay-springs 167 and 168, together with the ground-spring 169. The said repeater has in addition two condensers 170 and 171, one on either side of the main circuit, for inductively connecting the individual-switch bank-springs allotted to said repeater with the trunk-line leading from said condensers. The first-selector may be of any suitable or approved type. In Fig. 17, for instance, is shown the first-selector D with the bank 172 of trunk-line-terminals beneath it, while the private-bank 173 is located just above the trunk-line bank. The switch-shaft 174 is vertically disposed on

the front of the switch-frame and retained connected therewith by bearings which are not shown. The shaft may be moved vertically or endwise in said bearings and then rotatively by electro-magnetically-operated ratchet and pawl mechanisms, the vertical or endwise step-by-step movements occurring first. Among the functions of the shaft is that of a holder for the line-wipers 175 and 176 and the private-wiper 177. The former two comprise a set distinct from the latter, but both sets are located within range of the contacts of their respective banks 172 and 173. Said wipers are not only insulated from the shaft, but from each other as well. Among the details that are associated with the shaft is a cam-piece 178 which is of a split sleeve design and secured to the shaft by a screw 179. Said cam abuts on a hub 180 that is shrunk to the shaft near the middle of the latter. This hub carries a set of longitudinal teeth 181 that serve, as will be disclosed, to enable the forward rotation of the shaft, and as a means of locking against backward rotation of the same. On the neck portion of said hub is a set of circular teeth 182 that serve in turn as a means by which the raising of the shaft is accomplished, and for locking it when raised. These circular teeth are traversed by a groove or channel 183 into which the end of a so-called shaft-rest 184 normally projects; but when the shaft is rotated any one of the said circular teeth which may be at the proper height slides onto the end of the said rest. The end of the rest is, of course, adapted to fit the said circular groove between ratchet-teeth. The upper surface of the engaging end is level, but the under side is chamfered to correspond with the upper slope of the circular teeth. Above the hub 180 the shaft carries an arm 185 known as the normal-post-arm and which is, while the switch-shaft is at rest, and while the shaft-rest occupies the slot 183, retained against the normal-post 186 by the coiled spring 187. Among the magnets allotted to the first-selector some are used as relays and others as operating magnets. The magnets 188 and 189 are among the former kind and have become known as the vertical and rotary line-relays. By means of their respective armatures 190 and 191 the springs 192 and 193 are controlled with respect to the ground-spring 194. Said springs are comprised in energizing circuits of operating magnets that raise and rotate the shaft. The magnet 195 with its armature 196 and springs 197 and 198 constitutes the back-release-relay which is used for restoring the switch at any time after it has seized a trunk-line. Of the operating magnets the magnet 199 is known as the vertical-magnet and has a so-called 130

vertical-armature 200 that is supported by pivots 201. Whenever the coils 202 and 203 of said vertical-magnet become energized the armature 200 is attracted, and when the 5 magnetization ceases, the retracting-spring 204 restores said armature to its normal position. The upward movement of the armature is limited by the pole-pieces of the magnet-coils 202 and 203, and the lower limit is 10 marked by a section of the switch-frame (not shown) that passes under the arm 205. Said arm is known as the vertical-arm and extends forwardly from the vertical-armature 200, of which latter it is a part. The vertical-arm carries on its end a so-called vertical-pawl 206 which, when the vertical-armature is attracted, engages with some one of the circular teeth 182 to raise the shaft. Normally the under surface of the upper 15 section of said pawl rests against a piece (not shown) that is secured to the switch-frame and that retains the pawl away from the circular teeth. When the vertical-armature is attracted, as the said pawl rises, a 20 retracting-spring 207 thrusts the upward side of the pawl toward the circular teeth 182. As soon as said pawl clears or disengages its normal rest, and by the time that the vertical-armature strikes the pole-pieces, 25 the vertical-pawl strikes with the rear surface of its upper section a bumper piece or stop which constitutes a part of the switch-frame. Therefore, the shaft is thus prevented from being thrown up more than one 30 notch at a time by its own momentum. It is clear, then, that the said pawl not only raises the shaft, but that it also acts as a lock at the end of each stroke. The vertical-arm also has an L-shaped piece 208 on its 35 under edge that forks over a so-called release-link 209 of flexible spring material. Said link has an aperture 210 in its front end, and is secured to the armature 211 of one of the operating magnets 212 known as 40 the release-magnet. The said armature is suspended from the frame by the supports 213 and normally retained by the spring 214 away from the pole-piece of the release-magnet. A stop is suitably provided behind said 45 armature to limit its movement when retracted. The first-selector is provided with a peculiarly shaped mechanism 215 known as the double-dog. It is so pivoted that it may swivel about a vertical axis that passes 50 through the pivots 216. On its front side said double-dog develops into two dogs 217 and 218 which are so situated and constructed that the former may coöperate with the circular teeth 182, while the switch-shaft is 55 raised and in normal rotary position, and the latter with the longitudinal teeth when the shaft is rotated. To the right of the pivots 216 the body of the double-dog extends rearwardly, and projecting down therefrom is an 60 arm 219 that comes into use very promi- 65 nently during the releasing of the switch. Near the extremity of and on the upper side of said body a pin or lug 220 projects upwardly. Said lug is normally caught in the aperture 210 of the release-link 209, and because of the tension of the spring 214 exerted through said link the dogs 217 and 218 are retained away from the shaft. Always, at the first stroke of the vertical-armature, the link 209 is drawn from the lug 220 by 70 the piece 208, and then the double-dog is rotated by the retracting-spring 221 so that the dog 217 falls under the first circular tooth, and so that when the vertical-armature returns to its normal position the said 75 shaft is retained by said dog in its new position. The release-link 209, while the double-dog is free, rests with its free end upon the lug 220 and out of locking engagement therewith. When the vertical-magnet is energized a second time the shaft is raised a second step and the dog 217 at the second stroke passes from under the first tooth to below the second tooth, holding the shaft 80 again as above. The release-magnet 212 is composed of two coils like the vertical-magnet 199, but as a matter of convenience of illustration only one coil is shown. If while the shaft is raised the said release-magnet 85 should be energized, the release-armature 211, of course, is attracted and the release-link 209 thrust forward to catch the lug in the aperture 210. Upon the deenergization of the release-magnet the retracting-spring 214 then withdraws the dogs 217 and 218 90 from the shaft, which latter being deprived of its only support then falls to normal position by its own weight. After the shaft is once raised it may be rotated by a second operating magnet 222, known as the rotary-magnet. Said magnet has two coils 223 and 224 and, unlike the vertical-magnet, has its 95 armature 225 pivoted in a vertical plane. Said armature may be moved about a vertical axis that passes through the pivots 226. 100 The limit of movement of said armature toward the rotary-magnet is determined by the pole-pieces of said magnet, which movement is produced by the rotary-magnet itself. The motion of the armature in the opposite 105 direction is produced by the retracting-spring 227, and is limited by a switch-stop (not shown) behind the so-called rotary-arm 228. This arm, like the vertical-arm, carries a so-called rotary-pawl 229. Similar 110 to the vertical-pawl, said rotary-pawl normally rests against a stop (not shown) that retains it away from the longitudinal teeth, and when the rotary-armature is attracted 115 it is drawn into engagement with the longitudinal teeth by a spring 230 attached between the rotary-arm and the rear of said pawl. By the time the rotary-armature strikes the pole-pieces of the rotary-magnet, the rotary-pawl also strikes a bumping post, 120 125 130

as does the vertical-pawl, and locks the shaft against further advance by the force of its own momentum. At the end of the first rotary step the dog 218 falls behind the first 5 longitudinal tooth, so that when the rotary-pawl falls back the shaft is retained. It should be evident that as the shaft is rotated the vertical-dog 217 is extricated for a moment from the groove below the circular 10 tooth with which it has been in engagement, by the passage of the rotary-dog 218 over the longitudinal tooth across which it has to slide at the time; but at the beginning of the rotation it will be evident that the tooth 15 which has been caught by the vertical-dog slides onto the shaft-rest 184, and in this way the shaft is still held raised after the rotation begins. The construction is such that when any one of the circular teeth passes 20 onto the shaft-rest 184 the shaft rises a trifle in order that the tooth which has been resting upon the dog 217 may clear said dog and reduce the friction of the parts during operation. When the shaft is raised the circular 25 tooth resting on the shaft-support 184 is slightly below the level of the upper surface of the shaft-rest 184, and to enable a rotating tooth to pass onto the shaft-rest 184 the edge of the end of the shaft-rest 184, as 30 well as the edge of all circular teeth, are rounded off slightly to permit the rotary-armature 225 to raise the shaft slightly, as stated, without a catch. The rotary-armature is provided with a so-called interrupter-finger 35 231 that separates the interrupter-springs 232 and 233 whenever the rotary-armature is attracted; also with a rotary-armature-finger 234 that exercises certain controlling influences over the armature of 40 the last of the operating magnets—the private-magnet 235. The said private-armature 236 works in a vibratory manner about a horizontal axis that passes through the supporting points 237. This armature is 45 formed with a forwardly-projecting arm 238, the latter having two flat surfaces in an approximately horizontal plane. Furthermore, the end of the said arm is bent downwardly at right angles and carries certain mechanical details, namely a lateral arm 239 which 50 is designed to control circuits comprising the private-springs 240, 241 and 242, and a tooth-escapement which includes two flexible springs 243 and 244, each of which springs is riveted by one end to the arm 238, one on 55 the upper side and the other on the lower. The upper spring is straight and has formed on its end two tooth projections 245 and 246 which extend downwardly, while the lower 60 one is bent down and at right angles again to the front. This double angle on the lower spring is so designed that the latter may clear or disengage the bent portion of the private-arm, against which portion said 65 spring rests with a requisite degree of ten-

sion, and so that there may be space in front of said bent portion to receive two other tooth-shaped upwardly-projecting pieces 247 and 248 that are formed on the forward end of said escapement-spring 244, and which are 70 sustained in juxtaposition to the upper teeth, but slightly to the rear thereof. A retracting-spring 249, suitably located, holds said armature normally away from the private-magnet pole-piece. A well-known auxiliary 75 switching mechanism common to such switches is the so-called side-switch. It is shown in connection with the first-selector D and comprises an arm 250 which is secured to the switch-frame in such a manner that it 80 may be made to swing about a vertical axis that passes through the pivots 251. The right extremity of said arm is drawn out into a finger 252 that works in conjunction with the escapement-teeth previously described. Said teeth, in a manner to be demonstrated, reduce the outward movement of the side-switch to a step-by-step motion, which movement is produced by a retracting-spring 253. At the base of 85 the finger 252 a lug 254 is bent to the front and adapted to strike the cam 178 at a suitable time. Whenever the shaft is rotated, however, said cam is carried beyond the reach of said lug. Near its left 90 extremity the arm 250 carries a number of wipers 255, 256, 257 and 258 suitably mounted upon a pin 259 and insulated therefrom and from each other. Said wipers are known as the side-switch-wipers and are 95 adapted to be operated by the private-magnet and escapement device previously described. If the private-magnet is energized once the private-armature is drawn down once and restored to its normal position. The escapement-finger 252 then 100 passes from behind the tooth 247 to the rear of the tooth 245, at the downward stroke of the private-armature 236, and from behind the latter tooth at the return stroke. As 105 soon as the escapement-finger clears or disengages the latter tooth the retracting-spring 253 draws the side-switch to the second position, where it is stopped by the lug 254 when it strikes the cam 178. Immediately, then, when the rotary-magnet energizes, the shaft is rotated and the cam passes out of reach of the lug 254. Then the finger 252 of necessity falls against the tooth 248 because of the tension in the 110 spring 253. The rotation of the shaft results when the rotary-armature 225 is attracted by the rotary-magnet, and at the same time the rotary-armature-finger 234 depresses the private-armature 236 and 115 causes the finger 252 to disengage from the tooth 248 and advance against the tooth 246. Then, as the rotary-armature returns to normal position, when the rotary-magnet deenergizes, the private-armature on follow- 120 125 130

ing the finger 234 permits the escapement-finger 252 to escape from the last tooth 246, thus permitting the side-switch to pass to the third position, the said finger resting 5 against the side-switch-stop 260. In their normal positions the side-switch-wipers 255, 256, 257 and 258 engage with the contact-points 261, 262, 263 and 264, respectively. This position is known as the first position 10 of the side-switch, at which time, it will be clear, the finger 252 is held behind the escapement-tooth 247. In the second position, while the said finger is between the teeth 247 and 248, the said side-switch- 15 wipers engage instead with the contact-points 265, 266, 267 and 268, respectively; and when the said finger 252 falls against the stop 260 the wipers shift their positions and move into contact with contact-points 269, 270, 271, and 272, respectively. 20 Between the pivots 251 and the wiper-supporting pin 259 a rearwardly-extending arm 273 on the side-switch-arm 250 pivotally supports on its end one end of a link 274, the other end of which latter, being bifurcated, engages with the lower end of the double-dog-arm 219, which latter is constructed somewhat in the shape of an inverted T. Should the release-magnet be 25 energized while the side-switch is in third position, and, of course, while the shaft is rotated, the release-link 209, being attached to the release-armature 211, is then thrust forward when the release-armature is at- 30 tracted and catches the lug 220 in the aperture 210. Then, when said release-armature is restored, the spring 214, as before de- 35 scribed, withdraws the dog 218 from the circular teeth 181. At the same time the arm 40 219 drives the link 274 back, which latter then rotates the side-switch-arm about the pivots 251 and against the tension of the side-switch retracting-spring 253, thus driv- 45 ing the finger 252 backward between the springs 243 and 244 and into a position be- 50 hind the tooth 247, locking the side-switch in the first or normal position. The switch-shaft being unlocked by the removal of the dog 218, and being thus left free, is then 55 rotated by the coil-spring 187 until the instant that the end of the shaft-rest enters the slot 183, at which time the shaft drops to its normal position. Therefore, after the switch has been operated, the energization 60 and deenergization of the release-magnet is sufficient to restore the switch completely to its normal position. The line and pri- 65 vate banks are each provided with ten rows of contact terminals, each row consisting of ten sets of contacts, and the shaft is so con- 70 structed that it may be raised to any one of ten levels, and at each level it may be rotated ten successive steps in order that the wipers which it carries may be placed in 75 connection with any one of the ten sets of

contact terminals in each level. The second-selectors employed between the first-selectors and connectors are a modified form of the first-selector just described, one of said second-selectors being shown in Fig. 18. 80 In said second-selector the line-relays 275 and 276 are provided with two trunk-release-springs 277 and 278 to be used in releasing the switches, as hereinafter described, at any stage of the call after the calling subscriber has placed his line in connection with a second-selector. The use of said springs will be fully described. When reference is made to any part of the second-selector, and since its parts are similar to the corresponding parts in the first-selector, there will be no difficulty in understanding the operations when described. The repeater C' shown in Fig. 21 does not differ from the repeater C in general construction. 85 A dead-resistance coil within a release-circuit to be hereafter described, and which does not appear in the repeater C, is provided at the repeater C' for purposes to be described. With reference to the connector, the general structure of said switch is very similar to that of the selector-switches that have preceded. For instance, the line and private banks 279 and 280 are at once recognized, as well as the switch-shaft 281. 90 This latter carries the usual line-wipers 282 and 283, private-wiper 284, cam 285, the longitudinal teeth 286, circular teeth 287 with their longitudinal slot 288, the normal-post-arm 289 and the coiled spring 290. 95 The shaft-rest 291 is also provided, while the normal-post-arm 289 is given the additional office of controlling a couple of springs 292 and 293, the latter of which is normally separated from the former, but 100 which when the shaft is raised come into contact. The line-relays 294 and 295, together with the springs associated with them, are identical with those in the second-selector. Among said springs the trunk-release-springs 296 and 297 are easily recognized. The vertical-magnet 298 with its armature 299 and associate parts are the same as those of the selectors. The release-magnet 300, however, has the release-armature 110 301 upon the right side instead of on the left side of the magnet. Furthermore, said release-armature is provided with an arm 302 which is designed to control the double-dog 303, which latter is also the same as 115 that of the selectors, as well as the side-switch it controls. Another difference in the connector release mechanism is that the release-link 304 is permanently secured to the switch-frame at the pin 305, and that 120 the release of the switch-shaft and side-switch occur at the energization of the release-magnet rather than at the deenergization of the same. This latter becomes evi- 125 dent when it is explained that when the re- 130

lease-magnet 300 becomes energized the elongated section 302 of the armature 301 strikes the double-dog at a point between the bearings and the lug 306, causing the 5 said double-dog to be rotated about the pivots 307 in such manner that the lug 306 is driven beneath the aperture 308 in the end of the release-link 301 and latched by the latter in the usual or well-known manner. At the same time the double-dog release-arm 309 drives the side-switch to its normal position and the escapement-finger 310 is driven back between the usual escapement-springs 311 and 312 upon the armature 10 313 of the usual private-magnet 314, where it is retained by the rear lower-most escapement-tooth 315. In the connector, however, the lateral arm 316 controls four springs 317, 318, 319 and 320 instead of three as in 15 the selectors. Furthermore, in the connector each side of the subscriber's extended line terminates in a condenser. These condensers 321 and 322 are in turn connected with said line when the connector establishes a connection with a desired line. The rotary-magnet 323 has a rotary-armature 324 that is provided with a rotary-arm 325 upon the extremity of which the rotary-pawl 326 is located. The rotation of the 20 shaft each time the rotary-magnet is energized is produced in a manner similar to that described in connection with the first-selector. For the purpose of signaling a called subscriber a ringer-relay 327 is provided in the connector, which, by means of its armature 328, controls a number of ringer-relay-springs 329, 330, 331, 332, 333 and 334, whereby the called subscriber's line is for a moment separated from the 25 calling subscriber's line and placed in connection with a ringer-generator 335. The connector instead of being provided with a one-relay back-release device or mechanism is provided with a two-relay apparatus, 30 which relays 336 and 337 conjointly control an energizing circuit comprising the springs 338 and 339. When the said relays are energized simultaneously the armatures 340 and 341 carry the springs 338 and 339 35 into contact, thereby establishing a circuit, as will be pointed out, that comprises the connector-release-magnet 300. The object of the provision of the back-release switching mechanism is to enable a called subscriber to destroy or open a connection between any other subscriber and his line if he should desire to do so. The individual-switch mechanism outlined at A¹, Fig. 22, it will be understood, is identical to the individual-switch A; and the auxiliary-relay 342 is similar to the auxiliary-relay 62 upon the master-switch H.

Operation: A clearer understanding of the switching apparatus in an automatic system 40 comprising switching apparatus of the fore-

going character may be had by following the operations by which one subscriber establishes connection with another. For instance, the subscriber #1122, Fig. 20, in calling the subscriber #2211 (Fig. 22) first removes his receiver 138 from the switch hook 125 to permit the latter to rise. As the switch-hook rises the cam 128 permits the ground springs 150 and 151 to come into contact, closing the ground circuit between the ground terminal G¹ and the ground-post 149 through the conductors 343 and 344. Immediately the cam 126 engages the spring 156, thereby closing a connection between the ground terminal G¹ and the rotary-line-conductor 351 as follows: from ground G¹ through the springs 151 and 150, conductor 343, spring 156, cam 126, switch-hook 125, contact-point 160 and spring 162 to the rotary-line-conductor 351. As a result the trip-magnet 6 is energized, the current flowing from the said rotary-line-conductor to the individual-switch A and through the conductor 346, auxiliary-relay-springs 37 and 36, through the said trip-magnet 6 and 45 thence through the conductor 347, master-switch auxiliary-relay-springs 348 and 349 to the battery-lead 350, and from the non-grounded terminal of battery B to ground G. At the instant that the trip-magnet is energized the plunger 3, which is, it will be assumed, at this time located in front of the first set of bank-contacts with which the first 50 trunk-line is connected, is then released and thrust between the said first set of bank-contacts (see Fig. 23), thereby causing a number of circuits to be established. For instance, the subscribers' line-conductors 345 and 351 are connected through to a trunk-line of two conductors 352 and 353 that lead 55 to the repeater C; a guarding potential is established by way of the private-normal-conductor 354 from ground G² to the connector-private-bank-contacts corresponding to the connector-line-bank-contacts with 60 which the calling subscribers' normal-line-conductors 355 and 356 are connected, in order that no other subscriber may thereafter be able to establish connection with the calling line by way of the said normal-conductors while the said subscriber is calling. At the same time an energizing circuit is completed through the cut-off-relay 5, whereby the said relay is energized. The 65 current in this circuit passes from ground G² through the springs 357 and 358 to the conductor 359, thence through the said relay 5 and conductor 360 to the battery-lead 350 and through the non-grounded terminal of battery B to ground G. The subscribers' line-conductors 345 and 351 terminate in the springs 38 and 37, respectively, controlled by said relay, and while the relay is deenergized the said springs 38 and 37 are maintained in contact to keep the said line in a 70

balanced condition; but as soon as the said relay becomes energized the short-circuit created through these springs is opened by the armature 33, which latter forces the 5 spring 36 out of engagement with the spring 37 which in turn leaves the spring 38. Furthermore, at the instant that the springs 361 and 362 are forced into contact by the plunger 3 a guarding potential is established 10 from the non-grounded terminal of battery B through the release-magnet 7 and springs 361 and 362 to the first contact-point 110 of the master-switch-bank in connection with which the wiper 67 of the said switch is resting. The said wiper maintaining the contact-point 110 and the section 364 in connection a circuit is established through the auxiliary-relay 62, and through the differential-relay 63, energizing the said relays. The 15 current passes from the contact-point 110 through the wiper 67 to the contact-point 364, thence through the conductor 365, winding 124 of the auxiliary-relay 62, through the winding 122 of the differential-relay 63 20 to the ground terminal G^3 and to the grounded terminal of battery B. The differential-relay 63 then becomes energized, thereby attracting its armature 366, which latter then forces its springs 367 and 368 25 into contact, causing in turn the energization of the motor-magnet 61. In a manner that has been described the master-switch is operated to rotate the plunger-shaft one step, carrying the wiper 67 together with all idle 30 plungers found in engagement with the plunger-shaft to their second position. The engaging position of the plunger 3, the advance position of other plungers, plunger-shaft and master-switch-wiper are clearly 35 indicated in Fig. 23. At the instant that the master-switch-wiper 67 leaves the contact 40 110 the energizing circuit through the differential-relay 63 is opened or destroyed, so that by the time the motor-magnet-armature 45 81 restores the interrupter-springs 91 and 92, the armature 366 of the said differential-relay 63 is also restored and the connection between ground G^4 and the motor-magnet is destroyed by the separation of the springs 50 367 and 368. As already described, if the second trunk-line is occupied the second bank-contact 112 of the master-switch H is protected by a guarding potential coming from the nougrounded terminal of battery 55 B through the release-magnet of the individual-switch occupying the second trunk and through the second-position set of bank-springs of the occupying individual-switch (similar to the springs 361 and 362) to the 60 second contact-point 112 of the master-switch H. In that event the differential-relay 63 is not deenergized when the wiper 67 leaves the first bank-contact 110, but is instead retained energized so as to cause the 65 magnet 61 to be operated one more step for

the purpose of carrying the plunger-shaft to the third position. The step-by-step rotation of the plunger-shaft is automatically continued, therefore, as long as the wiper continues to meet guarded bank-contact-points, stopping, however, as described, as soon as it meets a contact-point that is not guarded. The master-switch having carried all idle plungers to the position indicated by the plunger 370 (Fig. 23)—opposite the next 70 idle trunk-line—it will be evident that if any subscriber of the same group then attempts to make a call his individual-switch will cause his plunger to seize the said second trunk-line opposite which it is positioned at 80 the time. Of course, the master-switch will be rotated one more step and the plunger-shaft is rotated so as to place all remaining idle plungers opposite the next idle trunk-line, and so on. However, the subscriber 85 having extended his line to the repeater C, as shown in Fig. 20, by removing his receiver 138 from the switch-hook 125, he then proceeds by pressing first the vertical-button 157 twice and then the rotary-button 158 once for the first digit; for the second digit he again presses the vertical-button twice and the rotary-button once; for the third digit the vertical-button is pressed once and the rotary-button once, and for the fourth 90 and last digit the vertical-button once and the rotary-button once. Upon pressing the vertical-button twice for the first digit the subscriber grounds the vertical-line-conductor 345 and thereby twice energizes the vertical-line-relay 163 of the repeater C. The energizing current passes from ground G^1 to the ground-post 149, thence through the spring 161 to the vertical-line-conductor 345, bank-springs 371 and 372, trunk-conductor 352 to the vertical-line-relay 163, to the battery-lead 350, and from the non-grounded terminal of battery B to ground G. When the said vertical-line-relay becomes energized it attracts its armature 373 and causes 100 the springs 167 and 169 to come into contact for a moment, sending a ground impulse to the vertical-trunk-conductor 374 from ground G^5 through the springs 169 and 167 and conductor 375, and to the said conductor 110 374. The effect of grounding said conductor will be described. When the subscriber presses the rotary-button 158 he grounds the rotary-line-conductor 351 by bringing the spring 162 in contact with the ground-post 120 149. At once the rotary-line-relay 164 becomes energized by a flow of current from said ground G^1 to the rotary-line-conductor 351, thence through the bank-springs 376 and 377, through the rotary-trunk-conductor 125 353, rotary-line-relay 164, to the battery-lead 350, and from the non-grounded terminal of battery B to ground G. The rotary-line-relay upon attracting its armature 378 forces the springs 168 and 169 into contact 130

for a moment, thereby sending a ground impulse to the rotary-trunk-conductor 379 from ground G^1 through said springs 169 and 168 and conductor 380 to the said trunk-conductor 379. The effect of grounding the said rotary-trunk-conductor will be described. It may be stated at this point that after the subscriber removes his receiver from the switch-hook 125, so that his individual-switch A selects an individual trunk-line to the repeater C, he may restore his individual-switch and disconnect it from the said selected line by simply hanging his receiver on the switch-hook. Upon doing so he grounds both the vertical and rotary line-conductors 345 and 351 simultaneously by means of the sub-station release-cam 127, which latter then forces the release-springs 152, 153 and 154 into contact for a moment. Of said release-springs the springs 154 and 153, respectively, are connected with the vertical and rotary line-conductors 345 and 351, while the third release-spring 152 is connected to ground G^1 . Therefore, as a result, a temporary electrical engagement of these three springs sends a ground impulse to the vertical-line-conductor 345 from ground G^1 , and to the rotary-line-conductor 351 from the same ground-point. Grounding the vertical-line-conductor energizes the repeater vertical-line-relay 163, and grounding the rotary-line-conductor energizes the rotary-line-relay 164 of the said repeater, both of which relays are energized over circuits that need not be further described. Said relays simultaneously attract their armatures so that the trunk-release-springs 165 and 166 are pressed into contact as long as said relays are thus actuated. At the same time it will be noticed that the trunk-line-conductors 374 and 379 are grounded by the action of the said armatures upon springs 167 and 168. The closure of contact between the trunk-release-springs 165 and 166 connects the trunk-release-conductor 381 directly to ground through the ground terminal G^5 , thereby establishing an energizing circuit through the release-magnet 7. The current, it will be seen, passes from ground G^5 through the trunk-release-springs 166 and 165, trunk-release-conductor 381, individual-switch bank-springs 362 and 361, conductor 382, through the said release-magnet 7 to the battery-lead 350, and from the non-grounded terminal of battery B to ground G . Upon being energized the release-magnet 7 attracts its armature 13, which latter raises the armature 16 of the trip-magnet 6 so that the end 26 of the armature 16 engages with the plunger-arm 4. When the subscribers' release-springs 152, 153 and 154 disengage, at the time when the switch-hook approaches its lowest point, the connection to the vertical and rotary line-conductors 345 and 351 from the ground ter-

inal G^1 is broken off, at which instant both the vertical and rotary line-relays 163 and 164 of the repeater C become deenergized. The armatures 373 and 378 of said line-relays 163 and 164 being restored, the connection to ground through the release-magnet 7 is destroyed, at which instant the release-armature 13 is restored to its normal position by the retracting-spring 15, at which time the plunger is withdrawn from the bank position which it has been occupying and restored into normal engagement with the plunger-shaft 25, by which operation the plunger 3 upon finding its seat in the angled section of said plunger-shaft assumes a position opposite an idle trunk-line, as previously described. It will be noticed that the differential-relay 63 may be energized by connecting either of the conducting leads 383 or 384 that pass to it through the auxiliary-relay 62 with either the grounded or the non-grounded terminal of the battery-lead. For instance, when the section 364 is connected to the non-grounded terminal of the battery B, as in conditions already cited, a current will flow to the conductor 384 and through the winding 122 to the grounded terminal G^3 ; or if the said section 364 is connected to ground the current will pass to the conductor 384 and through the winding 121 of the differential-coil 63 to the battery-lead 350 and to the non-grounded terminal of battery B. In either case (as shown in Fig. 15) the balanced condition of the coil will be disturbed so that the relay becomes magnetized. In the same way if the section 385 is connected either to the non-grounded terminal of battery B or to the grounded terminal of battery B, as the case may be, the current passes to the conductor 383, and in the first case through the winding 120 to the ground terminal G^3 , and in the last case through the winding 119 to the battery-lead 350, and from the non-grounded terminal of battery B to ground G , in either of which cases the differential-relay will also become energized. The object of such a construction is to prevent the master-switch from becoming locked in a manner which, although it may not occur, still might occur as follows: If for any reason the subscriber's switch-hook, when the receiver is restored, in the case just preceding, is so caught by any obstacle that it descends only part of the way and retains the vertical and rotary line-conductors 345 and 351 grounded indefinitely, the ground connection to the trunk-release-conductor 381 from the ground G^5 and, therefore, to the bank-contact 110 of the master-switch will remain established for an unusual length of time. If such a condition prevails for a length of time during which the other subscribers in the group to which the individual-switch C belongs make calls in

succession, the wiper 67 of the master-switch will then be advanced step-by-step as the subscribers call one after the other and until it reaches the contact 363; and when the ninth subscriber calls, the cam 66 will clear the pin over which it is sliding at the time, and the coil-spring in the cup 113 will carry the said wiper back onto the contact-point 110 which, it is assumed, has been connected to ground since the subscriber that last seized that contact attempted to release. In such a case the wiper 67 will connect the contact-points 110 and 364 and establish a ground connection to the winding 121, and a current will then flow through the winding 121 to the battery-lead 350 to the non-grounded terminal of battery B and to ground G. Therefore, the armature 366 of the differential-relay will be retained attracted in order that the motor-magnet may carry the wiper onto the next contact. If that contact is also busy the terminal 112 will be connected through some release-magnet (similar to the release-magnet 7) to the battery-lead 350 and to the non-grounded terminal of battery B. Again the armature 366 will be retained and the wiper driven along until some idle contact is found. If, however, the differential-relay 63 is disconnected from the battery-lead 350 and all the sections of plate *j* are connected together, as shown in Fig. 16, said relay will only be energized when the plate *j* is connected with the non-grounded terminal of battery, and not when connected with the grounded terminal. For instance, in a case as that considered, the contact-point 110 is directly connected with the grounded terminal of the battery; then if the wiper 67 passes onto said contact the master-switch will be locked out at the instant that the said wiper 67 of the said switch strikes the said grounded contact. Then if any subscriber tries to come in for an idle trunk-line he will release his plunger into a bank position the springs of which are identical with the springs shown at A, Fig. 14. Therefore, as soon as the plunger of said individual-switch presses the springs corresponding to the springs 361 and 362 into contact, instead of the wiper 67 being advanced to the next contact it will remain where it is. The plate *j* being thus connected to the grounded terminal of the battery only, the release-magnet of the calling switch, similar to the release-magnet 7, will be energized and retained so indefinitely. The same result would await all succeeding callers of the same group, a feature which would, of course, be undesirable. It will be noticed that each time the differential-relay 63 is energized the auxiliary-relay 62 is also energized, a different winding being provided for each of the multiple sections into which the plate *j* is divided. It is essen-

tial that the said relay be energized each time a subscriber seizes an idle trunk-line, until after the wiper 67 is carried onto the next idle trunk-line. The reason for this is as follows: If the wiper 67 is resting in engagement with the first contact 110, and if, for example, the next succeeding five or six contacts are busy, and a subscriber should seize the first trunk and thereby cause the wiper 67 to start on its step-by-step rotary motion across the busy trunks just mentioned, some time is then required for the passage of said wiper over said contacts. If while the said wiper is thus rotating a subscriber were to remove his receiver from its hook an impulse would be sent through his trip-magnet (similar to the trip-magnet 6 of the individual-switch A), and as a result his plunger might leave the plunger-shaft 25 at some point opposite one of the said busy bank positions, before the said wiper 67 reaches the next idle trunk-line and seize one of said busy trunk-lines. To preclude this possibility the energizing circuit of each trip magnet comprises the springs 349 and 348, under the control of the auxiliary-relay 62, so that it is impossible for any trip-magnet to become energized as long as the wiper 67 of the master-switch is passing over busy contacts, since at such a time the auxiliary-relay 62 is energized. Since the vertical and rotary trunk-conductors 374 and 379 are normally connected through the first-selector side-switch-wipers 257 and 258 with the vertical and rotary line-relays 188 and 189, the grounding of either of said conductors causes the corresponding one of said relays to be energized. When the subscriber at the calling sub-station #1122, by pressing the vertical-button 157 twice, as stated, causes the vertical-trunk-conductor 374 to be grounded twice, correspondingly, the vertical-line-relay 188 of the first-selector D is then energized twice by a flow of current over a circuit extending from the ground terminal G* at the repeater C through the repeater line-relay-springs 169 and 167 to the vertical-trunk-conductor 374, thence through the side-switch-wiper 257 and contact-point 263 (since the side-switch is in first position) to the conductor 387, and through the said vertical-line-relay 188 to the battery-lead 350, and to the non-grounded terminal of battery B and to ground G. Upon being energized twice, the vertical-line-relay attracts its armature 190 twice and forces the line-relay-springs 192 and 194 into contact, by which operation the vertical-magnet 199 is in turn twice energized. The current in this last circuit passes each time from ground G* through the line-relay-springs 194 and 192, conductor 388, private-springs 241 and 240, vertical-magnet 199 to the battery-lead 350, to the non-grounded

terminal of battery B and to ground G. Upon being magnetized the vertical-magnet 199 attracts the vertical-armature 200 once each time it is magnetized. At the first 3 step, of course, the release-link 209 is disengaged from the double-dog 215 by the L-shaped piece 208, at which time the dog 217 engages one of the circular teeth 182 and prevents the shaft from falling to its normal 10 position. At the second step the shaft is raised one more point and again caught by the vertical-dog 217 and held in its second position. By thus operating the shaft the shaft-wipers 175, 176 and 177 are raised 15 from level to level of their respective line and bank contacts, so that when the shaft is rotated the said wipers may be passed into engagement with bank contacts of the level to which they have been raised. After the 20 second step has been imparted to the shaft, therefore, the wipers are found opposite the first contact of the second level of their respective banks, ready and in a position to be passed onto the said contacts. After the 25 vertical-trunk-conductor 374 has been grounded twice, with the effect just described, and when the rotary-trunk-conductor 379 is grounded as a result of the calling subscriber #1122 pressing the rotary-button 158 once, the rotary-line-relay 189 of the 30 first-selector D is then energized once by a flow of current over a circuit as follows: from the ground terminal G⁶ at the repeater C through the line-relay-springs 169 and 168 to the rotary-trunk-conductor 379, thence through the side-switch-wiper 258 and contact-point 264 to the conductor 389, and through the said rotary-line-relay 189 to the battery-lead 350 to the non-grounded terminal of battery B and to ground G. The 35 rotary-line-relay 189 being thus energized, the line-relay-springs 193 and 194 are forced into contact, and as a result the private-magnet 235 is energized. The circuit over which magnetizing current flows extends from ground terminal G⁶ to the first-selector line-relay-springs 194 and 193, conductors 390 and 391, private-magnet 235 to the battery-lead 350, and to the non-grounded 40 terminal of battery B and to ground G. The private-armature 236 being attracted and restored once, the escapement-finger 252, under the tension of the side-switch retracting-spring 253, passes from behind the escapement-tooth 247 at the downward stroke of the armature 236 to the rear of the escapement-tooth 245, clearing the latter as the said private-armature returns to normal position, so that the side-switch is drawn into second 45 position and stopped when the lug 254 strikes the cam 178. The result of this operation, it will be evident, places the escapement-finger 252 between the escapement-teeth 247 and 248, the said finger being 50 nearly in contact with the escapement-tooth 248, and the side-switch-wipers in engagement with their respective contact-points 265, 266, 267 and 268. It will be understood that the prongs of the bifurcated end of the link 274, which rest upon the T-shaped extremity of the side-switch releasing-arm 219, are of sufficient length to permit the said releasing-arm to move from the position it holds when the double-dog is held normally locked by the release-link 209 to the position 55 it assumes when the double-dog 215 is released, and without disengaging the said prongs. At the moment of the passage of the side-switch from first to second position, and when the side-switch-wiper 255 engages the contact-point 265, an energizing circuit is established through the rotary-magnet 222 for energizing said magnet, which extends from ground terminal G⁷ to the side-switch contact-point 265, side-switch-wiper 255, 60 conductor 392, rotary-magnet coil 224, interrupter-springs 232 and 233, rotary-magnet-coil 223 to the battery-lead 350, and from the non-grounded terminal of battery B to ground G. The rotary-magnet 222 upon being thus energized attracts the rotary-armature 225 so that the rotary-pawl 229 is driven 65 into engagement with one of the longitudinal teeth 181, causing the shaft to be rotated one step. Just at about the time that the rotary-armature strikes the rotary-magnet pole-pieces the rotary-dog 218 falls behind the first of the longitudinal teeth 181 to prevent, as already described, the shaft from returning to its normal position when the 70 rotary-magnet becomes deenergized. Since the said selector is provided with an interrupter mechanism of the type described in United States Letters Patent No. 831,875, granted to me September 25, 1906, for improvement in interrupter for automatic telephone or other switches, the deenergization of the rotary-magnet referred to occurs immediately after or just at the time that the rotary-armature 225 strikes the pole-pieces. 75 When the rotary-pawl 229 advances, as described, to engage the longitudinal teeth, the rotary-armature-finger 234 comes into contact with the private-armature 236, depressing the latter (at the same time that the rotary-pawl produces a rotation of the shaft) to a degree determined by the adjustment of the mechanism. As the shaft begins to rotate the cam 178 very soon passes out of reach of the lug 254, thus permitting the escapement-finger 252 to fall against the lower foremost tooth 248 before the rotary-armature-finger 234 depresses the private-armature 236 too far. Immediately after, however, the said tooth 248 is cleared by the finger 252, which latter then falls against the upper foremost tooth 246 just at about the 80 time that the shaft-wipers are rotated onto the first contact of the second level of their 85 90 95 100 105 110 115 120 125

respective banks. As soon as the energizing circuit through the rotary-magnet 222 is interrupted, as described, the rotary-armature 225 begins to return to its normal position, 5 and the private-armature as well, following up the receding movement of the rotary-armature-finger 234. It will be evident that as soon as the said private-armature carries the escapement-tooth 246 to a given height 10 the side-switch is left to the action of the side-switch retracting-spring 253, which latter draws the side-switch to third position with the escapement-finger 252 resting against the side-switch-stop 260. The interrupter being of the type described the side-switch shifts to third position, as stated, before the interrupter-springs 232 and 233 re-engage, so that the energizing circuit that has been described for the rotary-magnet is 15 permanently opened or destroyed when the side-switch-wiper 255 leaves the contact-point 265 and passes to third position in engagement with the contact-point 269. When the motion of the rotary-armature ceases 20 permanently the calling operation of the first-selector is completed, the shaft-wipers 175, 176 and 177 having seized an idle trunk-line through the first contacts of the second level of their respective banks. The line-wipers thus appropriate to their use two trunk-conductors for talking purposes, and the private-wiper a trunk-line for releasing purposes, similar talking conductors 393 and 394 being shown connected to the tenth set 25 of contacts of the second level of the line-bank, and a similar releasing trunk 395 being shown connected to the tenth contact of the corresponding or second level of the private-bank 173. The seized trunk-line is protected against further seizure by a guarding potential that is provided at the private-wiper and, therefore, at the first contacts of the second level of the private-banks of all first-selectors of the same group to which 30 the first-selector D belongs. Said guarding potential is established by reason of a connection between the ground terminal of battery B and said contacts, by way of the ground terminal G⁸, side-switch contact-point 270 of the first-selector D, side-switch-wiper 256, conductor 396, back-release-relay 195, conductor 397 and private-wiper 177. It will be evident, therefore, that the first-selectors of each group, as here illustrated, 35 are provided with a hundred trunk-lines (ten to each level) from which they may select for trunking purposes. At the time of use each trunk is protected by a guarding potential that extends throughout the group; and if, as may at any time be the case, the first nine trunk-lines of the second level are in use a guarding potential would be at each one of the first nine private-contacts of the second level of all the private-banks in the group. If such a condition exists at the 40 time that the rotary-line-relay of the selector is energized, the wipers of which have been raised to the second level, the rotation of the shaft will begin in a step-by-step manner, not to cease until after the wipers have 45 been carried into engagement with some idle trunk-line. Assuming that such is the case—that is, that the first nine trunk-lines of the second level are busy at the time that the rotary-line-relay 189 of the first-selector 50 D is energized by the ground impulse given to the rotary-trunk-conductor 379, as previously explained, the first-selector-shaft will be rotated in a step-by-step manner until the wipers are carried beyond the first 55 nine trunks and brought onto the tenth terminal of the second level of their banks. To explain: The first nine private-contacts being grounded, then when the calling subscriber energizes the rotary-line-relay 189 60 the side-switch is tripped into second position, as before, at which time the energizing circuit through the rotary-magnet is established for producing a rotation of the shaft. The energizing circuit, it will be remembered, is established as soon as the side-switch-wiper 255 engages the side-switch contact-point 265, at which time the rotary-armature 225 is attracted by the rotary-magnet 222. The shaft is, therefore, rotated one 65 step, as described, so that the line and private wipers are carried into engagement with the second terminal of the first level of their respective banks. At such time, it will be remembered, the private-armature is depressed by the rotary-armature-finger 234, and at the end of the forward or attractive stroke of said rotary-armature the interrupter-springs are forced apart after destroying the energizing circuit through the 70 rotary-magnet. There being a guarding potential at the first contact which the private-wiper meets a circuit is established through the private-magnet 235 which extends from ground G of the battery B through the private-wiper of whatever first-selector is occupying the first trunk of the second level in question, and through the bank multiplying conductor to the contact-point with which the private-wiper has engaged, through the 75 said private-wiper 177, conductor 397, back-release-relay 195, conductor 396, side-switch-wiper 256, contact-point 266, conductor 391, and private-magnet 235 to the battery-lead 350, and from the non-grounded terminal of 80 battery B to ground G. The private-armature is thereby retained depressed after the deenergization of the rotary-magnet 222, since the escapement-finger 252 is held by the upper foremost escapement-tooth 246, 85 the side-switch-wiper 255 being, therefore, retained in engagement with the grounded contact-point 265. As soon as the interrupter-springs reengage, of course, the energizing circuit is once more closed through 90

the rotary-magnet. As a result the rotary-armature 225 is again attracted, the shaft is rotated one more step, and the private-wiper 177 is moved onto the second terminal of the 5 second level of the private-bank 173. The said second contact being also grounded the energizing circuit through the private-magnet is maintained and the side-switch is not liberated when the rotary-armature returns 10 again to normal position. Clearly, then, the shaft will be advanced step by step as long as the private-wiper 177 continues to meet grounded private-contacts. After being rotated onto the ninth contact the private- 15 wiper is rotated one more step and brought into engagement with the tenth contact of the second level of the private-bank; but as this last contact is devoid of guarding potential, and as soon as said wiper leaves the 20 ninth contact, the energizing circuit through the private-magnet that has up to this time maintained said magnet energized is then broken. This deenergization of the private-magnet occurs at just about the time when 25 the rotary-armature 225 is at the end of its attractive stroke, so that the private-armature that has up to this time held the side-switch in second position by the magnetizing force that has now disappeared from 30 the private-magnet falls back upon the rotary-armature-finger 234 and follows said finger as the rotary-armature returns to its normal position. Between the time that the private-armature is released by the private- 35 magnet and the time that the rotary-armature 225 fully regains its normal position the escapement-finger 252, which is, during the rotation of the shaft, kept resting against the foremost upper tooth of the escapement- 40 spring 243, disengages from said tooth; at which time, therefore, the side-switch passes into third position, as already stated. It is then that the side-switch-wipers leave the 45 contact-points 265, 266, 267 and 268, respectively, and pass onto the contact-points 269, 270, 271 and 272. The shifting of the side-switch and, therefore, the disengagement of the side-switch-wiper 255 from the contact-point 265 occur just before the interrupter- 50 springs 232 and 233 reengage, so that the circuit through the rotary-magnet 222 is for the time being permanently broken. The engagement of the side-switch-wiper 256 (in this third position) with the grounded side- 55 switch contact-point 270 provides the private-wiper 177 with a guarding potential to protect the line seized by the wipers 175 and 176, as described. It will be evident that as soon as the side-switch-wipers 257 and 258 60 pass onto the side-switch contact-points 271 and 272, when the side-switch passes to third position, the subscribers' extended line-conductors 374 and 379 are then connected by way of the selected trunk-conductors 393 and 65 394 with the second-selector E, as shown in

Fig. 21. If the subscriber after having trunked to the second-selector, as described in the foregoing, were to hang up his receiver before his call is completed, his individual-switch and the first-selector-switch 70 would be released together. The simultaneous ground impulses sent through the release-springs 152, 153 and 154 would be received by the repeater vertical and rotary line-relays 163 and 164, and a release 75 impulse would be sent from them backward, so to speak, to the individual-switch for releasing the latter, and the two original ground impulses will be repeated, as already pointed out, to the vertical and rotary trunk-conductors by the engagement of the line-relay springs 167, 168 and 169. If the first-selector-shaft is simply raised and the side-switch is in first position, the vertical and rotary line-relays 188 and 189 of the first- 80 selector will be energized simultaneously over paths already traced. The rotary-line-relay 189 upon attracting its armature, as is well known, will energize the private-magnet 235, which latter will then cause the 85 private-spring 241 to leave the private-spring 240 and engage with the spring 242, thereby placing the line-relay-spring 192 directly in connection with the release-magnet 212. The vertical-line-relay 188 upon attracting its armature during such a time establishes an energizing circuit through the release-magnet 212 from ground G⁵ through the line-relay-springs 194 and 192, conductor 388, private-springs 241 and 242, conductors 398 and 399, release-magnet 212 to the battery-lead 350, and from the non-grounded terminal of battery B to ground G. The release-magnet, of course, upon attracting its armature causes the release-link 209 to 90 engage the double-dog 215 at the pin 220, and when the subscriber's receiver carries the switch-hook to the point where the release-springs 152, 153 and 154 are disengaged the ground connection to the vertical 95 and rotary line-conductors is destroyed, the vertical and rotary line-relays 163 and 164 of the repeater are deenergized, the individual-switch A is released, and the first-selector release-magnet deenergizes immediately upon the deenergization of the vertical and rotary line-relays 188 and 189, and restores the switch-shaft to its normal position by depriving the latter of the support given it by the vertical-dog 217. Should the release be initiated while the first-selector side-switch is in second position the 100 same circuits and the same parts will be actuated with the same results save that the switch-shaft 174 will first be rotated (by the coil-spring) upon the shaft-rest 184 until the normal-post-arm 185 strikes the normal-post 186, when the release-magnet is deenergized, at which time the shaft falls to its 105 normal position, as before. Should the first- 110 selector release-magnet deenergize while the switch-shaft 174 is in second position, the 115 same results will be obtained, save that the switch-shaft 174 will first be rotated (by the coil-spring) upon the shaft-rest 184 until the normal-post-arm 185 strikes the normal-post 186, when the release-magnet is deenergized, at which time the shaft falls to its 120 normal position, as before. Should the first- 125 selector release-magnet deenergize while the switch-shaft 174 is in third position, the 130 same results will be obtained, save that the switch-shaft 174 will first be rotated (by the coil-spring) upon the shaft-rest 184 until the normal-post-arm 185 strikes the normal-post 186, when the release-magnet is deenergized, at which time the shaft falls to its normal position, as before.

selector side-switch be in third position when the release is initiated, the release of the first-selector occurs in a somewhat different manner, as will be described. The 5 subscriber not having released, however, and his line-conductors having been extended to the second-selector E, the subscriber, by pressing the vertical-button twice for the second digit of the number 2211, causes the 10 vertical-trunk-conductor 374 to be grounded twice, as before, so that the second-selector vertical-line-relay 275 is now energized twice in succession by a flow of current through a circuit that extends from ground 15 G^5 at the repeater C to the vertical-trunk-conductor 374 and to the first-selector side-switch-wiper 257, thence to the contact-point 271, conductor 400, vertical-line-wiper 175, vertical-trunk-conductor 393, second-selector 20 side-switch-wiper 401, contact-point 402, vertical-line-relay 275 to the battery-lead 350, and from the non-grounded terminal of battery B to ground G. The vertical-line-relay upon attracting its armature, as described in connection with the first-selector, operates the vertical-magnet 403 twice, the circuit of which latter, it will be understood, being very similar to that of the first-selector, extending from ground G^9 through the 25 line-relay-springs 404 and 405, private-springs 406 and 407, vertical-magnet 403 to the battery-lead 350, and from the non-grounded terminal of battery B to ground G. In this way the shaft is raised two steps. 30 By pressing the rotary-button 158 once the subscriber causes the rotary-trunk-conductor 379 to be grounded once, and as a result the rotary-line-relay 276 of the second-selector is energized from the ground terminal G^5 35 at the repeater C to the rotary-trunk-conductor 379, first-selector side-switch-wiper 258, contact-point 272, conductor 408, rotary-line-wiper 176, rotary-trunk-conductor 394, second-selector side-switch-wiper 409, 40 contact-point 410, through the rotary-line-relay 276 to the battery-lead 350, and from the non-grounded terminal of battery B to ground G. The second-selector shaft-wipers 411, 412 and 413 having been raised 45 to the second level, as stated, the rotary-line-relay 276 upon attracting its armature causes the private-magnet 414 to be energized once and to initiate thereby the rotary movement of the switch-shaft as soon as the 50 second-selector side-switch passes to second position. If the first nine trunks of the second level are busy the second-selector shaft-wipers will be rotated onto the tenth contacts of the second level of their respective 55 banks. The conductors 415 and 416 are shown terminating in the tenth set of contacts of the second level of the line-bank 417, and the trunk-release-conductor 418 is shown terminating in the tenth contact of the second level of the private-bank 419, all 60 of which conductors terminate in a repeater C clearly shown in Fig. 21. As soon as the calling operation of the second-selector comes to an end the subscribers' extended line-conductors 393 and 394 are connected to the trunk-conductors 415 and 416, respectively, the first through the side-switch-wiper 401, contact-point 420, conductor 421 and vertical-line-wiper 411 to the 65 said vertical-trunk-conductor, and the second through the side-switch-wiper 409, contact-point 422, conductor 423 and rotary-line-wiper 412 with the rotary-trunk-conductor 416. If the subscriber attempts a release while the second-selector side-switch 70 is in first or second position the vertical and rotary line-relays of the second-selector (like the vertical and rotary line-relays of the first-selector during a similar process, and described in the preceding) become 75 energized simultaneously over circuits that have already been described. The trunk-release-springs 277 and 278 in the said second-selector under the control of the second-selector line-relays being similar to the ones 80 described in the repeater C, when the said line-relays 275 and 276 are energized simultaneously, the said springs press into contact. As a result an energizing circuit is 85 established through the second-selector release-magnet 424 in series with the first-selector back-release-relay 195. Current in this circuit passes from ground G^8 at the 90 first-selector to the contact-point 270, side-switch-wiper 256, back-release-relay 195, 95 private-wiper 177, trunk-release-conductor 395, second-selector trunk-release-springs 278 and 277, conductor 425, second-selector release-magnet 424 to the battery-lead 350, and from the non-grounded terminal of 100 battery B to ground G. As a result both the second-selector release-magnet 424 and the first-selector back-release-relay 195 become energized simultaneously, with the result 105 that the second-selector release-armature 110 426 is attracted and the release-link 427 is thrust forward to engage the double-dog 428 at the lug 429, and the first-selector back-release-relay-armature 196 causes the 115 back-release-relay-springs 197 and 198 to 120 press into contact. As a result of this latter operation the first-selector release-magnet 212 is energized over a circuit that extends from ground G^{10} through the back-release-relay-springs 197 and 198, release-magnet 212 125 to the battery-lead 350, to the non-grounded terminal of battery B and to ground G. As soon as the releasing subscriber's switch-hook clears the release-springs 152, 153 and 154 the repeater line-relays 163 and 164 130 are deenergized, the individual-switch A is released, the second-selector line-relays are deenergized, and as a result the second-selector release-magnet 424 and first-selector back-release-relay 195 are deenergized, re- 135

sulting in the restoration of the said second-selector and first-selector in a manner already pointed out. If the subscriber attempts a release while the second-selector 5 side-switch is in third position other circuits are involved in the release that will be described hereinafter. If the subscriber extends his line to the repeater C¹, as described, then when he presses the vertical-10 button 157 once for the third digit of the number 2211 he energizes the repeater vertical-line-relay 430 once. The energizing circuit in this case extends from the repeater ground G⁵ to the vertical-trunk-conductor 15 374, side-switch-wiper 257 of the first-selector D, contact-point 271, vertical-line-wiper 175, vertical-trunk-conductor 393, side-switch-wiper 401 of the second-selector E, contact-point 420, vertical-line-wiper 411, 20 vertical-trunk-conductor 415 to the repeater vertical-line-relay 430, to the battery-lead 350, and from the non-grounded terminal of battery B to ground G. As a result the repeater vertical-line-relay is energized once, 25 causing the vertical-trunk-conductor 431 to be given a ground impulse by pressing the line-relay-springs 432 and 433 together. The grounding of the said vertical-trunk-conductor will hereinafter be considered. 30 When the subscriber presses the rotary-button 158 once (to ground the rotary-line-conductor 351 once) the rotary-trunk-conductor 379 is thereby grounded once, so that the repeater rotary-line-relay 434 is energized 35 once over a circuit as follows: from the usual ground terminal G⁵ at the repeater C to the rotary-trunk-conductor 379, first-selector side-switch-wiper 258, contact-point 272, rotary-line-wiper 176, rotary-trunk-conductor 394, second-selector side-switch-wiper 409, contact-point 422, rotary-line-wiper 412, rotary-trunk-conductor 416, repeater rotary-line-relay 434 to the battery-lead 350, and from the non-grounded 40 terminal of battery B to ground G. The rotary-line-relay 434 in turn causes the rotary-trunk-conductor 435 to be grounded once by forcing the springs 436 and 433 into contact, the grounding of which conductor 435 will 45 be referred to later on. Having extended his line-conductors to the repeater C¹ the subscriber #1122 (if he should initiate a release) will cause the repeater line-relays 163 and 164 at the repeater C to be energized 50 simultaneously, thereby energizing the release-magnet 7 of the individual-switch A and grounding the vertical and rotary trunk-conductors 374 and 379 simultaneously in the well-known manner. The vertical and rotary line-relays 430 and 434 of the repeater C¹ will likewise be energized simultaneously. As a result the vertical and rotary trunk-conductors 431 and 435 will 55 be grounded simultaneously, with an effect 60 to be hereinafter disclosed. The bringing together of the trunk-release-springs 437 and 438 by the simultaneous energization of the said line-relays causes the second-selector back-release-relay to be energized in series with the dead-resistance coil 439 at the 65 repeater C¹. As a result the back-release-relay 440 of the second-selector is energized by current flowing by ground G¹¹ to the second-selector side-switch-contact-point 441, side-switch-wiper 442, back-release-relay 70 75 440, private-wiper 413, trunk-release-conductor 418, trunk-release-springs 437 and 438 of the repeater C¹, resistance-coil 439 to the battery-lead 350 and to the non-grounded terminal of battery B to ground G. 80 The energization of the second-selector back-release-relay causes the latter to attract its armature 443 and to thereby close the springs 444 and 445, at which instant an energizing circuit is established through the second-selector ground terminal G⁸ 85 90 through the side-switch-wiper 256, back-release-relay 195, private-wiper 177, trunk-release-conductor 395, back-release-relay-springs 444 and 445, release-magnet 424 to the battery-lead 350 and to the non-grounded terminal of battery B to ground G. When the release-magnet 424 of the second-selector is energized it attracts its armature and the release-link 427 then engages the double-dog 428 in a well-known manner, and at the same 95 time the energization of the back-release-relay 195 of the first-selector causes said relay to attract its armature and thereby energize the release-magnet 212 of the said first-selector. When the releasing subscriber permits his switch-hook to descend 100 far enough so that the release-springs 152, 153 and 154 may again separate, the line-relays 163 and 164 of the repeater C become deenergized. The energizing circuit through the release-magnet 7 is destroyed and the individual-switch-plunger 3 is withdrawn 105 into normal position, thereby permitting the bank-springs 371 and 372 to separate and the springs 376 and 377 to do likewise. At the same time the line-relays 430 and 434 110 115 of the repeater C¹ become deenergized, so that the said switches are all restored. The vertical and rotary trunk-conductors 431 and 435 leading from the repeater C¹ being connected to the connector F, as shown in Figs. 21 and 22, the ground impulse given the vertical-trunk-conductor 431 (if the calling subscriber proceeds to complete his connection instead of releasing) energizes the connector vertical-line-relay 294 once. The energizing 120 125 130 circuit in this case extends from the repeater

ground G^{12} to the vertical-trunk-conductor 431, vertical-line-relay 294 of the connector F to the battery-lead 350, and from the non-grounded terminal of battery B to ground 5 G. The vertical-line-relay 294 on attracting its armature once energizes the vertical-magnet 298 once over a circuit that extends from ground G^{12} through the line-relay-springs 446 and 447, conductor 448, private-springs 10 318 and 317, conductor 449, side-switch-wiper 450, contact-point 451, conductor 452 to the vertical-magnet 298, battery lead 350, and through battery B to ground G. The connector-shaft is in this way raised one 15 step and the shaft-wipers 282, 283 and 284 are thus raised and placed opposite the first contacts of the first level of the line and private banks 279 and 280. The grounding of the rotary-trunk-conductor 435, when the 20 calling subscriber energizes the rotary-line-relay 434 of the repeater C¹ by pressing the rotary-button 158 for the third digit, energizes the rotary-line-relay 295 of the connector once through a circuit that extends 25 from the repeater ground terminal G^{12} to the rotary-trunk-conductor 435, connector rotary-line-relay 295 to the battery-lead 350, and from the non-grounded terminal of battery B to ground G. As a result of this energization of the rotary-line-relay 295 the 30 connector private-magnet 314 is energized once by current flowing from the ground terminal G^{12} through the line-relay-springs 446 and 453, conductor 454, private-magnet 314, the battery-lead 350, and from the non-grounded terminal of battery B through the latter to ground G. When the private-magnet energizes and deenergizes the side-switch passes to second position, and at the same 40 time the private-springs 319 and 320 are brought into contact, but their engagement at this time is without effect. When the side-switch passes to second position the side-switch-wiper 450 engages the contact-point 455, and the shifting of said side-switch-wiper produces a change in the circuits of the connector, whereby when the vertical-button 157 is pressed once for the last digit the rotary-magnet 323 (instead of 45 the vertical-magnet 298) is operated once when the line-relay-springs 447 and 446 are brought into contact. When the said springs are closed a current is sent from ground G^{12} through the springs 446 and 447, springs 50 55 318 and 317, side-switch-wiper 450, contact-point 455 and rotary-magnet 323 to the battery-lead 350 and to the non-grounded terminal of battery B and to ground G. When the rotary-magnet 323 is energized its armature 324 is attracted and rotates the shaft 60 65 281 one step, thereby sliding the wipers 282, 283 and 284 onto the first contact of the first level of their respective banks. Then for the last time the rotary-button 158 is pressed once, the said rotary-line-relay 295 again causes the private-magnet 314 to become energized, and to thus cause the side-switch to pass to third position with the wipers 450, 456, 457 and 458, respectively, in contact with the contact-points 459, 460, 461 and 462. The closure of connection between the side-switch-wipers 457 and 458 and contact-points 461 and 462, respectively, connects the calling subscribers' extended line-conductors 431 and 435 through the condensers 321 and 322 to the vertical and rotary line-wipers 282 and 283, respectively, and, therefore, with the normal-conductors 463 and 464 that constitute the terminals of the called line. The engagement of the side-switch-wiper 456 with the contact-point 460 places a guarding potential at the private-wiper 284, at the first private-contact of the first level of the private-bank 280, and at all other private-contacts that are connected in multiple thereto, to preclude any other subscriber from entering in upon the called line. The establishment of this guarding potential not only protects the called line from further seizure, but also forces a current through the cut-off-relay 465 of the called individual-switch A¹ of the called line in order that the relay (by means of its armature) may separate the line-relay-springs 466, 467 and 468 to remove the short-circuit already described across the called subscriber's line. The energizing circuit through the said cut-off-relay may be traced from the ground terminal G^{14} at the connector-switch F, contact-point 460, side-switch-wiper 456, conductor 469, private-wiper 284, private-normal-trunk-conductor 470, cut-off-relay 465 to the battery-lead 350, and from the non-grounded terminal of battery B through the latter to ground G. When the cut-off-relay-armature is attracted the springs 466, 467 and 468 are separated to leave the line-conductors free for talking and signaling purposes. The connection between the calling and called lines having been established the calling subscriber is in a position to signal the called line by pressing his signaling-button 142. But before going further it may be explained that if for any reason the called line is busy at the time that the calling subscriber grounds the rotary-line-conductor 351 for the last time (as explained in the matter immediately preceding) to transfer the connector side-switch from second to third position, and to complete the connection, the connector is thereby released. For instance, if the line #2211 has been called by any other connector there will be a guarding potential at the first private-contact of the first level of the private-bank 280 corresponding to the line of the sub-station #2211. Or, on the other hand, if the individual-switch A¹ of the called line is being used, the same private-bank-contact will be connected to ground

from the instant that the plunger of the individual-switch A¹ forces the bank-springs 471 and 472 into contact. This last guarding potential will reach the private-bank of the connector by way of the private-normal-conductor 470. At any rate, if the private-wiper 284 finds a guarding potential at the said first contact of the first level of the private-bank at the instant that the calling subscriber grounds his rotary-line-conductor 351 for the last time, the said connector will be released, and the side-switch will not shift to third position, because the private-magnet 314 on becoming energized as a final result of grounding the said rotary-line-conductor 351 completes an energizing circuit through the release-magnet of the connector that includes the private-wiper 284 when the armature of the said private-magnet 20 forces the private-springs 319 and 320 into contact. The energizing circuit through the said release-magnet may be traced from the ground terminal G of battery B to the first level of the connector private-bank 280, through the private-contact with which the private-wiper 284 is in engagement at the time, conductor 469, side-switch-wiper 456, contact-point 473, conductor 474, private-springs 319 and 320, conductors 475 and 476 and release-magnet 300 to the non-grounded terminal of battery B and to ground G. The connector release-magnet 300 being thus energized the release-armature 301 strikes the double-dog 303 to the right of the bearings 307, so that the lug 306 is driven under and caught in the aperture 308 in the end of the link 304. The shaft being thus unlocked by the removal of the rotary-locking-dog 477 of the double-dog 303 is then free to rotate back toward its normal rotary position, impelled by the tension in the coil-spring 290, which rotation ceases only when the normal-post-arm 289 strikes the normal-post 478. The shaft is deprived of its support when the shaft-rest 291 finds the longitudinal slot 288, at which time the shaft of necessity falls to normal position. The release-armature 301, by rotating the double-dog 303 to normal position, as stated, causes the latter, by means of the double-dog release-arm 309, to drive the side-switch to its normal position about the pivots 479 of the latter, and through the medium of the link 480. The said release-arm, by pressing the said link back, forces the escapement-finger 310 back between the springs 311 and 312, which finger is then caught behind the rear-most lower tooth 315. The restoration of the connector-shaft, as stated, begins even while the release-magnet is in an energized state; but since the energizing circuit through said magnet comprises the private-wiper 284 and the side-switch-wiper 456, it will be evident that when the shaft rotates back toward normal position, and when the said side-switch-wiper is forced away from the contact-point 473, the energizing circuit will then be destroyed at two points, at which time the connector release-armature 301 regains its normal position. The calling subscriber thinking he has established connection presses the signaling-button 142 to signal the called line, with the result that the vertical-line-conductor 345 is grounded, and this causes, of course, the energization of the connector vertical-line-relay 294 in the usual manner. Since the connector side-switch is in first position the latter relay produces in turn the energization of the connector vertical-magnet 298 through a circuit that is already familiar, when the line-relay-springs 446 and 447 are pressed into contact. When the signaling-button 142 is pressed the ground connection to the vertical-line-conductor 345 is not established from the ground-post 149, as it is when the vertical and rotary buttons 157 and 158 have been pressed, but instead from the contact-point 143 through the following circuit: from ground G¹ through the ground-springs 151 and 150 to the contact-point 143, signaling-button-spring 141, springs 144 and 145, contact-point 159, spring 161 to the vertical-line-conductor 345. As a result, and by means previously described, the shaft of the connector is raised, and the springs 292 and 293 which it controls through the medium of the normal-post-arm 289 are brought into contact. Upon the engagement of these two springs 292 and 293 a busy-signal circuit is established through the receiver of the calling subscriber, the busy-signal current for which circuit may be generated in any suitable apparatus well known in the art, as in the winding 481 of the induction-coil 482 shown in Fig. 21. The path of this busy-signal current may be traced from coil 481 to conductor 483, shaft-springs 293 and 292, side-switch-wiper 458, ringer-relay-springs 330 and 329, condenser 322, rotary-trunk-conductor 435, condenser 484 at the repeater C¹, trunk-conductor 416, second-selector rotary-line-wiper 412, contact-point 422, side-switch-wiper 409, trunk-conductor 394; first-selector rotary-line-wiper 176, contact-point 272, side-switch-wiper 258, rotary-trunk-conductor 379, condenser 171 of repeater C, trunk-conductor 353, individual-switch bank-springs 377 and 376, rotary-line-conductor 351, through the receiver 138 and secondary winding 139 of the induction-coil 134 at substation #1122 to the vertical-line-conductor 345, thence through the individual-switch A, bank-springs 371 and 372, vertical-trunk-conductor 352, condenser 170 at the repeater C, vertical-trunk-conductor 374, first-selector side-switch-wiper 257, contact-point 271, vertical-line-wiper 175, vertical-trunk-conductor 393, second-selector side-switch-wiper 130

401, contact-point 420, vertical-line-wiper 411, vertical-trunk-conductor 415, vertical-line-relay 430 of the repeater C¹ to the battery lead and back to the coil 481. The calling subscriber learning, therefore, that the desired line is busy will restore his receiver to its hook, thereby grounding simultaneously, in a familiar manner, the vertical and rotary line-conductors 345 and 351. As a result, therefore, the vertical and rotary line-relays 163 and 164 of the repeater C will be energized simultaneously. The release-magnet 7 of the individual-switch A, in a familiar manner, will be energized, and at the same time the vertical and rotary line-relays 430 and 434 of the repeater C¹ will also be energized. The last repeater thus causes the energization of the second-selector release mechanism, and the second-selector in turn causes the energization of the first-selector release mechanism, as heretofore described, the repeater at the same time grounding the vertical and rotary trunk-conductors 431 and 435, whereby the vertical and rotary line-relays of the connector F are momentarily energized. Said relays (upon pressing the release-springs 296 and 297 into contact) energize the release-magnet 300, which latter then causes the restoration of the connector-shaft 281. But as soon as the switch-hook of the releasing sub-station clears the release-springs 152, 153 and 154 there follows a deenergization of the line-relays of the repeater C and, therefore, a deenergization of the line-relays of the repeater C¹, so that the release-magnet of the connector F, and the release-magnets of the second and first selectors E and D, and of the individual-switch A, will become deenergized, upon which general deenergization there follows a full restoration of all the switches involved. But if, as described, the connection is established (the called line not being busy), the pressing of the signaling-button 142 grounds the vertical-line-conductor 345 over circuits described, and as a result the connector vertical-line-relay 294 is energized as before; but since the side-switch of the connector is in third position, when the vertical-line-relay 294 presses the springs 446 and 447 into contact, the ringer-relay 327 is, therefore, energized over a circuit as follows: from ground G¹² through the line-relay-springs 446 and 447 to the side-switch-wiper 450 and contact-point 459, thence through the ringer-relay 327 to the battery-lead 350, to the non-grounded terminal of battery B and to ground G. As a result the ringer-relay attracts its armature 328, which latter then forces the ringer-relay-springs 330 and 333 away from the normally engaging springs 329 and 332 and onto the generator terminal springs 331 and 334, whereby a ringing current is projected onto the called line. The path by which this ring-

ing current reaches the called subscriber's ringer or call-bell may be traced from the ringer-generator 335 through the ringer-relay-springs 334 and 333, side-switch-wiper 457, contact-point 461, conductor 485, vertical-line-wiper 282, vertical-normal-conductor 463, vertical-line-conductor 486 to the switch-hook 487, thence to the ringer-spring 488 and through the ringer 489 to the rotary-line-conductor 490, rotary-normal-conductor 464, rotary-line-wiper 283, conductor 491, contact-point 462, side-switch-wiper 458, ringer-relay-springs 330 and 331, and back to the ringer-generator 335. The called subscriber upon receiving the audible call-signal removes his receiver from the switch-hook, thereby interrupting the ringing current when the switch-hook leaves the ringer-spring 488, and substituting across the line his receiver 492 in series with the secondary winding 493, whereby when the calling subscriber releases his signaling-button 142 and thereby restores the ringer-relay 327 and springs 330 and 333 he may converse with the calling subscriber. The sub-station receivers 138 and 492 and secondary windings 139 and 493 of the induction-coils 134 and 495, respectively, are connected in series, and each of said induction-coils is associated with a primary winding, local battery and transmitter, as shown. The method by which voice-currents are produced and reproduced need not be described. It will be clear, however, that the circuit over which the two receivers and their respective induction-coils are connected is as follows: from the receiver 138 of the calling sub-station #1122, through the secondary winding 139 to the vertical-line-conductor 345, thence through the bank-springs 371 and 372 of the individual-switch A, and through the condenser 170 of the repeater C over the trunk-conductor 374 to the first-selector D, thence through the side-switch-wiper 257, vertical-line-wiper 175 and vertical-trunk-conductor 393 to the second-selector side-switch-wiper 401, vertical-line-wiper 411 and vertical-trunk-conductor 415 to the condenser 496 at the repeater C¹, thence over the vertical-trunk-conductor 431 to the connector condenser 321, ringer-relay-springs 332 and 333, side-switch-wiper 457, vertical-line-wiper 282, vertical-normal-conductor 463 and vertical-line-conductor 486 to the secondary winding 493 at the sub-station #2211, thence through the receiver 492 and back over the rotary-line-conductor 490, rotary-normal-conductor 464 and connector rotary-line-wiper 283, side-switch-wiper 458, ringer-relay-springs 330 and 329 and condenser 322 to the rotary-trunk-conductor 435 and condenser 484 at the repeater C¹ to the rotary-trunk-conductor 416, second-selector rotary-line-wiper 412, side-switch-wiper 409 and rotary-trunk-conductor 394 to the first-selector rotary- 130

line-wiper 176, side-switch-wiper 258 and rotary-trunk-conductor 379 to the condenser 171 of the repeater C, passing through which it extends over the rotary-trunk-conductor 5 353 to the bank-springs 377 and 376 of the individual-switch A to the rotary-line-conductor 351 and back to the receiver 138. After the two subscribers have communicated, and if the calling subscriber delays in destroying the established connection at a time when the called subscriber wishes to make a call, and unless special provision is made whereby the called subscriber may disconnect the calling connector from across the 10 line, the called subscriber will then be tied up, so to speak, for the time being. This, it will be evident, is by reason of the fact that the individual cut-off-relay 465 of the individual switch A¹ is energized, whereby the 15 trip-magnet 497 of said individual-switch is rendered inoperative as long as the said cut-off relay is energized, because the circuit of said trip-magnet terminates in the spring 466 under the control of the said relay 465. The called subscriber, with the arrangement provided herein, and by restoring his receiver to the switch-hook, can momentarily and simultaneously ground the vertical and 20 rotary line-conductors 486 and 490, whereby the 25 back-bridge-relays 336 and 337 of the connector F may be energized at the same time. In this event the said relays force the springs 338 and 339 into contact, thereby establishing an energizing circuit through the 30 connector release-magnet 300 from ground 35 G¹⁵ through the said springs 338 and 339, and through the said release-magnet to the battery-lead 350, and from the non-grounded terminal of battery B through the latter 40 to ground G. The energizing circuit for the vertical back-bridge-relay 336 is from ground G¹⁶ at the sub-station #2211 through the release-springs 498, 499 and 500 to the vertical-line-conductor 486 and vertical- 45 normal-conductor 463, connector vertical-line-wiper 282, side-switch-wiper 457 and ringer-relay-springs 333 and 332, through said relay 336 to the battery-lead 350 and to the non-grounded terminal of battery B 50 to ground G. The energizing circuit for the rotary-back-bridge-relay 337 is from ground G¹⁶ through the release-springs 498 and 499 to the rotary-line-conductor 490, rotary-normal-conductor 464, connector rotary-line-wiper 283, side-switch-wiper 458, ringer-relay-springs 330 and 329 and through said 55 relay 337 to the battery-lead 350 to the non-grounded terminal of battery B to ground G. The energization of the connector release-magnet, of course, will restore the connector-switch-shaft and thereby destroy the energizing circuit through the cut-off-relay 465 of the individual-switch A¹, after which 60 operation the called subscriber #2211 may then proceed to make his call, if he desires, 65 by operations and through apparatus similar to those described in connection with the subscriber #1122 in the preceding. But in the event that the calling subscriber should restore his receiver first he will, in a manner 70 that has been divulged, energize the releasing apparatus of the connector, and of all the other switches intermediate the said connector and the calling sub-station #1122, thus restoring all of said switches. Together with the restoration of the connector F there follows, of course, a restoration of the line-relay 465 of the individual-switch A¹ of the called line. Referring to Fig. 14 it will be noticed that the plate j which is 75 shown in Figs. 10 and 11 is cut into four sections, the first section corresponding to the contact 110 of the first position; the second section 385 corresponding to the succeeding four positions that the wiper 67 may 80 assume; the next section corresponding to the next succeeding four positions; and the last section corresponding to the last position. The object of this arrangement is to 85 overcome a possible difficulty that would become apparent were said sections all connected in one plate, as shown in Fig. 16, and without other special arrangement to be described. For instance, if the wiper 67 after traveling in the usual step-by-step 90 manner reaches the tenth position in engagement with the contact 363, then if a subscriber comes in and appropriates to his use the tenth trunk and thereby makes the tenth 95 contact 363 busy, the cam with which the wiper 67 is rigidly connected, as described, clears the pin over which it has been sliding during that phase. Then as a result, previously described and now well-known, the wiper 67 is started back over the first nine 100 contacts. Assuming that all the contacts save the first contact 110 are busy at the time that the wiper starts on this backward run, the differential-magnet 63 which is 105 energized at the instant that the aforesaid subscriber seizes the tenth trunk-line remains 110 energized as long as the wiper 67 is passing over the next succeeding eight busy contacts. During this interval of backward rotation the rotary-armature 81 that rotates the plunger-shaft 25 has time to return to normal 115 position, and to restore the energizing circuit again through the rotary-magnet 61. In other words, referring to Fig. 10, if the wiper 67 is resting upon the contact 363 120 when the pin 109 is resting in engagement with the tip of the cam 66 and all bank-contacts of the bank R are busy except the contacts 363 and 110, then if a subscriber 125 operates his individual-switch he will make the contact 363 busy also. As a result the motor-magnet 61 will be energized over well-known circuits to advance the ratchet-wheel 64 one step; but the energizing circuit through the differential-relay 63, Fig. 14, is 130

not destroyed since the wiper 67 must pass over eight succeeding busy contacts from the time that the pin 109 leaves the tip end of the cam 66 until the said cam falls against the pin 71. During that interval of time it is, of course, appreciable that the armature of the motor-magnet 61 has time to return to normal position and to be energized once more so that the ratchet-wheel 64 is advanced one more step before the cam 66 reaches the pin 71, and, therefore, it will be impossible for the wiper 67 to travel any farther than the contact-point 112. The object in dividing the rear plate *j* (as shown in Fig. 14) into sections is to overcome this difficulty, as will be shown. But the number of sections of plate *j* which are shown in Fig. 14, as stated, is arbitrary and discovered by experiment. The number of sections will vary according to conditions. With the arrangement shown it is found that the wiper 67 will reach the contact-point 110 and will stop upon said contact if the said contact is not busy; and without such a provision as I have described, or some other suitable provision, the wiper will not stop on said contact. The following may be an analysis of what takes place in the differential-relay 63 during the aforesaid operation in connection with the divided plate *j*. If the wiper is on the tenth contact 363 it may be started on its backward rotation if the tenth trunk is then seized or temporarily appropriated by some subscriber. This backward rotation is started by the energization of the differential-relay 63. The energizing current then flows from the non-grounded terminal of battery B to the contact 363, through the said wiper to the rear contact *j*, coil 123, conductor 383, winding 120 of the differential-relay 63 to ground G^3 . But as the said wiper passes onto the ninth contact 112^a the circuit just described is destroyed and another circuit is established from the non-grounded terminal of battery B to the said contact 112^a, through the wiper 67 to the segment *j* behind said contact, winding 124, conductor 384 and coil 122 to the ground terminal G^3 , and so on, as long as the wiper is passing over the contacts 118^a, 501 and 502, it being evident that the current in this last circuit affects the differential-relay 63 in an opposite direction from the current described through the first contact and through the winding 123 of the auxiliary-coil 62. At the instant that the wiper leaves the tenth contact 363 and passes onto the next succeeding four in its backward motion the magnetism developed in the differential-relay by the first circuit begins to fall toward zero, and by the time that the wiper reaches the contact-point 502 the said magnetism has reached zero and developed in an opposite and negative direction, but not to a sufficient intensity to attract the armature 366. Again,

as the wiper passes from the contact-point 502 onto the next set of contacts, the magnetizing current through the differential-relay 63 is first discontinued in the second circuit and then reestablished through the original circuit, so that the magnetism of the differential-relay starts once more toward zero under the force of the energizing current in an opposite or positive direction. However, by this time the wiper 67 is traveling with considerable speed, so that the length of time that the said wiper remains upon the section controlled by the segment 385 is of too short duration to enable the magnetism in the differential-relay 63 to develop sufficient strength to attract the armature 366. Immediately after, the wiper 67 passes onto the idle contact 110, and the magnetism in the differential-relay dwindles to zero, with no undesirable results following. Another method by means of which the foregoing possible difficulty may be overcome, and which I also use, is to provide an insulated spring 503 above the contacts *j* under which the wiper 67 passes while moving to the left in a step-by-step manner, but over which it slides on its return to normal position. The construction of the master-switch-bank with such provision is shown in Fig. 16. As the wiper reaches the tenth contact 363 it clears the insulated spring and then passes back toward first position. As soon as it leaves the tenth contact it rides on the insulated spring 503 until the wiper reaches the first contact, at which time it drops off from said spring onto the first contact, and so on. It will be evident that with such arrangement the differential-relay 63 has sufficient time to deenergize by the time the wiper reaches the first contact, and if that contact is not busy the motor-magnet will not energize. Of course, with the latter arrangement the plate *j* will not have to be divided into sections, but is constructed of one piece, as shown. It will be clear that when the master-switch-banks of the type shown in Fig. 16 are provided the differential-relay 63 need then have but two windings, and the auxiliary-relay 62 but one winding, as shown in said figure. The arrangement would be as shown in said Fig. 16, where the back-plate *j* is all one piece. The auxiliary-relay 62 has one winding, and the differential-relay has only two windings 504 and 505, with a common central point to which the winding of the auxiliary-relay 62 is attached, the outer end of the winding 504 being connected to the grounded terminal of battery B, and the outer terminal of the other winding 505 being connected to the non-grounded terminal of battery B. With such arrangement, either grounded or non-grounded battery current applied to the common section *j* will energize said differential-relay 63 and cause an energizing cir-

cuit to be established through the inter-
rupter-magnet 61 when the armature of said
magnet is in normal position.

The two sub-stations #1122 and #2211
6 shown in Figs. 20 and 22 are changed in
Fig. 29 to #22 and #11 to adapt them to a
one-hundred subscriber system in which
each subscriber is provided with an individ-
ual-switch, and in which a small number
10 of connectors (ten for example) provide the
means for the establishment of connections
between the lines. The connector shown is
the same as connector F and is thus design-
ated, while the individual-switch on the
15 calling line is the same as individual-switch
A and is so designated. The individual-
switch on the called line is the same as the
individual-switch A¹ and is designated by
A¹. The master-switch is the same as
20 master-switch II and is designated by H.
In making the call the subscriber at sub-
station #22 proceeds as usual. Upon re-
moving his receiver the individual-switch
A selects, for example, connector F, one of
25 the ten connectors provided. To call the
number 11 he presses the vertical-button
157 once and the rotary-button 158 once,
then again the vertical-button once and the
rotary-button once. The individual-switch
30 having connected the subscriber's line in a
well-known manner directly with the con-
nector F (when the switch-hook rises) the
subscriber, by grounding the vertical-line-
conductor 345 once for the first time, raises
35 the connector-shaft one step. Grounding the
rotary-line-conductor 351 thereafter shifts
the connector side-switch to second position;
then grounding the vertical-line-conductor
again once rotates the connector-shaft one
40 step, and upon grounding the rotary-line-
conductor for the last time either the busy
release ensues or the connection is estab-
lished, as already pointed out. If the con-
nection is established in the usual manner,
45 he signals the called subscriber, with whom
he may converse after the said subscriber
has answered. The connection having been
made the calling subscriber may release by
restoring his receiver, thereby simultane-
50 ously grounding the vertical and rotary line-
conductors 345 and 351 and energizing the
vertical and rotary line-relays 294 and 295
of the connector F. As a result the trunk-
release-springs 296 and 297 are brought into
55 contact, whereby both the connector release-
magnet 300 and the release-magnet 7 of the
individual-switch A are energized in a
multiple circuit. The energizing circuit for
the release-magnet 300 may be traced in
60 Fig. 29 from the ground terminal G¹³
through the trunk-release-springs 296 and
297 and connector release-magnet 300 to the
non-grounded terminal of battery B and to
ground G. The energizing circuit through
65 the individual-switch release-magnet 7 ex-

tends from the same ground G¹³ through the
said trunk-release-springs 296 and 297, indi-
vidual-switch bank-springs 362 and 361,
through the release-magnet 7, and to the
non-grounded terminal of battery B and to 70
ground G. As a result the connector-shaft
281, Fig. 19, will be immediately restored,
as well as the connector side-switch, and
upon the restoration of the sub-station re-
lease-springs 152, 153 and 154 to normal 75
condition the release-magnet 7 of the indi-
vidual-switch A and the release-magnet 300
of the connector F, together with the line-
relays 294 and 295 of the connector F, will
be deenergized at once, resulting in a res-
toration of the individual-switch-plunger 3
in the manner described. It will be evident
from the foregoing that the cut-off-relay
465 of the called individual-switch A¹ will,
in this case, as in the case already described,
80 energize and deenergize, respectively, when
the connector-switch connects and discon-
nects from the normal-trunk conductors 463
and 464. If the called subscriber were to
restore his receiver before the calling sub-
85 scriber, the back-release-relays 336 and 337
of the connector F would be energized simul-
taneously, in a well-known manner, whereby
the back-release-relay-springs 338 and 339
would be brought into contact, and an ener-
gizing circuit thereby established through
90 the connector release-magnet 300 and indi-
vidual-switch release-magnet 7 from ground
G¹⁵ through the said springs 338 and 339
and release-magnet 300 to the non-grounded
95 terminal of battery B in one circuit, and
through the individual-switch bank-springs
362 and 361, through the individual-switch
release-magnet 7 to the non-grounded termi-
nal of battery B in the other. There will
100 then follow, of course, a release of the con-
nector-switch F, and immediately thereafter
a deenergization of both release-magnets,
with a full restoration of both switches.
When the connector is given the busy re-
105 lease, the private magnet 314 energizes for
the last rotary impulse, as explained, and
presses the springs 320 and 319 into engage-
ment, whereby an energizing circuit is not
only closed through the release magnet 300
110 of the connector, but also through the release
magnet 7 of the individual switch A, thus
bringing about the release of both the con-
nector F and the individual switch A. Now,
when the calling subscriber presses the sig-
115 naling button, the ground impulse to the
vertical line conductor 345 is transmitted
through the cut-off relay springs 38, 37 and
36 to the trip magnet 6, and the said indi-
vidual switch A is again tripped-in on a 120
trunk-line leading to a connector switch,
whereby when the bank springs 371 and
372 engage, the ground impulse is trans-
mitted to the connector vertical line relay
294, and in turn the connector is operated 125
130

and the normal springs 293 and 292 engage to connect the busy-signaling coil 481 with the trunk conductor 435 through the condenser 322, thus giving the calling subscriber the busy-signal in the usual way. The diagram of the sub-central stations eleven-hundred, twelve-hundred, thirteen-hundred, etc., and of the main central or trunking station with the one-thousand, two-thousand, etc., groups of first-selectors and second-selectors, as shown in Fig. 28, gives a general idea of the situation of the relative parts in the system as a whole, outlined and described in the foregoing and comprised in my invention. Each group of sub-stations is shown connected with its sub-central or sub-exchange station, as are also the groups of the eleven and twenty-two hundreds, among which are the sub-stations #1122 and #2211, respectively. The individual-switches of the eleven-hundred, it will be noticed, operate through corresponding first-selectors (among which is the first-selector D) by means of repeaters c^1 , such as the repeater C, and if the said first-selectors are so operated that their wipers are raised to the second level they then gain control of some one of the second-selectors of that level, among which is shown the second-selector E. Said second-selectors when their wipers are raised to the second level operate the connectors of the twenty-second-hundred, including the connectors F, through repeaters c^2 , among which is the repeater C¹. The said figure, as stated, gives a general idea of the location of the different units and of the arrangement of the trunking cables, while Figs. 23 to 27, inclusive, show in detail the wiring and arrangement of the individual trunk-lines in the said cables. Since all like parts are given like characters a comparison will reveal the relation of the said Figs. 23 to 27, inclusive, to Fig. 28, and the position of the instruments shown in Figs. 17 to 22, inclusive.

Fig. 13 is a plan view of a section of a type of board or unit upon which the individual-switches of a given hundred are mounted, and shows clearly how the switches are mounted in the unit. Upon the angle-irons 21 and 22 there are mounted twenty-five individual-switches, thirteen on one angle-iron and twelve on the other. These switches are arranged in alternation, so that twelve switches if mounted on the angle-iron 22 fall between thirteen switches on the angle-iron 21. Furthermore, bridged between the angle-irons there are mounted twenty-five banks, each opposite one of the individual-switches. The arrangement, for instance, is as follows: The first switch on the angle-iron 21 uses the first bank, and the first switch on the angle-iron 22 uses the second bank; then the second switch on the angle-iron 21 uses the third bank, while the

second switch on the angle-iron 22 uses the fourth bank, etc. All of the banks are so multiplied that the corresponding springs or contacts are all connected together, which arrangement, of course, is essential, as described. The connector-switches and repeaters are mounted upon the lower part of the frame in any suitable manner.

It will be seen that my system employs a trunking arrangement that may be modified to suit any of the exigencies that may arise in a telephone system of either the automatic or combined automatic and manual type. I provide an individual-switch of highly improved character and efficiency, which switch is adapted to be used in any part of the system in which trunk-selecting is a feature. Said individual-switch may be operated by a distinct and special preliminary impulse, as described, or it may be operated by the first vertical impulse sent over the vertical line-conductor when the calling subscriber grounds the said vertical line-conductor to send the first impulse for the first digit of the called number. In that case, the calling subscriber, when he begins to call, by any suitable method, causes the said first connection to ground to be maintained long enough to permit the individual-switch to operate and establish a connection between the line-conductors of the calling line and the conductors of the trunk-line, at which time practically the same original impulse is transmitted over the seized trunk-line to some switch or signaling device, whereby the said seized switch or device is given one impulse before the said first or initial ground circuit is broken. Although, as described, only one centralized battery at the main trunking exchange is used for operating all switches at main and sub-exchange stations, this is not essential. Each sub-exchange station may be very easily provided with its own local battery for operating the local switches, while the battery at the main exchange may be made to provide current only for the switches therein located. The ringer-generator 335, however, located at the main central office, is provided with leads 506 and 507 from which taps are taken to each of the sub-central or sub-exchange stations to provide the connectors with ringing current.

My improved individual-switches are each individual to a subscriber's line, while each group of individual-switches is controlled by the single master-switch allotted to said group. The master-switch which is common to all of the individual switches in such group performs the trunk-selecting operation, and each individual-switch performs the connecting operation—that is to say, connects the subscriber's line with any trunk-line which may have been previously selected by the master-switch. In this way,

each calling subscriber gets connection with the next idle trunk-line, which trunk-line has already been selected for him by the switch-operating machine, and in so doing 5 he automatically causes the said switch-operating machine or master-switch to travel on and select the next idle trunk-line. In this way, each subscriber gets the trunk-line automatically selected for him by the subscriber who made the last call. In other 10 words, the subscriber gets the trunk-line selected by the subscriber making the call just ahead of him, and the said subscriber then in turn automatically selects a trunk-line for the subscriber who comes after him. With the arrangement shown, it will be seen 15 that each subscriber's line is normally short-circuited through the springs of the relay 5, as described. By using repeaters at the auxiliary or sub-exchange stations I avoid the 20 necessity of employing third trunk-line-conductors between the sub and main exchanges for releasing purposes. Third trunk-line-conductors are employed between the individual-switches and the repeaters associated therewith, and third trunk-line-conductors are also employed between switches at the 25 main or central station; but in order that the cables employed between the central station and the said sub-exchange stations may 30 be as light as possible, I employ repeaters at the said sub-exchange stations and thus reduce the number of conductors for each trunk-line to two. The battery or centralized 35 source of switching current has its non-grounded terminal connected with all of the auxiliary or sub-exchange stations, as shown and described. Also, it will be seen that the ringing-generator has both poles connected by a cable with all of the outlying or sub-exchange stations. Of course, as 40 shown and described, the individual-switches or individual trunk-selecting switch mechanisms are operated by the preliminary impulse transmitted over the line of any calling subscriber by the upward movement of the switch-hook at the calling sub-station. In this connection it may be stated, however, that both the operation of the individual-switch and the first vertical step of 45 the first-selector can be accomplished by a first vertical impulse transmitted over the calling subscriber's line by the key 157, or by any other suitable device employed for transmitting the number-impulses. Should 50 the subscriber's transmitter or calling device be thus used for operating both the individual-switches and the selectors and connectors, it is evident that the first vertical 55 impulse incident to the actual calling of any number should be of sufficient duration to insure the first vertical step of the first-selector automatically connected with the calling subscriber's line by his individual 60 switch. This, however, is fully set forth in 65

application No. 258,026, filed by me April 29, 1905, and also in application No. 278,901, filed by Keith, Erickson and Erickson September 18, 1905, which latter fully describes the use and advantages of the so-called 70 elongated first vertical impulse for both operating the individual-switch and producing the first vertical step of the selector. As each subscriber's line is normally short-circuited, it is evident that the line-circuit is 75 balanced, and that this arrangement will tend to quiet the lines and prevent cross-talk, since otherwise the rotary-line-conductor would be open and the vertical-line-conductor would be connected through the trip-magnet to the battery B and to ground. The circuit being normally closed through the bell, the unbalanced condition would 80 tend to make the cables noisy through which the line passes and thus annoy the other 85 lines when in use. In my improved construction each individual-switch has but a single plunger, and only a single bank of contacts, which I find to be of advantage in various ways. For instance, the plunger 90 being simple it is more easily manufactured and very cheaply produced. The banks are, as shown, made very compact and to cover very little space. The bank-springs being all together the bank-multiplying-conductors 95 are adapted to be more systematically arranged, and in case of trouble the said trouble may be located much more easily. Furthermore, with my improved construction it will be seen that either a grounded or non-grounded connection will afford a guarding potential at any particular contact in the bank of the master-switch, thus insuring the 100 desired automatic operation. For example, should the subscriber disconnecting fail to 105 fully restore his switch-hook to its normally depressed condition, a temporary grounding of both sides of the line would thereby result, and without the provisions shown and described the master-switch might fail to 110 move on--that is, would not pass the contact corresponding to the trunk-line thus blocked or tied up. This, of course, would result in giving the same trunk-line to several different subscribers, inasmuch as the 115 succeeding calls would all pile up, so to speak, on the same trunk-line as a result of the accidental and temporary grounding of both sides of the line-circuit at a certain subscriber's station. Consequently, as stated, 120 either grounded or non-grounded potential at the contact of the master-switch will cause the wiper thereof to automatically move on to the next contact. When non-grounded guarding potential is supplied to 125 the contacts of the master-switch, the same necessarily comes through the restoring-magnet 7, and when the same contact is connected with the grounded pole also a closed circuit is thereby formed, the switch-contact 130

being connected with the circuit at a point between the grounded pole of the battery and the said restoring-magnet. Consequently, the contact of the master-switch-wiper with a contact thus temporarily connected with both poles of the battery results in a flow of current from the grounded pole of the battery directly to the master-switch-wiper, and thence through the relay-coils, 5 as previously described, and back to the non-grounded pole of the battery. Thus the relay 63 is provided with alternate paths or energizing circuits, whereby it is always energized when the wiper of the master-switch engages a contact having guarding potential, regardless of whether such potential is negative or positive. Furthermore, I provide means, such, for example, as that shown and described, for preventing an 10 accidental rotation of the shaft when the master-switch-wiper has occasion to pass over busy contacts in returning to normal or first position. In Fig. 14, for example, the polarity of the relay 63 is reversed several 15 times when the wiper 67 travels back over contacts which are all busy, and the reversal of polarity takes place in such manner that the relay 63 does not have time to attract its armature, thus allowing the wiper to come 20 to a standstill on the first contact of the bank, providing such contact is not busy. The relay 62, of course, controls the circuits of all of the trip-magnets 6, and consequently when this relay 62 is energized all 25 of said circuits are opened, thus preventing any subscriber who happens to call just at the time the shaft is rotating from obtaining connection with a busy line. In Fig. 16 the master-switch-wiper is, as previously explained, simply carried out of contact with the bank-contacts during its back stroke or return movement to normal or first position. With my improved arrangement each auxiliary or sub-exchange station contains as 30 many individual-switches as there are subscribers connected with such station, a single master-switch or switch-operating machine for accomplishing the selective operations of such stations, and a suitable number of 35 connectors, preferably ten per cent. of the total number of subscribers' lines leading in to such station. In addition, each auxiliary or sub-exchange station contains as many repeaters as there are trunk-lines leading from 40 the said individual-switches to the main or central exchange station. The provision of repeaters at the main or central station, in the manner described, one for each outgoing trunk-line, and the combination with the 45 repeaters at the auxiliary stations, makes it unnecessary to employ a third conductor for each trunk-line. In this way, I obtain the advantages of the so-called trunk-release 50 for the various switches or switching machines, but at the same time avoid the neces-

sity of using more than two conductors for each trunk-line running between the main and sub-exchange stations. It will be seen that the repeaters at the auxiliary or sub-exchange stations are each interposed between a switch for making a preliminary trunking connection and a switch for performing a trunking operation in accordance with the first digit of the called number, the latter switch being a first-selector. All of 70 the switches or switching machines, of course, with the exception of the connectors, are adapted to perform trunking operations, but at the same time it will be seen that these trunk-selecting switches or switch 75 mechanisms may be divided into two classes, those of one class being adapted to perform preliminary trunking operations, and those of the other class being adapted to perform trunking operations corresponding to the 80 first and second digits of any called number. If the exchange is smaller, then the trunk-selecting switch mechanisms of the second class include only means for performing 85 trunking operations corresponding to the first digit of any called number. Again, if the exchange is considerably larger, the trunk-selecting switches of the second class will include means for performing trunking operations corresponding to the first, second 90 and third digits of any called number. Obviously, however, the trunk-selecting switches of the first class are each adapted to perform only a mere preliminary trunking operation—that is to say, a trunking 95 operation which is preliminary to the trunking operation which takes place later on and which represents or corresponds to the first digit of the called number. In this way, therefore, I combine a minimum length 100 of subscriber's line with a minimum number of first and second selectors, and with trunk-releasing means of such character that the cables between the main and sub-trunking 105 stations are of minimum weight and contain practically the minimum number of trunk-line-conductors. Furthermore, I accomplish this result in an exchange system in which all calls must pass through a main trunking station, even though one subscriber be calling another subscriber of the 110 same auxiliary or sub-trunking station. In other words, and in this connection, it will be seen that the trunk-lines connecting any sub-exchange station with the main or central station constitute the means by which the subscribers of such sub-exchange station communicate between themselves, as well as with subscribers of other sub-exchange stations. Each subscriber in making a call 115 finally obtains connection with a connector at some distant auxiliary or sub-exchange station, and the operation of this connector, in accordance with the last two digits of the called number, is then accomplished 120 125 130

through the medium of two repeaters one at the sub-exchange station of the calling subscriber, and the other at the main or central trunking station. In a similar manner, the releasing of the switches is initiated by the calling subscriber through the medium of the different repeaters, the connector releasing first, and the two selectors and the individual-switch then releasing upon the deenergization of the repeater-relays, as explained.

The selectors herein shown and described can be of the general type disclosed in Patent No. 815,321, granted March 13, 1906, to 5 Keith, Erickson and Erickson. The connectors herein referred to can be of the general type shown and described in Patent No. 815,176, granted March 13, 1906, to Keith, Erickson and Erickson.

With the arrangement shown the battery B can be of 50 volts. The different relays and magnets may have the following resistances: the trip-magnet 60 ohms; the release-magnet 60 ohms; the line-relay or bridge-cut-off-relay 2300 ohms; the motor-magnet of the master-switch 60 ohms; each winding of the differential-relay 500 ohms; and each winding of the auxiliary-relay 500 ohms. It is obvious, however, that the current strength and resistances of the different coils can be changed or adjusted to suit the requirements of different cases without departing from the spirit of my invention.

The auxiliary or sub-exchange or outlying trunking stations can be located in any suitable manner. For example, in Fig. 30 the individual-switches, master-switch and connectors and repeaters are all contained in the receptacle T mounted on top of the pole t. Aerial wires can be used for the subscribers' line-wires leading into the pole-top terminal thus provided, and the trunk-line cables can be laid in the ground between the auxiliary station and the main station. In Fig. 31 45 the auxiliary station trunking apparatus is all contained in the receptacle U located under ground in a manhole u. Figs. 32 and 33 illustrate a portion of a district system embodying the principles of my invention, showing the different kinds of auxiliary stations, including, in addition to those already described, a police-box auxiliary station V and a house-top auxiliary station W, each containing the individual- 50 switches, connectors and master-switch, together with the necessary repeaters, substantially as previously described. Thus it will be seen that the only operations performed at the auxiliary or outlying trunking stations are the preliminary trunking operations and the final line-connecting operations—that is to say, these are the only step-by-step operations which take place at these outlying stations. The repeaters, of course, at these outlying or sub-trunking sta-

tions are relied upon by the subscribers for operating the main or central exchange station apparatus, and for operating the connectors at any of the outlying or auxiliary stations. For example, a subscriber in calling must necessarily rely upon one of the repeaters (at his particular auxiliary or sub-exchange station) for accomplishing all of the step-by-step operations which take place subsequent to the operation of his individual-switch. Consequently, the calling subscriber uses this repeater as a medium through which to operate a connector at some other auxiliary station, or he may use the same repeater as a medium through which to operate a connector at his own auxiliary or sub-trunking station. In all cases, therefore, with the arrangement shown, the connecting up of two subscribers' lines involves the use of two repeaters, even though the calling and called subscribers' lines may terminate at the same auxiliary or sub-exchange station.

With my improved arrangement the subscribers have impulse transmitters for operating the individual-switches at the sub-central stations, and the said sub-central stations have repeaters which act as impulse transmitters for operating the selectors at the central station. Also, with this arrangement the central station is provided with repeaters which serve as impulse transmitters for operating the connectors at the sub-central stations. In each case the impulses transmitted by any repeater are simply exact reproductions, so to speak, of the impulses transmitted from a subscriber's station. The talking circuits, although they pass through the repeater, as shown, comprise in said repeaters nothing but condensers, which latter divide the circuits, as illustrated. The method of transmitting the voice-currents from one circuit to the other—that is, for passing from one division to the other—may be of any suitable and well-known character. For instance, repeating coils may be inserted, together with condensers, if desired.

Figs. 23 and 24, as stated, represent one of the outlying sub-centrals, and the normal-conductors of the individual-switches, such as the individual-switches I and A there shown, run to the banks of the connectors X. It will be clear that the private-normals run to the private-banks Y of said connectors, and that the line-normals run to the corresponding line-banks Z. In the former of said figures (Fig. 23) the plunger 3 is shown engaging the bank-springs of the first bank position. By the first bank position, it will be understood, is meant the position that corresponds to the position of the master-switch-cam 66, as more clearly shown in Fig. 10, when the said cam engages any one of the said pins 68, 69, 70 and 71 on the

ratchet-wheel 64 at the point marked by the line 109, as stated heretofore.

- In a system such as disclosed it will be seen that vertical motion is employed for 5 selecting groups and rotary motion for connecting with a line in any selected group. For example, the trunks are divided into groups, and the selectors have first vertical motion to select a group, and then rotary motion to automatically select an idle trunk in the predetermined group. Also, the subscribers' lines are divided into groups, say one hundred in each group, and each one hundred then subdivided into groups of ten, 10 15 20 25 30
- 16 The connectors, therefore, have first vertical motion to select the desired group and then rotary motion to find the called line in the predetermined group. In addition automatic means are provided for reducing the number of bridges across any established talking circuit. In other words, bridging relays are employed for controlling the operations of the selectors and connectors, but the number of such bridges is automatically 35 reduced during the process of establishing connection from a calling line to a called line. Thus when the talking circuit is established there is only a minimum number of bridges across the same. The bridges which are retained are, for example, merely for releasing purposes.

What I claim as my invention is:—

1. In a telephone system, the combination of a main or central station, a plurality of 35 outlying or sub-central stations, trunking cables connecting the said central station with the said sub-central stations, selectors located at the central station and adapted for performing trunking operations corresponding to all of the digits of any called 40 number except the last two thereof, subscribers' telephone lines leading into the sub-central stations, an individual trunk-selecting switch for each subscriber's line, a 45 switch-operating machine or master-switch located at each sub-central station and common to all the individual-switches thereof, connectors located at the sub-central stations, the connectors of any sub-central 50 station being less in number than the subscribers' lines leading thereto, but each connector having a multiple terminal of each telephone line terminating at the sub-central station at which such connector is located.
- 55 2. In a telephone system, the combination of a central station, a plurality of sub-central stations, trunking cables connecting the central station with the sub-central stations, trunk-selecting apparatus at the central station, trunk-selecting apparatus at the sub-central stations, connectors at the sub-central stations, a switch-operating machine or master-switch located at each sub-central station and common to all the trunk-selecting apparatus thereof, a plurality of sub-

scribers' telephone lines terminating at each sub-central station, subscribers' devices for controlling the operations of the central and sub-central switching apparatus, and means for supplying all necessary current. 70

3. In a telephone system, the combination of a central station, a plurality of outlying or sub-central stations, first and second selectors located at the central station, trunking cables connecting the central station with the sub-central stations, said cables as a whole containing as many incoming trunk-lines leading into the central station as there are first-selectors, and containing also as many outgoing trunk-lines leading from the central station as there are second-selectors, and the system also comprising repeaters located at the central station, one for each outgoing trunk-line leading therefrom, connectors located at the sub-central stations, one for each outgoing trunk-line leading from the central station, repeaters located at the sub-central stations, one for each incoming trunk-line leading to the central station, a plurality of subscribers' telephone lines 80 terminating at each sub-central station, the subscribers' telephone lines of each sub-central station being greater in number than the trunk-lines thereof, individual-switches located at the sub-central stations, one for each subscriber's telephone line, a switch-operating machine or master-switch located at each sub-central station and common to all the individual-switches thereof, subscriber-operated means for controlling the operations of the central and sub-central station apparatus, and means for supplying all necessary current. 90

4. In a telephone system, the combination of a central station, a plurality of auxiliary or sub-central stations, trunk-lines connecting the central station with the sub-central stations, suitable switchboard apparatus at the said central station, a plurality of subscribers' telephone lines terminating at each sub-central station, an individual trunking switch for each subscriber's telephone line, said individual-switches located at the sub-central stations, a master-switch or switch-operating machine located at each sub-central station and common to all the individual-switches thereof, a plurality of connectors at each sub-central station, the connectors of any sub-central station being less in number than the total number of telephone lines terminating thereto, subscribers' devices for automatically operating the individual-switches to obtain trunk-line connection with the central station, and means for supplying all necessary current. 115 120

5. In a telephone system, the combination of a central station, a plurality of sub-central stations, trunk-lines connecting the central station with the sub-central stations, a plurality of subscribers' telephone lines ter- 130

minating at each sub-central station, means at the central station upon which the system is dependent for accomplishing connection between any two subscribers' lines, whether 5 of the same or different sub-central stations, trunking apparatus located at each sub-central station, connectors located at the sub-central stations, subscribers' impulse transmitters for operating the trunking apparatus to obtain trunk-line connection with the central station, suitably operated impulse transmitters located at the central station and adapted for operating said connectors to obtain connection with any subscriber's line, and means for supplying all necessary current.

6. In a telephone system, the combination of a central station, a plurality of sub-central stations, trunking cables connecting the 20 main or central station with the sub-central stations, a plurality of subscribers' telephone lines terminating at each sub-central station, the subscribers' lines terminating at each sub-central station being greater in number 25 than the trunk-lines thereof, electrically-propelled and step-by-step-actuated switching machinery at each sub-central station, subscribers' impulse transmitters for operating said switching machinery to obtain 30 trunk-line connection with the central station, suitably operated impulse transmitters located at the central station and adapted for operating said switching machinery to obtain connection with any subscriber's line, 35 and means for supplying all necessary current.

7. In a telephone system, the combination of a central station, a plurality of outlying or sub-central stations, electrically-propelled 40 and step-by-step-actuated switching machinery located at the central station, trunk-lines connecting the central station with the sub-central stations, electrically-propelled and step-by-step-actuated switching machinery located at the sub-central stations, a plurality of subscribers' telephone lines terminating at each sub-central station, subscribers' impulse transmitters for operating the switching machinery at the sub-central 45 stations, suitably operated impulse transmitters located at the sub-central stations and adapted for operating the switching machinery at the central station, suitably operated impulse transmitters located at the 50 central station and adapted for operating the switching machinery at the sub-central stations, and means for supplying all necessary current, the switching machinery of the central station constituting the medium 55 for establishing connection between any two subscribers' lines, whether of the same or different sub-central stations.

8. In a telephone system, the combination of a central station, a plurality of outlying

or auxiliary stations, trunk-lines connecting the central station with the said auxiliary stations, each trunk-line consisting of but two metallic conductors, automatic trunking machinery at the central station, release-trunks for said trunking machinery, repeaters located at the central station, one for each outgoing trunk-line leading therefrom, automatic selecting and connecting machinery located at the auxiliary stations, local released trunks for said auxiliary station switching machinery, repeaters located at the auxiliary stations, one for each incoming trunk-line leading into the central station, a plurality of subscribers' telephone lines terminating at each auxiliary station, subscribers' impulse transmitting devices for operating the central and auxiliary station switching machinery, and means for supplying all necessary current, the system being dependent upon the central station for connection between any two subscribers' lines, whether of the same or different auxiliary stations.

9. In a telephone system, the combination of a central station, a plurality of outlying or auxiliary stations, trunking cables connecting the central station with the auxiliary stations, first and second selectors located at the central station, three-wire trunks connecting the first-selectors with the second-selectors, release-circuits for said selectors, said circuits including the third wires or conductors of the trunks, repeaters at the central station, one for each outgoing trunk-line leading therefrom, a plurality of subscribers' telephone lines terminating at each auxiliary station, subscribers' individual-switches at the auxiliary stations, connectors at the auxiliary stations, repeaters at the auxiliary stations, one for each incoming trunk-line leading to the central station, three-wire trunks between the individual-switches and repeaters of the auxiliary stations, local release-circuits for said individual-switches, said local release-circuits including the third wires or conductors of the trunks which connect the individual-switches with the repeaters of the auxiliary stations, subscribers' impulse transmitters for operating the individual-switches, adapted also to operate the selectors and connectors through the medium of said repeaters, and means for supplying all necessary current.

10. In a telephone system, the combination of a plurality of subscribers' telephone lines, an individual-switch for each line, each switch provided with an energizing circuit for bringing the switch into use, a switch-operating machine or master-switch common to all of said individual-switches, provided with a relay controlling all of said energizing circuits, and means where-

by said relay is always energized while the switch-operating machine or master-switch is in motion.

11. In a telephone system, the combination of a plurality of subscribers' lines, an individual-switch for each subscriber's line, a trip-magnet and mechanism to be released thereby for each individual-switch, an energizing circuit for each trip-magnet, a switch-operating machine or master-switch common to all of said individual-switches, provided with a relay controlling all of said energizing circuits, and means whereby said relay is always energized while the switch-operating machine or master-switch is in motion.

12. In a telephone system, the combination of a plurality of subscribers' lines, an individual switching means for each line, means for rendering all idle switches inoperative while moving from one connecting position to another, a motor-magnet, a ratchet mechanism operated by the magnet, a bank of contacts, a wiper operated by said ratchet mechanism and adapted to traverse said bank of contacts, and means for preventing forward actuation of the ratchet mechanism during the return movement of said wiper over one or more busy contacts to normal position or starting point, substantially as set forth.

13. In a telephone system, the combination of a plurality of subscribers' telephone lines, a plurality of trunk-lines, trunk-selecting and connecting machinery for each line controlled by the subscribers for automatically selecting idle trunk-lines for the next calling subscriber, and means for preventing any calling subscriber from actuating the machinery for his line and accidentally securing connection with a busy trunk-line while the selecting machinery is in motion, responsive to one subscriber, and in search of an idle trunk-line for the next calling subscriber.

14. In a telephone system, the combination of a plurality of subscribers' lines, a plurality of trunk-lines, an individual trunk-selecting switch for each subscriber's line, and a switch-operating machine or master-switch common to all of said individual-switches, provided with a motor-magnet, a differential-relay connected to control the energizing of said motor-magnet, and means for reversing the polarity of said relay one or more times during the return of the master-switch to normal position or starting point.

15. In a telephone system, the combination of a plurality of subscribers' telephone lines, a plurality of trunk-lines, an individual-switch for each subscriber's line, and a master-switch common to all of said individual-switches, provided with a differential-relay having a permanently closed circuit

including differential windings thereof in parallel, whereby said relay is not energized except by unbalancing the relative flow of current in its windings.

16. In a telephone system, the combination of a plurality of subscribers' telephone lines, trunk-selecting switching machinery, a plurality of trunk-lines, and means for supplying all necessary current, said machinery having a motor-magnet, an energizing circuit for said magnet, a differential-relay controlling said energizing circuit, and a permanently closed circuit including differential windings of said relay in parallel, whereby said relay is energized by unbalancing the relative flow of current in its windings.

17. In a telephone system, the combination of a plurality of subscribers' telephone lines, a plurality of trunk-lines, and trunk-selecting switching machinery controlled by the subscribers, provided with a plurality of contacts each representing one of said trunk-lines, and means by which either a positive or negative potential at any contact will cause the said machinery to vacate such contact.

18. In a telephone system, the combination of a battery having one pole grounded, a plurality of subscribers' lines, a plurality of trunk-lines, trunk-selecting switching machinery controlled by the subscribers, provided with a bank of contacts whereof each represents one of said trunk-lines, and means whereby the temporary connection of a contact with either the grounded or non-grounded pole of said battery will cause said machinery to vacate such contact.

19. In a telephone system, the combination of a plurality of subscribers' individual-switches, a shaft common to all of said switches, each switch having an energizing circuit, a master-switch common to all of said individual-switches and adapted for operating said shaft, provided with a relay controlling all of said energizing circuits, and means for always energizing said relay while the shaft is in motion, for the purpose set forth.

20. In a telephone system, the combination of a plurality of subscribers' lines, a plurality of trunk-lines, and a selectively operated individual trunking switch for each subscriber's line, said individual-switches each comprising only a single row of spring sockets and only a single plunger for operating said spring sockets, substantially as and for the purpose set forth.

21. In a telephone system, the combination of a plurality of subscribers' lines, a plurality of trunk-lines, and a selectively operated subscriber's individual trunking switch for each subscriber's line, each individual-switch comprising a single row of sockets or guide openings, switch-springs or contacts mount-

- ed at each side of said row of sockets, and a single plunger adapted to swing back and forth along said row of sockets and to enter any socket when connection is to be closed 5 between a subscriber's line and an idle trunk-line. 70
22. In a telephone system, the combination of a plurality of subscribers' lines, a plurality of trunk-lines, a selectively operated subscriber's individual trunking switch for each subscriber's line, a master-switch for operating said individual-switches, each individual-switch having a single bank of contacts provided with a single row of guide openings, metal plates and switch-springs mounted at each side of said row of guide openings, and a single plunger adapted to swing back and forth along said row of guide openings, and to enter any guide opening when 15 connection is to be closed between a subscriber's line and an idle trunk-line, said guide openings being provided with a piece of insulation having a row of notches or recesses, substantially as and for the purpose 20 set forth. 25
23. In a telephone system, the combination of a main or central station, a plurality of outlying or sub-central stations, trunking cables connecting the said central station 30 with the said sub-central stations, selectors located at the central station and adapted for performing trunking operations corresponding to all of the digits of any called number except the last two thereof, subscribers' telephone lines leading into the 35 sub-central stations, an individual trunk-selecting switch for each subscriber's line, a switch-operating machine or master-switch located at each sub-central station and common to all the individual-switches thereof, 40 connectors located at the sub-central stations, the connectors of any sub-central station being less in number than the subscribers' lines leading thereto, but each connector having a multiple terminal of each telephone line terminating at the sub-central station at which such connector is located, the said system being also provided with automatic means for precluding connection 45 with a busy subscriber's line. 50
24. In a telephone system, the combination of a central station, a plurality of sub-central stations, trunking cables connecting the central station with the sub-central stations, 55 trunk-selecting apparatus at the central station, trunk-selecting apparatus at the sub-central stations, connectors at the sub-central stations, a switch-operating machine or master-switch located at each sub-central 60 station and common to all the trunk-selecting apparatus thereof, a plurality of subscribers' telephone lines terminating at each sub-central station, subscribers' devices for controlling the operations of the central and 65 sub-central switching apparatus, and means for supplying all necessary current, the said system being also provided with automatic means for precluding connection with a busy subscriber's line. 70
25. In a telephone system, the combination of a central station, a plurality of outlying or sub-central stations, first and second selectors located at the central station, trunking cables connecting the central station with the sub-central stations, said cables as a 75 whole containing as many incoming trunk-lines leading into the central station as there are first-selectors, and containing also as many outgoing trunk-lines leading from the central station as there are second-selectors, 80 and the system also comprising repeaters located at the central station, one for each outgoing trunk-line leading therefrom, connectors located at the sub-central stations, one for each outgoing trunk-line leading 85 from the central station, repeaters located at the sub-central stations, one for each incoming trunk-line leading to the central station, a plurality of subscribers' telephone lines terminating at each sub-central station, the 90 subscribers' telephone lines of each sub-central station being greater in number than the trunk-lines thereof, individual-switches located at the sub-central stations, one for each subscriber's telephone line, a switch-operating machine or master-switch located 95 at each sub-central station and common to all the individual-switches thereof, subscriber-operated means for controlling the operations of the central and sub-central 100 station apparatus, and means for supplying all necessary current, the said system being also provided with automatic means for precluding connection with a busy subscriber's line. 105
26. In a telephone system, the combination of a central station, a plurality of auxiliary or sub-central stations, trunk-lines connecting the central station with the sub-central stations, suitable switchboard apparatus at the said central station, a plurality of subscribers' telephone lines terminating at each sub-central station, an individual trunking switch for each subscriber's telephone line, said individual-switches 110 located at the sub-central stations, a master-switch or switch-operating machine located at each sub-central station and common to all the individual-switches thereof, a plurality of connectors at each sub-central station, the connectors of any sub-central station being less in number than the total number of telephone lines terminating thereat, subscribers' devices for automatically operating the individual-switches to obtain 115 trunk-line connection with the central station, and means for supplying all necessary current, the said system being also provided with automatic means for precluding connection with a busy subscriber's line. 120
27. In a telephone system, the combination of a central station, a plurality of sub-central stations, trunking cables connecting the central station with the sub-central stations, first and second 125 selectors located at the central station, trunking cables connecting the central station with the sub-central stations, said cables as a whole containing as many incoming trunk-lines leading into the central station as there are first-selectors, and containing also as many outgoing trunk-lines leading from the central station as there are second-selectors, and the system also comprising repeaters located at the central station, one for each outgoing trunk-line leading therefrom, connectors located at the sub-central stations, one for each outgoing trunk-line leading from the central station, repeaters located at the sub-central stations, one for each incoming trunk-line leading to the central station, a plurality of subscribers' telephone lines terminating at each sub-central station, the subscribers' telephone lines of each sub-central station being greater in number than the trunk-lines thereof, individual-switches located at the sub-central stations, one for each subscriber's telephone line, a switch-operating machine or master-switch located at each sub-central station and common to all the individual-switches thereof, subscriber-operated means for controlling the operations of the central and sub-central station apparatus, and means for supplying all necessary current, the said system being also provided with automatic means for precluding connection with a busy subscriber's line. 130

27. In a telephone system, the combination of a central station, a plurality of out-lying or sub-central stations, trunk-lines connecting the central station with the different sub-central stations, a plurality of subscribers' telephone lines terminating at each sub-central station, the trunk-lines for each sub-central station being less in number than the total number of subscribers' telephone lines thereof, a plurality of connectors at each sub-central station, said connectors less in number than the total number of subscribers' lines, automatic trunking apparatus at each sub-central station, subscribers' impulse transmitters for operating said trunking apparatus to obtain trunk-line connection with the central station, suitably operated impulse-transmitters located at the central station and adapted for operating said connectors to obtain connection with any subscriber's line, and means for supplying the electric current necessary for producing the switch-operating impulses, the said system being also provided with automatic means for precluding connection with a busy subscriber's line.
28. In a telephone system, the combination of a central station, a plurality of sub-central stations, trunk-lines connecting the central station with the sub-central stations, a plurality of subscribers' telephone lines terminating at each sub-central station, means at the central station upon which the system is dependent for accomplishing connection between any two subscribers' lines, whether of the same or different sub-central stations, trunking apparatus located at each sub-central station, connectors located at the sub-central stations, subscribers' impulse transmitters for operating the trunking apparatus to obtain trunk-line connection with the central station, suitably operated impulse transmitters located at the central station and adapted for operating said connectors to obtain connection with any subscriber's line, and means for supplying all necessary current, the said system being also provided with automatic means for precluding connection with a busy subscriber's line.
29. In a telephone system, the combination of a central station, a plurality of out-lying or sub-central stations, electrically-propelled and step-by-step-actuated switching machinery located at the central station, trunk-lines connecting the central station with the sub-central stations, electrically-propelled and step-by-step-actuated switching machinery located at the sub-central stations, a plurality of subscribers' telephone lines terminating at each sub-central station, subscribers' impulse transmitters for operating the switching machinery at the sub-central stations, suitably operated impulse transmitters located at the sub-central stations and adapted for operating the switching machinery at the central station, suitably operated impulse transmitters located at the central station and adapted for operating the switching machinery at the sub-central stations, and means for supplying all necessary current, the switching machinery at the central station constituting the medium for establishing connection between any two subscribers' lines, whether of the same or different sub-central stations, the said system being also provided with automatic means for precluding connection with a busy subscriber's line.
30. In a telephone system, the combination of a central station, a plurality of out-lying or auxiliary stations, trunk-lines connecting the central station with the said auxiliary stations, each trunk-line consisting of but two metallic conductors, automatic trunking machinery at the central station, release-trunks for said trunking machinery, repeaters located at the central station, one for each outgoing trunk-line leading therefrom, automatic selecting and connecting machinery located at the auxiliary stations, local release-trunks for said auxiliary station switching machinery, repeaters located at the auxiliary stations, one for each incoming trunk-line leading into the central station, a plurality of subscribers' telephone lines terminating at each auxiliary station, subscribers' impulse transmitting devices for operating the central and auxiliary station switching machinery, and means for supplying all necessary current, the system being dependent upon the central station for connection between any two subscribers' lines, whether of the same or different auxiliary stations, and the said system being also provided with automatic means for precluding connection with a busy subscriber's line.
31. In a telephone system, the combination of a central station, a plurality of out-lying or auxiliary stations, trunking cables connecting the central station with the auxiliary stations, first and second selectors located at the central station, three-wire trunks connecting the first-selectors with the second-selectors, release-circuits for said selectors, said circuits including the third wires or conductors of the trunks, repeaters at the central station, one for each outgoing trunk-line leading therefrom, a plurality of subscribers' telephone lines terminating at each auxiliary station, subscribers' individual-switches at the auxiliary stations, connectors at the auxiliary stations, repeaters at the auxiliary stations, one for each incoming trunk-line leading to the central station, three-wire trunks between the individual-switches and repeaters of the auxiliary stations, local release-circuits for said individual-switches, said local release-

- circuits including the third wires or conductors of the trunks which connect the individual-switches with the repeaters of the auxiliary stations, subscribers' impulse 5 transmitters for operating the individual-switches, adapted also to operate the selectors and connectors through the medium of said repeaters, and means for supplying all necessary current, the said system being 10 also provided with automatic means for precluding connection with a busy subscriber's line.
32. In a telephone system, the combination of a plurality of subscribers' telephone 15 lines, an individual-switch for each line, each switch provided with an energizing circuit for bringing the switch into use, a switch-operating machine or master-switch common to all of said individual-switches, 20 provided with a relay controlling all of said energizing circuits, and means whereby said relay is always energized while the switch-operating machine or master-switch is in motion, the said system being also provided 25 with automatic means for precluding connection with a busy subscriber's line.
33. In a telephone system, the combination of a plurality of subscribers' lines, an individual-switch for each subscriber's line, 30 a trip-magnet and mechanism to be released thereby for each individual-switch, an energizing circuit for each trip-magnet, a switch-operating machine or master-switch common to all of said individual-switches, 35 provided with a relay controlling all of said energizing circuits, and circuit means whereby said relay is always energized while the switch-operating machine or master-switch is in motion, the said system being also provided 40 with automatic means for precluding connection with a busy subscriber's line.
34. In a telephone system, the combination of a plurality of subscribers' lines, an individual switching means for each line, 45 means for rendering all idle switches inoperative while moving from one connecting position to another, a motor-magnet, a ratchet mechanism operated by the magnet, a bank of contacts, a wiper operated by said 50 ratchet mechanism and adapted to traverse said bank of contacts, and circuit means for preventing forward actuation of the ratchet mechanism during the return movement of said wiper over one or more busy contacts 55 to normal position or starting point, the said system being also provided with automatic means for precluding connection with a busy subscriber's line, substantially as set forth.
60. 35. In a telephone system, the combination of a plurality of subscribers' telephone lines, a plurality of trunk-lines, trunk-selecting and connecting machinery for each line controlled by the subscribers for auto- 65 matically selecting idle trunk-lines for the next calling subscriber, and means for preventing any calling subscriber from actuating the machinery for his line and accidentally securing connection with a busy trunk-line while the selecting machinery is in motion, responsive to one subscriber, and in search of an idle trunk-line for the next calling subscriber, the said system being also provided with automatic means for precluding connection with a busy subscriber's line. 70 75
36. In a telephone system, the combination of a plurality of subscribers' lines, a plurality of trunk-lines, an individual trunk-selecting switch for each subscriber's line, and a switch-operating machine or master-switch common to all of said individual-switches, provided with a motor-magnet, a differential-relay connected to control the energizing of said motor-magnet, and means for reversing the polarity of said 80 relay one or more times during the return of the master-switch to normal position or starting point, the said system being also provided with automatic means for precluding connection with a busy subscriber's line. 85 90
37. In a telephone system, the combination of a plurality of subscribers' telephone lines, a plurality of trunk-lines, an individual-switch for each subscriber's line, and a master-switch common to all of said individual-switches, provided with a differential-relay having a permanently closed circuit including differential windings thereof in parallel, whereby said relay is not energized except by unbalancing the relative flow of 95 current in its windings, the said system being also provided with automatic means for precluding connection with a busy subscriber's line. 100
38. In a telephone system, the combination of a plurality of subscribers' telephone lines, trunk-selecting switching machinery, a plurality of trunk-lines, and means for supplying all necessary current, said machinery having a motor-magnet, an energizing circuit for said magnet, a differential-relay controlling said energizing circuit, and a permanently closed circuit including differential windings of said relay in parallel, whereby said relay is energized by unbalancing the relative flow of current in its windings, the said system being also provided with automatic means for precluding connection with a busy subscriber's line. 105 110
39. In a telephone system, the combination of a plurality of subscribers' telephone lines, a plurality of trunk-lines, and trunk-selecting switching machinery controlled by the subscribers, provided with a plurality of contacts each representing one of said trunk-lines, and means by which either a positive or negative potential at any contact will cause the said machinery to vacate such con- 115 120 125

tact, the said system being also provided with automatic means for precluding connection with a busy subscriber's line.

40. In a telephone system, the combination of a battery having one pole grounded, a plurality of subscribers' lines, a plurality of trunk-lines, trunk-selecting switching machinery controlled by the subscribers, provided with a bank of contacts whereof each 10 represents one of said trunk-lines, and means whereby the temporary connection of a contact with either the grounded or non-grounded pole of said battery will cause said machinery to vacate such contact, the said 15 system being also provided with automatic means for precluding connection with a busy subscriber's line.

41. In a telephone system, the combination of a plurality of subscribers' individual-switches, a shaft common to all of said switches, each switch having an energizing circuit, a master-switch common to all of said individual-switches and adapted for operating said shaft, provided with a relay 20 controlling all of said energizing circuits, and means for always energizing said relay while the shaft is in motion, the said system being also provided with automatic means for precluding connection with a busy subscriber's line, for the purpose set forth.

42. In a telephone system, the combination of a plurality of subscribers' lines, a plurality of trunk-lines, and a selectively operated individual trunking switch for each 35 subscriber's line, said individual-switches each comprising only a single row of spring sockets and only a single plunger for operating said spring sockets, the said system being also provided with automatic means for 40 precluding connection with a busy subscriber's line, substantially as and for the purpose set forth.

43. In a telephone system, the combination of a plurality of subscribers' lines, a plurality of trunk-lines, and a selectively-operated subscriber's individual trunking switch for each subscriber's line, each individual-switch comprising a single row of 45 sockets or guide openings, switch-springs or contacts mounted at each side of said row of sockets, and a single plunger adapted to swing back and forth along said row of sockets and to enter any socket when connection is to be closed between a subscriber's line and an idle trunk-line, the said 50 system being also provided with automatic means for precluding connection with a busy subscriber's line.

44. In a telephone system, the combination of a plurality of subscribers' lines, a plurality of trunk-lines, a selectively operated subscriber's individual trunking switch for each subscriber's line, a master-switch 55 for operating said individual-switches, each

individual-switch having a single bank of 65 contacts provided with a single row of guide openings, metal plates and switch-springs mounted at each side of said row of guide openings, and a single plunger adapted to swing back and forth along said row of 70 guide openings, and to enter any guide opening when connection is to be closed between a subscriber's line and an idle trunk-line, said guide openings being provided with a piece of insulation having a row of notches 75 or recesses, the said system being also provided with automatic means for precluding connection with a busy subscriber's line, substantially as and for the purpose set forth. 80

45. A telephone system comprising a trunk line, a plurality of telephone lines, each reaching the battery bus-bar via an individual magnet, said individual magnets for closing connection between the telephone 85 lines and the trunk line, line circuits by which any subscriber may energize his individual magnet to close connection with the trunk line, a battery, a common magnet, and automatic means by which said common magnet is energized to open a plurality 90 of said line circuits when a subscriber calls.

46. A telephone system comprising a trunk line, a plurality of telephone lines, each reaching the battery bus-bar via an individual magnet, said individual magnets for closing connection between the telephone lines and said trunk line, line circuits for energizing said magnets, a common magnet, and means for energizing said common 95 magnet to open the circuits of a plurality of said individual magnets when a subscriber calls. 100

47. A telephone system comprising a trunk line, a plurality of telephone lines, each reaching the battery bus-bar via an individual magnet, a main station, a branch station at which the telephone lines terminate, and which is connected with the main station by said trunk line, said individual 105 magnets for closing connection between the telephone lines and the trunk line, located at the branch station, a common magnet also located at the branch station, line circuits for energizing said individual magnets 110 to close connection with the trunk line, and means for energizing said common magnet to open a plurality of said circuits when a subscriber calls. 115

48. A telephone system comprising a battery, a main central station, a branch central station, a trunk line between said stations, telephone lines leading to the branch station, each reaching the battery bus-bar via an individual magnet, automatic means 120 for closing connection between the telephone lines and the trunk line, to place a calling subscriber in connection with said trunk 125

line, and automatic means for opening the circuits of a plurality of said telephone lines when a subscriber calls.

49. A telephone system comprising a battery and automatic means for trunking calling telephone lines into connection with the called lines, responsive to the calling subscribers, said lines arranged in groups and each reaching the battery bus-bar via an individual magnet, and automatic means by which any calling subscriber of a group opens the circuits of a plurality of said telephone lines in the same group.

50. A telephone system comprising a battery and trunk lines, automatic means for selecting idle trunk lines, a plurality of subscribers' telephone lines, each reaching the battery bus-bar via an individual magnet, and automatic means by which a calling subscriber opens the normal line circuit of a plurality of said telephone lines.

51. A telephone system comprising a battery, a main station, a branch station, a plurality of trunk lines connecting the main station with the branch station, subscribers' telephone lines leading to the branch station, each reaching the battery bus-bar via an individual magnet, instrumentalities at the branch station for selecting idle trunk lines and connecting calling telephone lines therewith, including the individual magnets for said telephone lines, line circuits for energizing said magnets, and automatic means for opening a plurality of said circuits when a subscriber calls.

52. A telephone system comprising trunk lines, subscribers' telephone lines, instrumentalities for selecting idle trunk lines and connecting calling telephone lines therewith, including individual magnets for said telephone lines, circuits extending over said telephone lines for directly energizing said magnets to close connection from calling telephone lines to idle trunk lines, and automatic means for opening a plurality of said circuits when a subscriber calls.

53. A telephone system comprising a main station, a branch station, a plurality of trunk lines connecting the main station with the branch station, subscribers' telephone lines leading to the branch station, means at the branch station for selecting idle trunk lines and connecting the calling telephone lines therewith, individual magnets for said telephone lines, normally open circuits extending over said telephone lines for directly energizing said magnets to effect connection with idle trunk lines, a normally closed switch in each circuit, and automatic means for opening said switch when a subscriber calls.

54. A telephone system comprising trunk lines, a plurality of telephone lines to which said trunk lines are common, means under

the control of the subscribers of said telephone lines for closing connection therefrom to an idle trunk line and for selecting an idle trunk for the next call, and automatic means for preventing the other subscribers from calling while another trunk is being selected for the next call.

55. A telephone system comprising a main station, sub-central or branch stations, trunk line connection between the main station and the sub-central or branch stations, telephone lines leading to the branch stations, means at the branch stations for extending trunk line connections from the telephone lines and for selecting an idle trunk for the next call, and automatic means at the branch stations for preventing any other subscriber in the same branch station from calling while another trunk is being selected for the next call.

56. In a telephone system, the combination of a main or central station, a plurality of outlying or sub-central stations, trunking cables connecting the said central station with the said sub-central stations, selectors located at the central station and adapted for performing trunking operations corresponding to all of the digits of any called number except the last two thereof, having vertical motion to select groups and rotary motion to connect with a line in the selected group, subscribers' telephone lines leading into the sub-central stations, an individual trunk-selecting switch for each subscriber's line, a switch-operating machine or master-switch located at each sub-central station and common to all the individual-switches thereof, and connectors located at the sub-central stations, the connectors of any sub-central station being less in number than the subscribers' lines leading thereto, but each connector having a multiple terminal of each telephone line terminating at the sub-central station at which such connector is located.

57. In a telephone system, the combination of a central station, a plurality of sub-central stations, trunking cables connecting the central station with the sub-central stations, trunk-selecting apparatus at the central station, having vertical motion to select groups and rotary motion to connect with a line in the selected group, trunk-selecting apparatus at the sub-central stations, connectors at the sub-central stations, a switch-operating machine or master-switch located at each sub-central station and common to all the trunk-selecting apparatus thereof, a plurality of subscribers' telephone lines terminating at each sub-central station, subscribers' devices for controlling the operations of the central and sub-central switching apparatus, and means for supplying all necessary current.

58. In a telephone system, the combination of a central station, a plurality of out-lying or sub-central stations, first and second selectors located at the central station, 5 having vertical motion to select groups and rotary motion to connect with a line in the selected group, trunking cables connecting the central station with the sub-central stations, said cables as a whole containing as 10 many incoming trunk-lines leading into the central station as there are first-selectors, and containing also as many outgoing trunk-lines leading from the central station as there are second-selectors, and the system 15 also comprising repeaters located at the central station, one for each outgoing trunk-line leading therefrom, connectors located at the sub-central stations, one for each outgoing trunk-line leading from the central 20 station, repeaters located at the sub-central stations, one for each incoming trunk-line leading to the central station, a plurality of subscribers' telephone lines terminating at each sub-central station, the subscribers' 25 telephone lines of each sub-central station being greater in number than the trunk-lines thereof, individual-switches located at the sub-central stations, one for each subscriber's telephone line, a switch-operating 30 machine or master-switch located at each sub-central station and common to all the individual-switches thereof, subscriber-operated means for controlling the operations of the central and sub-central station apparatus, and means for supplying all necessary current.

59. In a telephone system, the combination of a central station, a plurality of auxiliary or sub-central stations, trunk-lines 40 connecting the central station with the sub-central stations, suitable switchboard apparatus at the said central station, having vertical motion to select groups and rotary motion to connect with a line in the selected group, a plurality of subscribers' telephone lines terminating at each sub-central station, an individual trunking switch for each subscriber's telephone line, said individual-switches located at the sub-central stations, 45 a master-switch or switch-operating machine located at each sub-central station and common to all the individual-switches thereof, a plurality of connectors at each sub-central station, the connectors of any sub-central 50 station being less in number than the total number of telephone lines terminating thereat, subscribers' devices for automatically operating the individual-switches to obtain trunk-line connection with the central 55 station, and means for supplying all necessary current.

60. In a telephone system, the combination of a central station, a plurality of sub-central stations, trunk-lines connecting the 65 central station with the sub-central stations,

a plurality of subscribers' telephone lines terminating at each sub-central station, means at the central station upon which the system is dependent for accomplishing connection between any two subscribers' lines, 70 whether of the same or different sub-central stations, trunking apparatus located at each sub-central station, connectors located at the sub-central stations, having vertical motion to select groups and rotary motion to connect with a line in the selected group, subscribers' impulse transmitters for operating the trunking apparatus to obtain trunk-line connection with the central station, suitably operated impulse transmitters located at the 75 central station and adapted for operating said connectors to obtain connection with any subscriber's line, and means for supplying all necessary current.

61. In a telephone system, the combination of a central station, a plurality of out-lying or sub-central stations, electrically-propelled and step-by-step-actuated switching machinery located at the central station, having vertical motion to select groups and 80 rotary motion to connect with a line in the selected group, trunk-lines connecting the central station with the sub-central stations, electrically-propelled and step-by-step-actuated switching machinery located at the sub-central stations, a plurality of subscribers' telephone lines terminating at each sub-central station, subscribers' impulse transmitters for operating the switching machinery at the sub-central stations, suitably operated impulse transmitters located at the sub-central stations and adapted for operating the switching machinery at the central station, 85 suitably operated impulse transmitters located at the central station and adapted for operating the switching machinery at the sub-central stations, and means for supplying all necessary current, the switching machinery of the central station constituting the medium for establishing connection between any two subscribers' lines, whether of the same or different sub-central stations.

62. In a telephone system, the combination of a central station, a plurality of out-lying or auxiliary stations, trunk-lines connecting the central station with the said auxiliary stations, each trunk-line consisting of but two metallic conductors, automatic trunking machinery at the central station, having vertical motion to select groups and 105 rotary motion to connect with a line in the selected group, release-trunks for said trunking machinery, repeaters located at the central station, one for each outgoing trunk-line leading therefrom, automatic selecting and connecting machinery located at the auxiliary stations, local release-trunks for said auxiliary station switching machinery, repeaters located at the auxiliary stations, one for each incoming trunk-line 110 120 125 130

leading into the central station, a plurality of subscribers' telephone lines terminating at each auxiliary station, subscribers' impulse transmitting devices for operating the central and auxiliary station switching machinery, and means for supplying all necessary current, the system being dependent upon the central station for connection between any two subscribers' lines, whether of the same or different auxiliary stations.

63. In a telephone system, the combination of a central station, a plurality of outlying or auxiliary stations, trunking cables connecting the central station with the auxiliary stations, first and second selectors located at the central station, three-wire trunks connecting the first-selectors with the second-selectors, release-circuits for said selectors, said circuits including the third wires or conductors of the trunks, repeaters at the central station, one for each outgoing trunk-line leading therefrom, a plurality of subscribers' telephone lines terminating at each auxiliary station, subscribers' individual-switches at the auxiliary stations, connectors at the auxiliary stations, having vertical motion to select groups and rotary motion to connect with a line in the selected group, repeaters at the auxiliary stations, one for each incoming trunk-line leading to the central station, three-wire trunks between the individual-switches and repeaters of the auxiliary stations, local release-circuits for said individual-switches, said local release-circuits including the third wires or conductors of the trunks which connect the individual switches with the repeaters of the auxiliary stations, subscribers' impulse transmitters for operating the individual-switches, adapted also to operate the selectors and connectors through the medium of said repeaters, and means for supplying all necessary current.

64. In a telephone system, the combination of a plurality of subscribers' telephone lines, means having vertical motion to select groups and rotary motion to connect with a line in the selected group, an individual-switch for each line, each switch provided with an energizing circuit for bringing the switch into use, a switch-operating machine or master-switch common to all of said individual-switches, provided with a relay controlling all of said energizing circuits, and means whereby said relay is always energized while the switch-operating machine or master-switch is in motion.

65. In a telephone system, the combination of a plurality of subscribers' lines, means having vertical motion to select groups and rotary motion to connect with a line in the selected group, an individual-switch for each subscriber's line, a trip-magnet and mechanism to be released thereby for each individual-switch, an energizing circuit for each

trip-magnet, a switch-operating machine or master-switch common to all of said individual-switches, provided with a relay controlling all of said energizing circuits, and means whereby said relay is always energized while the switch-operating machine or master-switch is in motion.

66. In a telephone system, the combination of a plurality of subscribers' lines, means having vertical motion to select groups and rotary motion to connect with a line in the selected group, an individual switching means for each line, means for rendering all idle switches inoperative while moving from one connecting position to another, a motor-magnet, a ratchet mechanism operated by the magnet, a bank of contacts, a wiper operated by said ratchet mechanism and adapted to traverse said bank of contacts, and means for preventing forward actuation of the ratchet mechanism during the return movement of said wiper over one or more busy contacts to normal position or starting point, substantially as set forth.

67. In a telephone system, the combination of a plurality of subscribers' telephone lines, means having vertical motion to select groups and rotary motion to connect with a line in the selected group, a plurality of trunk-lines, trunk-selecting machinery controlled by the subscribers for automatically selecting an idle trunk-line for the next calling subscriber, and means for preventing any calling subscriber from accidentally securing connection with a busy trunk-line while the selecting machinery is in motion and in search of an idle trunk-line for the next calling subscriber.

68. In a telephone system, the combination of a plurality of subscribers' telephone lines, means having vertical motion to select groups and rotary motion to connect with a line in the selected group, a plurality of trunk-lines, means for automatically selecting an idle trunk-line, and means for preventing forward actuation of said trunk-selecting means while the same is returning to normal position or starting point.

69. In a telephone system, the combination of a plurality of subscribers' lines, means having vertical motion to select groups and rotary motion to connect with a line in the selected group, a plurality of trunk-lines, an individual trunk-selecting switch for each subscriber's line, and a switch-operating machine or master-switch common to all of said individual-switches, provided with a motor-magnet, a differential-relay connected to control the energizing of said motor-magnet, and means for reversing the polarity of said relay one or more times during the return of the master-switch to normal position or starting point.

70. In a telephone system, the combination of a plurality of subscribers' telephone

- lines, means having vertical motion to select groups and rotary motion to connect with a line in the selected group, a plurality of trunk-lines, an individual-switch for each 5 subscriber's line, and a master-switch common to all of said individual-switches, provided with a differential-relay having a permanently closed circuit including differential windings thereof in parallel, whereby 10 said relay is not energized except by unbalancing the relative flow of current in its windings.
71. In a telephone system, the combination of a plurality of subscriber's telephone 15 lines, means having vertical motion to select groups and rotary motion to connect with a line in the selected group, trunk-selecting switching machinery, a plurality of trunk-lines, and means for supplying all necessary 20 current, said machinery having a motor-magnet, an energizing circuit for said magnet, a differential-relay controlling said energizing circuit, and a permanently closed circuit including differential windings of 25 said relay in parallel, whereby said relay is energized by unbalanceing the relative flow of current in its windings.
72. In a telephone system, the combination of a plurality of subscribers' telephone lines, 30 means having vertical motion to select groups and rotary motion to connect with a line in the selected group, a plurality of trunk-lines, and trunk-selecting switching machinery controlled by the subscribers, provided with a plurality of contacts each representing one of said trunk-lines, and means by which either a positive or negative potential at any contact will cause the said 35 machinery to vacate such contact.
73. In a telephone system, the combination of a battery having one pole grounded, a plurality of subscribers' lines, means having vertical motion to select groups and rotary motion to connect with a line in the selected 40 group, a plurality of trunk-lines, trunk-selecting switching machinery controlled by the subscribers, provided with a bank of contacts whereof each represents one of said trunk-lines, and means whereby the temporary connection of a contact with either the grounded or non-grounded pole of said battery will cause said machinery to vacate 45 such contact.
74. In a telephone system, the combination of means having vertical motion to select groups and rotary motion to connect with a line in the selected group, a plurality of subscribers' individual-switches, a shaft common to all of said switches, each switch 50 having an energizing circuit, a master-switch common to all of said individual-switches and adapted for operating said shaft, provided with a relay controlling all of said energizing circuits, and means for 55 always energizing said relay while the shaft 65 is in motion, for the purpose set forth.
75. In a telephone system, the combination of a plurality of subscribers' lines, means having vertical motion to select groups and rotary motion to connect with a line in the selected group, a plurality of trunk-lines, and a selectively operated individual trunking switch for each subscriber's line, said individual-switches each comprising only a single row of spring 70 sockets and only a single plunger for operating said spring sockets, substantially as and for the purpose set forth.
76. In a telephone system, the combination of a plurality of subscribers' lines, 75 means having vertical motion to select groups and rotary motion to connect with a line in the selected group, a plurality of trunk-lines, and a selectively operated subscriber's individual trunking switch for each 80 subscriber's line, each individual-switch comprising a single row of sockets or guide openings, switch-springs or contacts mounted at each side of said row of sockets, and a single plunger adapted to swing back and 85 forth along said row of sockets and to enter any socket when connection is to be closed between a subscriber's line and an idle trunk-line.
77. In a telephone system, the combination of a plurality of subscribers' lines, 90 means having vertical motion to select groups and rotary motion to connect with a line in the selected group, a plurality of trunk-lines, a selectively operated subscriber's individual trunking switch for each 95 subscriber's line, a master-switch for operating said individual-switches, each individual-switch having a single bank of contacts provided with a single row of guide 100 openings, metal plates and switch-springs mounted at each side of said row of guide openings, and a single plunger adapted to swing back and forth along said row of guide 105 openings, and to enter any guide opening 110 when connection is to be closed between a subscriber's line and an idle trunk-line, said guide openings being provided with a piece of insulation having a row of notches or recesses, substantially as and for the purpose 115 set forth.
78. In a telephone system, the combination of a main or central station, a plurality of outlying or sub-central stations, trunking cables connecting the said central station 120 with the said sub-central stations, selectors located at the central station and adapted for performing trunking operations corresponding to all of the digits of any called number except the last two thereof, having 125 vertical motion to select groups and rotary motion to connect with a line in the selected group, subscribers' telephone lines leading

into the sub-central stations, an individual trunk-selecting switch for each subscriber's line, a switch-operating machine or master-switch located at each sub-central station 5 and common to all the individual-switches thereof, connectors located at the sub-central stations, the connectors of any sub-central station being less in number than the subscribers' lines leading thereto, but each connector 10 having a multiple terminal of each telephone line terminating at the sub-central station at which such connector is located, the said system also being provided with automatic means for precluding connection 15 with a busy subscriber's line.

79. In a telephone system, the combination of a central station, a plurality of sub-central stations, trunking cables connecting the central station with the sub-central stations, 20 trunk-selecting apparatus at the central station, having vertical motion to select groups and rotary motion to connect with a line in the selected group, trunk-selecting apparatus at the sub-central stations, connectors at the 25 sub-central stations, a switch-operating machine or master-switch located at each sub-central station and common to all the trunk-selecting apparatus thereof, a plurality of subscribers' telephone lines terminating at 30 each sub-central station, subscribers' devices for controlling the operations of the central and sub-central switching apparatus, and means for supplying all necessary current, the said system being also provided with 35 automatic means for precluding connection with a busy subscriber's line.

80. In a telephone system, the combination of a central station, a plurality of outlying or sub-central stations, first and second selectors 40 located at the central station, having vertical motion for selecting groups and rotary motion to connect with a line in the selected group, trunking cables connecting the central station with the sub-central stations, said cables as a whole containing as 45 many incoming trunk-lines leading into the central station as there are first-selectors, and containing also as many outgoing trunk-lines leading from the central station as 50 there are second-selectors, and the system also comprising repeaters located at the central station, one for each outgoing trunk-line leading therefrom, connectors located at the sub-central stations, one for each outgoing 55 trunk-line leading from the central station, repeaters located at the sub-central stations, one for each incoming trunk-line leading to the central station, a plurality of subscribers' telephone lines terminating at each 60 sub-central station, the subscribers' telephone lines of each sub-central station being greater in number than the trunk-lines thereof, individual-switches located at the sub-central stations, one for each subscriber's

telephone line, a switch-operating machine 65 or master-switch located at each sub-central station and common to all the individual-switches thereof, subscriber-operated means for controlling the operations of the central and sub-central station apparatus, and means 70 for supplying all necessary current, the said system being also provided with automatic means for precluding connection with a busy subscriber's line.

81. In a telephone system, the combination 75 of a central station, a plurality of auxiliary or sub-central stations, trunk-lines connecting the central station with the sub-central stations, suitable switch-board apparatus at the said central station, having vertical motion to select groups and rotary motion to connect with a line in the selected group, a plurality of subscribers' telephone lines terminating at each sub-central station, an individual trunking switch for each subscriber's 80 telephone line, said individual-switches located at the sub-central stations, a master-switch or switch-operating machine located at each sub-central station and common to all the individual-switches thereof, a plurality 85 of connectors at each sub-central station, the connectors of any sub-central station being less in number than the total number of telephone lines terminating thereat, subscribers' devices for automatically operating 90 the individual-switches to obtain trunk-line connection with the central station, and means for supplying all necessary current, the said system being also provided with automatic means for precluding connection 95 with a busy subscriber's line.

82. In a telephone system, the combination 100 of a central station, a plurality of outlying or sub-central stations, electrically-propelled and step-by-step-actuated switching machinery located at the central station, having vertical motion to select groups and rotary motion to connect with a line in the selected group, trunk-lines connecting 105 the central station with the sub-central stations, electrically-propelled and step-by-step actuated switching machinery located at the sub-central stations, a plurality of subscribers' telephone lines terminating at each sub-central station, subscribers' impulse transmitters for operating the switching machinery at the sub-central stations, suitably operated impulse transmitters located at the sub-central stations and adapted for operating 110 the switching machinery at the central station, suitably operated impulse transmitters located at the central station and adapted for operating the switching machinery at the sub-central stations, and means for 115 supplying all necessary current, the switching machinery at the central station constituting the medium for establishing connection 120 between any two subscribers' lines,

- whether of the same or different sub-central stations, the said system being also provided with automatic means for precluding connection with a busy subscriber's line.
83. In a telephone system, the combination of a central station, a plurality of out-lying or auxiliary stations, trunk-lines connecting the central station with the said auxiliary stations, each trunk-line consisting of but two metallic conductors, automatic trunking machinery at the central station, having vertical motion to select groups and rotary motion to connect with a line in the selected group, release-trunks for said trunking machinery, repeaters located at the central station, one for each outgoing trunk-line leading therefrom, automatic selecting and connecting machinery located at the auxiliary stations, local release-trunks for said auxiliary station switching machinery, repeaters located at the auxiliary stations, one for each incoming trunk-line leading into the central station, a plurality of subscribers' telephone lines terminating at each auxiliary station, subscribers' impulse transmitting devices for operating the central and auxiliary station switching machinery, and means for supplying all necessary current, the system being dependent upon the central station for connection between any two subscribers' lines, whether of the same or different auxiliary stations, and the said system being also provided with automatic means for precluding connection with a busy subscriber's line. 7c
84. In a telephone system, the combination of a central station, a plurality of out-lying or auxiliary stations, trunking cables connecting the central station with the auxiliary stations, first and second selectors located at the central station, three-wire trunks connecting the first-selectors with the second-selectors, release-circuits for said selectors, said circuits including the third wires or conductors of the trunks, repeaters at the central station, one for each outgoing trunk-line leading therefrom, a plurality of subscribers' telephone lines terminating at each auxiliary station, subscribers' individual-switches at the auxiliary stations, connectors at the auxiliary stations, having vertical motion to select groups and rotary motion to connect with a line in the selected group, repeaters at the auxiliary stations, one for each incoming trunk-line leading to the central station, three-wire trunks between the individual-switches and repeaters of the auxiliary stations, local release-circuits for said individual-switches, said local release-circuits including the third wires or conductors of the trunks which connect the individual-switches with the repeaters of the auxiliary stations, subscribers' impulse transmitters for operating the individual-switches, adapted also to operate the selec- 100
- tors and connectors through the medium of said repeaters, and means for supplying all necessary current, the said system being also provided with automatic means for precluding connection with a busy subscriber's line. 105
85. In a telephone system, the combination of a plurality of subscribers' telephone lines, means having vertical motion to select groups and rotary motion to connect with a line in the selected group, an individual-switch for each line, each switch provided with an energizing circuit for bringing the switch into use, a switch-operating machine or master-switch common to all of said individual-switches, provided with a relay controlling all of said energizing circuits, and means whereby said relay is always energized while the switch-operating machine or master-switch is in motion, the said system being also provided with automatic means for precluding connection with a busy subscriber's line. 110
86. In a telephone system, the combination of a plurality of subscribers' lines, means having vertical motion to select groups and rotary motion to connect with a line in the selected group, an individual-switch for each subscriber's line, a trip-magnet and mechanism to be released thereby for each individual-switch, an energizing circuit for each trip-magnet, a switch-operating machine or master-switch common to all of said individual-switches, provided with a relay controlling all of said energizing circuits, and means whereby said relay is always energized while the switch-operating machine or master-switch is in motion, the said system being also provided with automatic means for precluding connection with a busy subscriber's line. 115
87. In a telephone system, the combination of a plurality of subscribers' lines, means having vertical motion to select groups and rotary motion to connect with a line in the selected group, an individual switching means for each line, means for rendering all idle switches inoperative while moving from one connecting position to another, a motor-magnet, a ratchet mechanism operated by the magnet, a bank of contacts, a wiper operated by said ratchet mechanism and adapted to traverse said bank of contacts, and means for preventing forward actuation of the ratchet mechanism during the return movement of said wiper over one or more busy contacts to normal position or starting point, the said system being also provided with automatic means for precluding connection with a busy subscriber's line, substantially as set forth. 120
88. In a telephone system, the combination of a plurality of subscribers' telephone lines, means having vertical motion to select groups and rotary motion to connect with a line in the 125

the selected group, a plurality of trunk-lines, trunk-selecting machinery controlled by the subscribers for automatically selecting an idle trunk-line, and means for preventing 5 any calling subscriber from accidentally securing connection with a busy trunk-line while the selecting machinery is in motion and in search of an idle trunk-line, the said system being also provided with automatic 10 means for precluding connection with a busy subscriber's line.

89. In a telephone system, the combination of a plurality of subscribers' telephone lines, means having vertical motion to select 15 groups and rotary motion to connect with a line in the selected group, a plurality of trunk-lines, means for automatically selecting an idle trunk-line, and means for preventing forward actuation of said trunk- 20 selecting means while the same is returning to normal position or starting point, the said system being also provided with automatic means for precluding connection with a busy subscriber's line.

90. In a telephone system, the combination of a plurality of subscribers' lines, means having vertical motion to select groups and rotary motion to connect with a line in the selected group, a plurality of trunk-lines, 30 an individual trunk-selecting switch for each subscriber's line, and a switch-operating machine or master-switch common to all of said individual-switches, provided with a motor-magnet, a differential-relay connected to control the energizing of said motor-magnet, and means for reversing the polarity of said 35 relay one or more times during the return of the master-switch to normal position or starting point, the said system being also 40 provided with automatic means for precluding connection with a busy subscriber's line.

91. In a telephone system, the combination of a plurality of subscribers' telephone lines, means having vertical motion to select 45 groups and rotary motion to connect with a line in the selected group, a plurality of trunk-lines, an individual-switch for each subscriber's line, and a master-switch common to all of said individual-switches, provided 50 with a differential-relay having a permanently closed circuit including differential windings thereof in parallel, whereby said relay is not energized except by unbalancing the relative flow of current in its 55 windings, the said system being also provided with automatic means for precluding connection with a busy subscriber's line.

92. In a telephone system, the combination of a plurality of subscribers' telephone 60 lines, means having vertical motion to select groups and rotary motion to connect with a line in the selected group, trunk-selecting switching machinery, a plurality of trunk-lines, and means for supplying all necessary 65 current, said machinery having a motor-

magnet, an energizing circuit for said magnet, a differential-relay controlling said energizing circuit, and a permanently closed circuit including differential windings of said relay in parallel, whereby said relay is 70 energized by unbalancing the relative flow of current in its windings, the said system being also provided with automatic means for precluding connection with a busy subscriber's line. 75

93. In a telephone system, the combination of a plurality of subscribers' telephone lines, means having vertical motion to select groups and rotary motion to connect with a line in the selected group, a plurality of 80 trunk-lines, and trunk-selecting switching machinery controlled by the subscribers, provided with a plurality of contacts each representing one of said trunk-lines, and means by which either a positive or negative potential at any contact will cause the said machinery to vacate such contact, the said system being also provided with automatic means for precluding connection with a busy subscriber's line. 90

94. In a telephone system, the combination of a battery having one pole grounded, a plurality of subscribers' lines, means having vertical motion to select groups and rotary motion to connect with a line in the 95 selected group, a plurality of trunk-lines, trunk-selecting switching machinery controlled by the subscribers, provided with a bank of contacts whereof each represents one of said trunk-lines, and means whereby 100 the temporary connection of a contact with either the grounded or non-grounded pole of said battery will cause said machinery to vacate such contact, the said system being also provided with automatic means for precluding connection with a busy subscriber's line. 105

95. In a telephone system, the combination of means having vertical motion to select groups and rotary motion to connect 110 with a line in the selected group, a plurality of subscribers' individual-switches, a shaft common to all of said switches, each switch having an energizing circuit, a master-switch common to all of said individual-switches 115 and adapted for operating said shaft, provided with a relay controlling all of said energizing circuits, and means for always energizing said relay while the shaft is in motion, the said system being also provided 120 with automatic means for precluding connection with a busy subscriber's line, for the purpose set forth.

96. In a telephone system, the combination of a plurality of subscribers' lines, 125 means having vertical motion to select groups and rotary motion to connect with a line in the selected group, a plurality of trunk-lines, and a selectively operated individual trunking switch for each subscriber's 130

line, said individual-switches each comprising only a single row of spring sockets and only a single plunger for operating said spring sockets, the said system being also 5 provided with automatic means for precluding connection with a busy subscriber's line, substantially as and for the purpose set forth.

97. In a telephone system, the combination 10 of a plurality of subscribers' lines, means having vertical motion to select groups and rotary motion to connect with a line in the selected group, a plurality of trunk-lines, and a selectively-operated subscriber's individual trunking switch for each subscriber's line, each individual-switch comprising a single row of sockets or guide openings, switch-springs or contacts mounted at each side of said row of sockets, and 15 a single plunger adapted to swing back and forth along said row of sockets and to enter any socket when connection is to be closed between a subscriber's line and an idle trunk-line, the said system being also provided 20 with automatic means for precluding connection with a busy subscriber's line.

98. In a telephone system, the combination 25 of a plurality of subscribers' lines, means having vertical motion to select groups and rotary motion to connect with a line in the selected group, a plurality of trunk-lines, a selectively operated subscriber's individual trunking switch for each subscriber's line, a master-switch for operating 30 said individual-switches, each individual-switch having a single bank of contacts provided with a single row of guide openings, metal plates and switch-springs mounted at each side of said row of guide openings, and a single plunger adapted to swing back and forth along said row of guide openings, and to enter any guide opening when connection is to be closed between a subscriber's line and an idle trunk-line, said 35 guide openings being provided with a piece of insulation having a row of notches or recesses, the said system being also provided with automatic means for precluding connection with a busy subscriber's line, substantially as and for the purpose set forth.

99. A telephone system comprising a trunk-line, a plurality of telephone lines, means whereby a plurality of calling connections may be made at the same time including means having vertical motion to select groups and rotary motion to connect with a line in the selected group, individual magnets for closing connection between the calling telephone line and a trunk-line, line 55 circuits by which any subscriber may energize his individual magnet to close connection with the trunk-line, a common magnet, and automatic means by which said common magnet is energized to momentarily open a

plurality of said line circuits when a subscriber calls. 65

100. A telephone system comprising a trunk-line, a plurality of telephone lines, means whereby a plurality of calling connections may be made at the same time including means having vertical motion to select groups and rotary motion to connect with a line in the selected group, individual magnets for closing connection between the telephone lines and said trunk-line, line circuits 70 for energizing said magnets, a common magnet, and means for energizing said common magnet to momentarily open the circuits of a plurality of said individual magnets when a subscriber calls. 80

101. A telephone system comprising a trunk-line, a plurality of telephone lines, means having vertical motion to select groups and rotary motion to connect with a line in the selected group, a main station, a branch station at which the telephone lines terminate, and which is connected with the main station by said trunk-line, subscribers' individual magnets for closing connection between the telephone lines and the trunk-line, located at the branch station, a common magnet also located at the branch station, line circuits for energizing said individual magnets to close connection with the trunk-line, and means for energizing said common magnet to open a plurality of said circuits when a subscriber calls. 90

102. A telephone system comprising trunk-lines, automatic means for selecting idle trunk-lines, a plurality of subscribers' telephone lines normally disconnected from each other, means for extending connection between two subscribers' lines, said means having one motion to select groups and a second motion to connect with a line in the selected group, and automatic means by which a calling subscriber opens the normal line circuit of a plurality of said telephone lines. 105

103. A telephone system comprising a main station, a branch station, a plurality of trunk-lines connecting the main station with the branch station, subscribers' telephone lines leading to the branch station, means for extending connection between two subscribers' lines, said means having one motion to select groups and a second motion to connect with a line in the selected group, instrumentalities at the branch station for selecting idle trunk-lines and connecting calling telephone lines therewith, including individual magnets for said telephone lines, line circuits for energizing said magnets, and automatic means for opening a plurality of said circuits when a subscriber calls. 110

104. A telephone system comprising trunk-lines, subscribers' telephone lines, means for extending connection between two subscribers' lines, said means having one motion

to select groups and a second motion to connect with a line in the selected group, instrumentalities for selecting idle trunk-lines and connecting calling telephone lines therewith, 5 including individual magnets for said telephone lines, line circuits for energizing said magnets to close connection from calling telephone lines to idle trunk-lines, and automatic means for opening a plurality of said 10 circuits when a subscriber calls.

105. A telephone system comprising a main station, a branch station, a plurality of trunk-lines connecting the main station with the branch station, subscribers' telephone 15 lines leading to the branch station, means for extending connection between two subscribers' lines, said means having one motion to select groups and a second motion to connect with a line in the selected group, means 20 at the branch station for selecting idle trunk-lines and connecting the calling telephone lines therewith, individual magnets for said telephone lines, normally open line circuits for energizing said magnets to effect connection 25 with idle trunk-lines, a normally closed switch in each circuit, and automatic means for opening said switch when a subscriber calls.

106. A telephone system comprising a 30 trunk-line, a plurality of telephone lines to which said trunk-line is common, means for extending connection between two subscribers' lines, said means having one motion to select groups and a second motion to connect with a line in the selected group and adapted to pass over busy lines without being interfered with, means under the control of the subscribers of said telephone lines for closing connection therefrom to the trunk-line, and automatic means for at times preventing the other subscribers from calling when one subscriber is calling over said 35 trunk-line.

107. A telephone system comprising a 45 main station, sub-central or branch stations, trunk-line connection between the main station and the sub-central or branch stations, telephone lines leading to the branch stations, means for extending connection between 50 two subscribers' lines, said means having one motion to select groups and a second motion to connect with a line in the selected group, and adapted to pass over busy lines without being interfered with, means at the 55 branch stations for extending trunk-line connection from the telephone lines, and automatic means at the branch stations for at times preventing any other subscriber in the same branch station from calling while another subscriber of the same station is calling.

108. In a telephone system, a central station, a branch central station having a trunk-line connection therewith, a group of subscriber's stations connected to the branch 60

central station, an electromagnet at the branch central station connected to each of the subscribers' lines and under the sole control of the subscriber, contacts under the control of said electromagnets for closing 70 connection between the trunk-line and the subscriber's station when the electromagnet is energized, and an additional electromagnet common to the entire group of subscribers' stations, and contacts under the control 75 of the additional magnet and through which all connections must be primarily made, the energizing of the additional electromagnet by any subscriber cutting out all of the remaining subscribers of the group. 80

109. In a telephone system, a main central station, a branch central station connected thereto by a trunk-line, a series of circuit-closing electromagnets arranged at the branch central station, a group of subscribers' stations, each of which is individually connected to one of said electromagnets, a circuit-breaking electromagnet arranged at the branch central station and common to an entire group of subscriber's stations, and contacts under the control of the electromagnets for closing connection between the trunk-line and any subscriber, and automatically breaking the circuits of the remaining subscribers of the group. 95

110. In a telephone system, a trunk-line, a branch central station forming one terminal of the trunk-line, a series of electromagnets arranged at the branch central station, contacts arranged adjacent to each magnet and under the control of its armature, the terminals of the trunk-line being connected to two of the contacts of each set, a group of subscribers' stations connected each to one of the electromagnets and also to contacts 100 under the control of the electromagnet to which it is connected, whereby energizing of the subscriber's line and electromagnet connects the subscriber's station to the trunk-line, and a circuit-breaking electromagnet 110 having contacts under the control of said armature, the contacts being connected in multiple with the entire group of subscribers' stations, whereby on the energizing of the circuit-breaking electromagnet by any 115 subscriber the connections of the remaining subscribers of the group will be broken.

111. In a system employing relay bridges for the line circuits, the combination of a main or central station, a plurality of out-lying or sub-central stations, trunking cables connecting the said central station with the said sub-central stations, selectors located at the central station and adapted for performing trunking operations corresponding to all 120 of the digits of any called number except the last two thereof, subscribers' telephone lines leading into the sub-central stations, an individual trunk-selecting switch for each subscriber's line, a switch-operating machine or 125

130

master-switch located at each sub-central station and common to all the individual switches thereof, connectors located at the sub-central stations, the connectors of any 5 sub-central station being less in number than the subscribers' lines leading thereto, but each connector having a multiple terminal of each telephone line terminating at the sub-central station at which such connector is located, and means for automatically reducing the number of bridges across the conductors of any talking circuit between calling and called subscribers.

112. In a system employing relay bridges 15 for the line circuits, the combination of a central station, a plurality of sub-central stations, trunking cables connecting the central station with the sub-central stations, trunk-selecting apparatus at the central station, 20 trunk-selecting apparatus at the sub-central stations, connectors at the sub-central stations, a switch-operating machine or master switch located at each sub-central station and common to all the trunk-selecting apparatus 25 thereof, a plurality of subscribers' telephone lines terminating at each sub-central station, subscribers' devices for controlling the operations of the central and sub-central switching apparatus, means for supplying all necessary current, and means for automatically reducing the number of bridges 30 across the conductors of any talking circuit between calling and called subscribers.

113. In a system employing relay bridges 35 for the line circuits, the combination of a central station, a plurality of outlying or sub-central stations, first and second selectors located at the central station, trunking cables connecting the central station with the 40 sub-central stations, said cables as a whole containing as many incoming trunk-lines leading into the central station as there are first selectors, and containing also as many outgoing trunk-lines leading from the 45 central station as there are second selectors, and the system also comprising repeaters located at the central station, one for each outgoing trunk-line leading therefrom, connectors located at the sub-central stations, one for each 50 outgoing trunk-line leading from the central station, repeaters located at the sub-central stations, one for each incoming trunk-line leading to the central station, a plurality of subscribers' telephone lines terminating at 55 each sub-central station, the subscribers' telephone lines of each sub-central station being greater in number than the trunk-lines thereof, individual switches located at the sub-central stations, one for each subscriber's 60 telephone line, a switch-operating machine or master switch located at each sub-central station and common to all the individual switches thereof, subscriber-operated means for controlling the operations of the 65 central and sub-central station apparatus,

means for supplying all necessary current, and means for automatically reducing the number of bridges across the conductors of any talking circuit between calling and called subscribers.

70

114. In a system employing relay bridges for the line circuits, the combination of a central station, a plurality of auxiliary or sub-central stations, trunk-lines connecting the central station with the sub-central stations, suitable switchboard apparatus at the said central station, a plurality of subscribers' telephone lines terminating at each sub-central station, an individual trunking switch for each subscriber's telephone line, 80 said individual switches located at the sub-central stations, a master-switch or switch-operating machine located at each sub-central station and common to all the individual switches thereof, a plurality of connectors 85 at each sub-central station, the connectors of any sub-central station being less in number than the total number of telephone lines terminating thereat, subscribers' devices for automatically operating the individual switches 90 to obtain trunk-line connection with the central station, means for supplying all necessary current, and means for automatically reducing the number of bridges across the conductors of any talking circuit between 95 calling and called subscribers.

85

90

95

115. In a system employing relay bridges for the line circuits, the combination of a central station, a plurality of outlying or sub-central stations, trunk-lines connecting the central station with the different sub-central stations, a plurality of subscribers' telephone lines terminating at each sub-central station, the trunk-lines for each sub-central station being less in number than 100 the total number of subscribers' telephone lines thereof, a plurality of connectors at each sub-central station, said connectors less in number than the total number of subscribers' lines, automatic trunking apparatus at each sub-central station, subscribers' impulse transmitters for operating said trunking apparatus to obtain trunk-line connection with the central station, suitably operated impulse transmitters located at the 105 central station and adapted for operating said connectors to obtain connection with any subscriber's line, means for supplying the electric current necessary for producing the switch-operating impulses, and means 110 for automatically reducing the number of bridges across the conductors of any talking circuit between calling and called subscribers.

105

110

120

125

116. In a system employing relay bridges for the line circuits, the combination of a central station, a plurality of sub-central stations, trunk-lines connecting the central station with the sub-central stations, a plurality of subscribers' telephone lines termi- 130

- nating at each sub-central station, means at the central station upon which the system is dependent for accomplishing connection between any two subscribers' lines, whether of 5 the same or different sub-central stations, trunking apparatus located at each sub-central station, connectors located at the sub-central stations, subscribers' impulse transmitters for operating the trunking apparatus, 10 thus to obtain trunk-line connection with the central station, suitably operated impulse transmitters located at the central station and adapted for operating said connectors to obtain connection with any subscriber's line, 15 means for supplying all necessary current, and means for automatically reducing the number of bridges across the conductors of any talking circuit between calling and called subscribers.
- 20 117. In a system employing relay bridges for the line circuits, the combination of a central station, a plurality of sub-central stations, trunking cables connecting the main or central station with the sub-central stations, a plurality of subscribers' telephone lines terminating at each sub-central station, the subscribers' lines terminating at each sub-central station being greater in number than the trunk-lines thereof, electrically- 25 propelled and step-by-step-actuated switching machinery at each sub-central station, subscribers' impulse transmitters for operating said switching machinery to obtain trunk-line connection with the central station, suitably operated impulse transmitters located at the central station and adapted for operating said switching machinery to obtain connection with any subscriber's line, 30 means for supplying all necessary current, and means for automatically reducing the number of bridges across the conductors of any talking circuit between calling and called subscribers.
- 35 118. In a system employing relay bridges for the line circuits, the combination of a central station, a plurality of outlying or sub-central stations, electrically-propelled and step-by-step-actuated switching machinery located at the central station, trunk- 40 lines connecting the central station with the sub-central stations, electrically-propelled and step-by-step-actuated switching machinery located at the sub-central stations, a plurality of subscribers' telephone lines 45 terminating at each sub-central station, subscribers' impulse transmitters for operating the switching machinery at the sub-central stations, suitably operated impulse transmitters located at the sub-central stations 50 and adapted for operating the switching machinery at the central station, suitably operated impulse transmitters located at the central station and adapted for operating the switching machinery at the sub-central stations 55 60 65

current, the switching machinery of the central station constituting the medium for establishing connection between any two subscribers' lines, whether of the same or different sub-central stations, and means for 70 automatically reducing the number of bridges across the conductors of any talking circuit between calling and called subscribers.

119. In a system employing relay bridges 75 for the line circuits, the combination of a central station, a plurality of outlying or auxiliary stations, trunk-lines connecting the central station with the said auxiliary stations, each trunk-line consisting of but two 80 metallic conductors, automatic trunking machinery at the central station, release trunks for said trunking machinery, repeaters located at the central station, one for each outgoing trunk-line leading therefrom, automatic selecting and connecting machinery located at the auxiliary stations, local release trunks for said auxiliary station switching machinery, repeaters located at the auxiliary stations, one for each incoming 85 trunk-line leading into the central station, a plurality of subscribers' telephone lines terminating at each auxiliary station, subscribers' impulse transmitting devices for operating the central and auxiliary station 90 switching machinery, means for supplying all necessary current, the system being dependent upon the central station for connecting between any two subscribers' lines, whether of the same or different auxiliary 95 stations, and means for automatically reducing the number of bridges across the conductors of any talking circuit between calling and called subscribers.

120. In a system employing relay bridges 105 for the line circuits, the combination of a central station, a plurality of outlying or auxiliary stations, trunking cables connecting the central station with the auxiliary stations, first and second selectors located at 110 the central station, three-wire trunks connecting the first selectors with the second selectors, release circuits for said selectors, said circuits including the third wires or conductors of the trunks, repeaters at the 115 central station, one for each outgoing trunk-line leading therefrom, a plurality of subscribers' telephone lines terminating at each auxiliary station, subscribers' individual switches at the auxiliary stations, connectors at the auxiliary stations, repeaters at the auxiliary stations, one for each incoming 120 trunk-line leading to the central station, three-wire trunks between the individual switches and repeaters of the auxiliary stations, local release circuits for said individual switches, said local release circuits including the third wires or conductors of the trunks which connect the individual switches 125 with the repeaters of the auxiliary stations, 130

- subscribers' impulse transmitters for operating the individual switches, adapted also to operate the selectors and connectors through the medium of said repeaters, means for 5 supplying all necessary current, and means for automatically reducing the number of bridges across the conductors of any talking circuit between calling and called subscribers.
- 10 121. In a trunking system in which the trunks are disposed in groups, the combination of a main or central station, a plurality of outlying or sub-central stations, trunking cables connecting the said central station with the said sub-central stations, selectors located at the central station and adapted for performing trunking operations corresponding to all of the digits of any called number except the last two thereof, subscribers' telephone lines leading into the sub-central stations, an individual trunk-selecting switch for each subscriber's line, a switch-operating machine or master switch located at each sub-central station and common to all the individual switches thereof, connectors located at the sub-central stations, the connectors of any sub-central station being less in number than the subscribers' lines leading thereto, but each connector having a multiple terminal of each telephone line terminating at the sub-central station at which such connector is located, said trunk-selecting and line-connecting apparatus including switches having vertical motion to select groups and rotary motion to automatically select an idle trunk in a predetermined group. 15 20 25 30 35 40 45 50 55 60 65
122. In a trunking system in which the trunks are disposed in groups, the combination of a central station, a plurality of sub-central stations, trunking cables connecting the central station with the sub-central stations, trunk-selecting apparatus at the central station, trunk-selecting apparatus at the sub-central stations, connectors at the sub-central stations, a switch-operating machine or master switch located at each sub-central station and common to all the trunk-selecting apparatus thereof, a plurality of subscribers' telephone lines terminating at each sub-central station, subscribers' devices for controlling the operations of the central and sub-central switching apparatus, and means for supplying all necessary current, said trunk-selecting and line-connecting apparatus including switches having vertical motion to select groups and rotary motion to automatically select an idle trunk in a predetermined group. 123. In a trunking system in which the trunks are disposed in groups, the combination of a central station, a plurality of auxiliary or sub-central stations, trunk-lines connecting the central station with the sub-central stations, suitable switch-board apparatus at the said central station, a plurality of subscribers' telephone lines terminating at each sub-central station, an individual trunking switch for each subscriber's telephone line, said individual switches located at the sub-central stations, a master switch or switch-operating machine located at each sub-central station and common to all the individual switches thereof, a plurality of connectors at each sub-central station, the connectors of any sub-central station being less in number than the total number of telephone lines terminating thereat, subscribers' devices for automatically operating the individual switches to obtain trunk-line connection with the central station, and means for supplying all necessary current, said trunk-selecting and line-connecting apparatus including switches having vertical motion to select groups and rotary motion to automatically select an idle trunk in a predetermined group. 124. In a trunking system in which the trunks are disposed in groups, the combination of a central station, a plurality of sub-central stations, trunk-lines connecting the central station with the sub-central stations, a plurality of subscribers' telephone lines terminating at each sub-central station, means at the central station upon which the system is dependent for accomplishing connection between any two subscribers' lines, whether of the same or different sub-central stations, trunking apparatus located at each sub-central station, connectors located at the sub-central stations, subscribers' impulse transmitters for operating the trunking apparatus to obtain trunk-line connection with the central station, suitably operated impulse transmitters located at the central station and adapted for operating said connectors to obtain connection with any subscriber's line, and means for supplying all necessary current, said trunk-selecting and line-connecting apparatus including switches having vertical motion to select groups and rotary motion to automatically select an idle trunk in a predetermined group. 125. In a trunking system in which the trunks are disposed in groups, the combination of a central station, a plurality of sub-central stations, trunking cables connecting the main or central station with the sub-central stations, a plurality of subscribers' telephone lines terminating at each sub-central station, the subscribers' lines terminating at each sub-central station being greater in number than the trunk-lines thereof, electrically-propelled and step-by-step-actuated switching machinery at each sub-central station, subscribers' impulse transmitters for operating said switching machinery to obtain trunk-line connection with the central station, suitably operated impulse transmitters located at the central station and adapt-

ed for operating said switching machinery to obtain connection with any subscriber's line, and means for supplying all necessary current, said trunk-selecting and line-connecting apparatus including switches having vertical motion to select groups and rotary motion to automatically select an idle trunk in a predetermined group.

126. In a trunking system in which the trunks are disposed in groups, the combination of a central station, a plurality of out-lying or sub-central stations, electrically-propelled and step-by-step-actuated switching machinery located at the central station, trunk-lines connecting the central station with the sub-central stations, electrically-propelled and step-by-step-actuated switching machinery located at the sub-central stations, a plurality of subscribers' telephone lines terminating at each sub-central station, subscribers' impulse transmitters for operating the switching machinery at the sub-central stations, suitably operated impulse transmitters located at the sub-central stations and adapted for operating the switching machinery at the central station, suitably operated impulse transmitters located at the central station and adapted for operating the switching machinery at the sub-central stations, and means for supplying all necessary current, the switching machinery at the central station constituting the medium for establishing connection between any two subscribers' lines, whether of the same or different sub-central stations, said trunk-selecting and line-connecting apparatus including switches having vertical motion to select groups and rotary motion to automatically select an idle trunk in a predetermined group.

127. In a trunking system in which the trunks are disposed in groups, the combination of a central station, a plurality of out-lying or auxiliary stations, trunk-lines connecting the central station with the said auxiliary stations, each trunk-line consisting of but two metallic conductors, automatic trunking machinery at the central station, release trunks for said trunking machinery, repeaters located at the central station, one for each outgoing trunk-line leading therefrom, automatic selecting and connecting machinery located at the auxiliary stations, local release trunks for said auxiliary station switching machinery, repeaters located at the auxiliary stations, one for each incoming trunk-line leading into the central station, a plurality of subscribers' telephone lines terminating at each auxiliary station, subscribers' impulse transmitting devices for operating the central and auxiliary station switching machinery, and means for supplying all necessary current, the system being dependent upon the central station for connection between any two subscribers' lines,

whether of the same or different auxiliary stations, said trunk-selecting and line-connecting apparatus including switches having vertical motion to select groups and rotary motion to automatically select an idle trunk in a predetermined group.

128. In a trunking system in which the trunks are disposed in groups, the combination of a central station, a plurality of out-lying or auxiliary stations, trunking cables connecting the central station with the auxiliary stations, first and second selectors located at the central station, three-wire trunks connecting the first selectors with the second selectors, release circuits for said selectors, said circuits including the third wires or conductors of the trunks, repeaters at the central station, one for each outgoing trunk-line leading therefrom, a plurality of subscribers' telephone lines terminating at each auxiliary station, subscribers' individual switches at the auxiliary stations, connectors at the auxiliary stations, repeaters at the auxiliary stations, one for each incoming trunk-line leading to the central station, three-wire trunks between the individual switches and repeaters of the auxiliary stations, local release circuits for said individual switches, said local release circuits including the third wires or conductors of the trunks which connect the individual switches with the repeaters of the auxiliary stations, subscriber-controlled means for operating the individual switches, subscribers' impulse transmitters adapted to operate the selectors and connectors through the medium of said repeaters, and means for supplying all necessary current, said trunk-selecting and line-connecting apparatus including switches having vertical motion to select groups and rotary motion to automatically select an idle trunk in a predetermined group.

129. In a telephone system, subscribers' lines, trunk lines extending from said lines, a switch individual to said subscribers' lines for selecting a trunk, a plunger and a bank of contacts for each switch, and means controlled by the subscriber for operating said plunger to cause it to enter said bank, said plunger engaging certain of said bank contacts to cause them to engage other of said contacts with a rubbing or longitudinal motion, whereby the contact points are kept clean from dirt and dust.

130. In a telephone system, subscribers' lines, a plunger under the control of each subscriber, a bank of contacts, and a magnet adapted upon energization to cause said plunger to enter and engage said bank of contacts, said plunger engaging certain of said contacts to cause them to engage other of said contacts with a rubbing or longitudinal action, whereby the contact points are kept clean from dirt and dust.

131. In a telephone system, an automatic

- switch including a bank of normally separated sets of spring contacts, one spring in each set being bent, a plunger adapted to enter said bank, and means for operating said plunger to cause it to enter said bank and cause said contacts to engage with a rubbing or longitudinal action due to the straightening of said bent spring, whereby the contact points are kept clean from dirt and dust. 65
132. A telephone system comprising a trunk line, a plurality of telephone lines, non-numerical switches individual to said lines for closing connection between the telephone lines and the trunk line, line circuits by which any subscriber may operate his individual switch to close connection with the trunk line, a common magnet, and automatic means by which said common magnet is energized to open a plurality of said line circuits when a subscriber calls. 70
133. In a telephone exchange system, the combination of a main or central station, sub-central stations, trunking cables connecting the main station with the sub-central stations, subscribers' telephone lines terminating at the sub-central stations, stationary individual line relays for said telephone lines, means controlled by said relays for trunking a calling subscriber into the main station, means at the main or central station for trunking the calling subscriber to the sub-central station at which the called line terminates, and means at the sub-central stations for completing connection with the called line, substantially as described. 75
134. In a telephone system, the combination of a main or central station, auxiliary or sub-central stations, trunk lines connecting the said central station with the said auxiliary stations, a plurality of subscribers' stations allotted to each auxiliary station, subscribers' telephone lines connecting said subscribers' stations with the said auxiliary stations, automatic trunk-selecting apparatus at the main or central station, automatic trunk-selecting and line-connecting apparatus at the auxiliary stations, repeaters located at the auxiliary stations and adapted for controlling the operation of the apparatus at the central station, repeaters located at the central station and adapted for controlling the operation of the connecting apparatus at the auxiliary stations, and means for supplying all necessary current, substantially as described. 80
135. In a telephone system, the combination of a plurality of subscribers' telephone lines, a plurality of trunk lines, an automatic trunk selector common to said lines for selecting an idle trunk line for any one of said subscribers' lines, and automatic means for preventing forward actuation of said trunk selector while the same is returning to normal position. 85
136. In a telephone system, the combination of a plurality of subscribers' telephone lines, a plurality of trunk lines, an automatic trunk selector common to said lines for selecting an idle trunk line, and automatic means for preventing forward actuation of said trunk selector while the same is returning to normal position, said system being also provided with automatic means for precluding connection with a busy subscriber's line. 90
137. In a telephone system, a plurality of telephone lines, an individual electromagnetic device for each line, a common electrically controlled progressively movable normally at rest mechanism for controlling said individual devices, and a common battery for energizing said devices under the control of said common mechanism. 95
138. In a telephone system, a plurality of telephone lines, an individual electromagnetic device for each line, a common electrically controlled progressively movable normally at rest mechanism for controlling a plurality of said individual devices, and a battery common to a number of said devices under the control of said common mechanism. 100
139. In a telephone system, the combination of a plurality of subscribers' telephone lines, an individual switch for each line, each switch provided with an energizing circuit for bringing the switch into use, a switch-operating machine or master-switch common to all of said individual switches, provided with a relay controlling all of said energizing circuits, and circuit means whereby said relay is always energized while the switch-operating machine or master-switch is in motion. 105
140. In a telephone system, the combination of a plurality of subscribers' lines, an individual-switch for each subscriber's line, a trip-magnet and mechanism to be released thereby for each individual-switch, an energizing circuit for each trip-magnet, a switch-operating machine or master-switch common to all of said individual switches, provided with a relay controlling all of said energizing circuits, and circuit means whereby said relay is always energized while the switch-operating machine or master-switch is in motion. 110
141. In a telephone system, the combination of a plurality of subscribers' lines, an individual switching means for each line having a number of switching positions, means for moving said switching means from one position to another, means for rendering all idle switching means inoperative while in motion from one position to another, said means for moving comprising a 115
- 120
- 125

motor-magnet, a ratchet mechanism operated by the magnet, a bank of contacts, a wiper operated by said ratchet mechanism and adapted to traverse said bank of contacts, automatic electrically controlled means for preventing forward actuation of the ratchet mechanism during the return movement of said wiper over one or more busy contacts to normal position or starting point, and means for making said contacts busy substantially as set forth.

142. In a telephone system, the combination of a plurality of subscribers' telephone lines, a plurality of trunk-lines, trunk selecting and connecting machinery for each line controlled by the subscribers for automatically selecting idle trunk lines for the next calling subscriber, and automatic electrically controlled means for preventing any calling subscriber from actuating the machinery for his line and accidentally securing connection with a busy trunk-line while the selecting machine is in motion, responsive to one subscriber, and in search of an idle trunk-line.

143. In a telephone system, the combination of a battery having one pole grounded, a plurality of subscribers' lines, a plurality of trunk-lines, trunk-selecting switching machinery controlled by the subscribers, provided with a bank of contacts whereof each represents one of said trunk-lines, and electrically controlled means whereby the temporary connection of a contact with either the grounded or non-grounded pole of said battery will cause said machinery to vacate such contact.

144. In a telephone system, the combination of a plurality of subscribers' individual switches, a shaft common to all of said switches, each switch having an energizing circuit, a master-switch common to all of said individual-switches and adapted for operating said shaft, provided with a relay controlling all of said energizing circuits, and circuit means for always energizing said relay while the shaft is in motion, for the purpose set forth.

145. In a telephone system, the combination of a plurality of subscribers' telephone lines, a plurality of trunk-lines, trunk-selecting and connecting machinery for each line controlled by the subscribers for automatically selecting idle trunk-lines for the next calling subscriber, and automatic means for preventing any calling subscriber from actuating the machinery for his line and accidentally securing connection with a busy trunk-line while the selecting machinery is in motion responsive to one subscriber, and in search of an idle trunk-line for the next calling subscriber, the said system being also provided with automatic means for precluding connection with a busy subscriber's line.

146. In a telephone system, the combina-

tion of a plurality of subscribers' telephone lines, a plurality of trunk-lines, and trunk-selecting switching machinery controlled by the subscribers, provided with a plurality of contacts each representing one of said trunk-lines, and circuit means by which either a positive or negative potential at any contact will cause the said machinery to vacate such contact, the said system being also provided with automatic means for precluding connection with a busy subscriber's line.

147. A telephone system comprising a trunk line, a plurality of telephone lines, each reaching the battery bus-bar via a separate path, individual magnets for closing connection between the telephone lines and said trunk line, line circuits for energizing said magnets, a common magnet, and means for energizing said common magnet to open the circuits of a plurality of said individual magnets when a subscriber calls.

148. In a telephone system, the combination of a plurality of subscribers' telephone lines, electrically controlled means having vertical motion to select groups and rotary motion to connect with a line in the selected group, a plurality of trunk-lines, electrically controlled means for automatically selecting an idle trunk-line, and circuit means for preventing forward actuation of said trunk-selecting means while the same is returning to normal position or starting point.

149. In a telephone system, the combination of means having vertical motion to select groups and rotary motion to connect with a line in the selected group, a plurality of subscribers' individual-switches, a shaft common to all of said switches, each switch having an energizing circuit, a master-switch common to all of said individual-switches and adapted for operating said shaft, provided with a relay controlling all of said energizing circuits, and circuit means for always energizing said relay while the shaft is in motion, for the purpose set forth.

150. In a telephone system, the combination of a plurality of subscribers' lines, electrically controlled means having vertical motion to select groups and rotary motion to connect with a line in the selected group, a plurality of trunk-lines, and a selectively operated individual trunking switch for each subscriber's line, said individual-switches each comprising only a single row of spring sockets and only a single plunger for operating said spring sockets, substantially as and for the purpose set forth.

151. A telephone system comprising trunk-lines, automatic means for selecting idle trunk-lines, a plurality of subscribers' telephone lines normally disconnected from each other, electrically controlled means for extending connection between two subscribers' lines, said means having one motion to

- select groups and a second motion to connect with a line in the selected group, and automatic means by which a calling subscriber opens the normal line circuit of a plurality of said telephone lines.
152. In a telephone system, subscribers' lines, trunk lines extending from said line, a switch individual to said subscribers' lines for selecting a trunk, a plunger and a bank of contacts for each switch and electrically controlled means controlled by the subscriber for operating said plunger to cause it to enter said bank, said plunger engaging certain of said bank contacts to cause them to engage other of said contacts with a rubbing or longitudinal motion, whereby the contact points are kept clean from dirt and dust.
153. In a telephone exchange system, the combination of a main or central station, sub-central stations, trunking cables connecting the main station with the sub-central stations, subscribers' telephone lines terminating at the sub-central stations, stationary individual line relays for said telephone lines, automatic means controlled by said relays for trunking a calling subscriber into the main station, automatic electrically controlled means at the main or central station for trunking the calling subscriber to the sub-central station at which the called line terminates, and circuit controlling means at the sub-central stations for completing connection with the called line, substantially as described.
154. In a telephone system, the combination of a plurality of subscribers' lines, an individual switching means for each line having a number of switching positions,
- means for moving said switching means from one position to another, means for rendering all idle switching means inoperative while in motion from one position to another, said means for moving comprising a motor magnet, a ratchet mechanism operated by said magnet, a bank of contacts, a wiper operated by said ratchet mechanism and adapted to traverse said bank of contacts, and automatic electrically controlled means for preventing forward actuation of the ratchet mechanism during the return movement of said wiper to normal position or starting point, substantially as set forth.
155. In a telephone system, a subscriber's line, a line switch allotted to said line for use in making calls, a connector switch for use in calling said line, a plunger mechanism for said line switch comprising a plunger arm, a normal short circuit for said line, a bridge cut off relay for removing said short circuit, a private normal conductor leading from said line switch to the bank of said connector switch, and means under the control of said plunger arm comprising a pair of springs whereby when said line switch is operated the bridge cut off relay is energized and a guarding potential is placed on said private normal conductor for preventing said connector from establishing connection with the line that terminates in said line switch.

Signed by me at Chicago, Cook county, Illinois, this 26th day of March, 1906.

ALEXANDER E. KEITH.
